TELEPHONE SYSTEM

Edward Sigford Peterson, Elmwood Park, Ill., assignor to Associated Electric Laboratories, Inc., Chicago, Ill., a corporation of Delaware

Application October 3, 1938, Serial No. 233,021

18 Claims. (Cl. 179—16)

The present invention relates to telephone systems and more particularly to telephone systems comprising a number of interconnected exchanges of the automatic type.

5 In a telephone system comprising a number of interconnected automatic exchanges, each exchange usually includes a plurality of automatic switching links having access to the subscriber lines terminating at the exchange and to the 10 trunk lines extending between the exchanges for setting up connections between the various lines, and a distributor for assigning idle ones of the 15 links to the use of calling ones of the lines in a predetermined order. Frequently, some of the subscriber lines terminating at each of the exchanges are of the multiparty type; and each of the 20 links in the exchange is provided with a switch operative to select characteristic sources of ringing current to be projected over the called 25 subscriber lines of the multiparty type selected by the link.

An alternating current repeater is frequently associated with each trunk line terminating at each exchange, whereby a connection between 25 two of the subscriber lines respectively terminating in two of the exchanges is set up therebetween by way of one of the trunk lines extending between the exchanges and the repeaters associated with the one trunk line in the exchanges.

30 In setting up a connection between two of the subscriber lines respectively terminating at two of the exchanges, when repeaters of this character are utilized, a repeater in the calling exchange associated with an idle trunk line extending 35 between the exchanges is controlled in accordance with switch control impulses transmitted thereto from one of the links in the calling exchange which has seized a calling line and is operative to transmit alternating current impulses over the trunk line to the called exchange. The repeater associated with the trunk line in the called exchange is operative in response to the alternating current impulses transmitted thereto to transmit switch control impulses therefrom to 40 an idle link in the called exchange, thereby to cause the link to seize the called line. Usually the release of this connection is primarily under the control of the calling line, in which event the calling line must be released in order to cause 45 the link seizing it to be released, whereupon the associated repeater in the calling exchange associated with the trunk line is released, whereby alternating current release impulses are transmitted from the repeater in the calling exchange 50 over the trunk line to the called exchange. The

repeater associated with the trunk line in the called exchange is released in response to the alternating current release impulses transmitted thereto, thereby to cause the associated link to be released in order to release the called line. From 5 the foregoing it will be apparent that this connection must be released in a particular manner, and under the control of the calling line, in order to insure that all of the apparatus utilized in setting up this connection is properly 10 released for further use.

It is noted that it is desirable that an established connection between any two of the lines in the system, whether the lines terminate in the same or different exchanges, be held only a predetermined time interval, thereby to restrict the use of an established connection to a reasonable time interval in order to minimize the amount of apparatus required in each of the exchanges and the number of trunk lines extending therebetween. Accordingly, it is desirable that automatic timing means be provided in the system in order to effect this end. A timing means of this character may be provided which is automatically operative to force the release of the apparatus utilized in establishing a connection between two lines terminating in the same exchange, in order to effectively clear out the connection. However, such a timing means would not be effective to clear out a connection established between two lines terminating in different exchanges due to the fact that the apparatus utilized in the established connection includes an alternating current repeater in each of the exchanges associated with the trunk line, which repeaters must be released under the control of the calling line, as previously explained.

Accordingly, it is an object of the present invention to provide in a telephone system comprising a number of interconnected automatic exchanges and apparatus for setting up connections between the exchanges; an improved arrangement for effecting the release of an established connection set up between the exchanges a predetermined time interval after the connection is set up.

Another object of the invention is to provide, in a telephone system of the character described comprising a number of interconnected automatic exchanges, each terminating a number of subscriber lines having subscriber substations associated therewith, and apparatus for setting up connections between the substations; an automatic arrangement for giving a warning to the subscribers at two of the substations respectively 55

associated with two of the lines respectively terminating at two of the exchanges and involved in an established communication connection set up therebetween a first predetermined time interval after the connection is set up and then for blocking the communication connection a second predetermined time interval after the connection is set up.

The features of the invention are illustrated as being incorporated in a telephone system including an automatic central office or exchange and an automatic suboffice or subexchange interconnected by a plurality of trunk lines, an alternating current repeater in each of the offices being associated with each of the trunk lines terminating thereat. Also, a number of subscriber lines, some of which are of the multiparty type, are terminated in each of the offices; and each office includes a number of switching links having access to the subscriber lines terminating thereat and to the repeater therein for setting up connections between the various lines, and a distributor for assigning idle ones of the links therein to the use of calling ones of the lines terminating thereat in a predetermined order. Each of the links, in at least the suboffice, comprises timing means including a stepping switch which is initially operative to select one of a number of characteristic sources of ringing current to be projected over a called line terminating at the suboffice and selected by the link, and which is subsequently operative after a first time interval to cause warning current to be applied to an established connection set up between two of the subscriber lines terminating at the suboffice by way of the link, and which is finally operative after a second time interval to cause the link to be released. Each of the repeaters, in at least the suboffice, comprises a timing means including a stepping switch which is operative after a first time interval to cause warning current to be applied to an established communication connection set up by way of the associated trunk line between the suboffice and the central office, and which is subsequently operative after a second time interval to cause the communication connection set up by way of the associated trunk line between the suboffice and the central office to be blocked.

In accordance with one feature of the invention the telephone system comprises first and second exchanges, a trunk line including a first portion extending to the first exchange and a second portion extending to the second exchange, means including a reactance element reactively coupled between the portions of the trunk line for establishing a two-way communication connection between the portions of the trunk line, and means in each of the exchanges for routing a connection by way of the trunk line to the other of the exchanges. Also the telephone system includes a source of warning current, a control switch operative to change the reactive coupling of the reactance element between the portions of the trunk line, thereby to block the communication connection between the portions of the trunk line, and timing means for connecting the source of warning current to a connection routed by way of the trunk line between the exchanges a first predetermined time interval after the connection is routed therebetween and for automatically operating the control switch a second predetermined time interval after the connection is routed between the exchanges.

In accordance with another feature of the in-

vention, there is provided in each of the exchanges an automatic switch having access to the trunk line extending between the exchanges, means including the automatic switches and the trunk line for setting up a two-way communication connection between the exchanges, control means for operating and for releasing the switches, and means operative to block a communication connection set up between the exchanges without releasing the automatic switches, whereby the automatic switches may be released under the control of the control means. Furthermore, the system includes timing means for automatically operating the blocking means a predetermined time interval after a communication connection is set up between the exchange.

In accordance with another feature of the invention, there is provided in the system a repeater in the second exchange connected to the trunk line extending between the exchanges, a control trunk in the second exchange associated with the repeater, and an automatic switch in the second exchange having access to a line terminating at the second exchange and to the control trunk. A two-way communication connection between the first exchange and the last-mentioned line is set up by way of the trunk line, the repeater, the control trunk, and the automatic switch. The system also includes means responsive to received impulses projected over the trunk line to the second exchange for operating the repeater, first control means responsive to the operation of the repeater for causing the automatic switch to seize the control trunk, and second control means governed by the repeater for causing the automatic switch to seize the last-mentioned line, thereby to extend a call from the first exchange to the last-mentioned line. Furthermore, the system comprises a timer included in the repeater, means responsive to the operation of the repeater for initiating a timing operation of the timer, further control means governed by the completion of the timing operation of the timer for releasing the repeater, and means responsive to the answering of the call on the last-mentioned line for terminating the timing operation of the timer.

In accordance with a further feature of the invention, the telephone system comprises a plurality of subscriber lines, a switching link operative to set up connections between the lines, first control means for causing the link to seize a calling one of the lines, second control means for causing the link to seize a called one of the lines, a number of characteristic sources of ringing current, means including a switch for selectively connecting the sources of ringing current to a called line, and means governed by the second control means for controlling the switch. Also the system comprises a source of warning current and timing means included in the switch for connecting the source of warning current to a connection established between two of the lines a predetermined time interval after the connection is set up by way of the link.

In accordance with a further feature of the invention, the system comprises timing means including the switch for connecting the source of warning current to a connection established between two of the lines a first predetermined time interval after the connection is set up by way of the link and for automatically releasing the link a second predetermined time interval after the connection is set up by way of the link.

In accordance with a further feature of the in-

invention, the system comprises a plurality of subscriber lines each including two line conductors, a number of ringing conductors individually connected to characteristic sources of ringing current, and a switch operative simultaneously to select either one of the line conductors of a called line and any one of the ringing conductors. Furthermore, the system comprises timing means including the switch for connecting the source of warning current to an established connection between two of the lines a first predetermined time interval after the connection is set up by way of the link and for automatically releasing the link a second predetermined time interval after the connection is set up by way of the link.

Further features of the invention pertain to the particular arrangement of the circuit elements thereof, whereby the above-outlined and additional features are attained.

The novel features believed to be characteristic of the invention are set forth with particularity in the appended claims. The invention, both as to its organization and method of operation, together with further objects and advantages thereof will best be understood by reference to the following specification taken in connection with the accompanying drawings in which Fig. 8 illustrates the general arrangement of a telephone system including an automatic central office and an automatic suboffice and incorporating the present invention; Figs. 1 to 7, inclusive, taken together, illustrate the details of a system having incorporated therein the features of the system, as briefly outlined above; and Fig. 9 illustrates the mode of combining Figs. 1 to 7, inclusive, of the drawings to form a unified system.

Description of the apparatus incorporated in the telephone system

Referring now more particularly to Fig. 8 of the drawings, the telephone system there illustrated comprises an automatic central office 698, an automatic suboffice 50 and a first group of two-way trunk lines extending therebetween and terminating at the suboffice, each of the lines in the first group of trunk lines being individually associated with an alternating current repeater in the suboffice 50 and provided with a control individual thereto. For example, the line 694 included in the first group of trunk lines is individually associated with the alternating current repeater 400 and is provided with a control trunk 130 individual thereto. A second group of trunk lines extending to another office, not shown, and a number of subscriber lines, including the subscriber lines 115 and 315, are terminated at the suboffice 50; and a plurality of links, including the link 60, are provided for setting up connections between the various lines. More specifically, the suboffice 50 has an ultimate capacity of one hundred lines, the first and second groups of trunk lines may each comprise ten lines, and the number of subscriber lines may comprise eighty lines. The number of lines included in the first and second group of trunk lines is determined by the amount of traffic which the suboffice 50 is required to handle and usually satisfactory service may be rendered when each of these groups of trunk lines includes three lines.

Also the automatic central office 698 comprises a number of alternating current repeaters individually associated with the lines in the first group of trunk lines extending to the suboffice

50, a number of subscriber lines terminating thereat having subscriber substations associated therewith, a plurality of links for setting up the various connections between the lines and a distributor for assigning idle ones of the links to the use of calling ones of the lines in a predetermined order. These pieces of apparatus included in the central office 698 are not shown and may be of any conventional form. However, it is preferable that these pieces of apparatus in the central office 698 are of the same form as the corresponding pieces of apparatus in the suboffice 50, described in detail hereinafter.

Each of the links may be identical to the link 60 which comprises a finder portion or switch 101 and a connector portion or switch 200, each having access to each line in the system. Preferably, the links are arranged in first and second groups, each group being provided with a distributor individual thereto for assigning idle ones of the links in the group to the use of calling lines. The number of links included in each group is determined by the amount of traffic which the suboffice 50 is required to handle and usually satisfactory service may be rendered when each of the two groups of links includes five links. For example, the first group of links including the link 60 is provided with a distributor 700. Also the lines terminating at the suboffice 50 are arranged in first and second groups which are individually associated with corresponding ones of the distributors whereby calling lines in the first group of lines are normally assigned for use idle ones of the links in the first group of links, and calling lines in the second group of lines are normally assigned for use idle ones of the links in the second group of links, thereby rendering it possible to extend simultaneously a call initiated on a line in each of the two groups of lines. Furthermore, the distributors are so connected and arranged that a call initiated on a line in the first group of lines is assigned for use an idle link in the second group of links, in the event that all of the links in the first group of links are busy; and a call initiated on a line in the second group of lines is assigned for use an idle link in the first group of links, in the event all of the links in the second group of links are busy.

The subscriber lines terminating at the suboffice 50 may comprise private automatic branch exchange or P. A. B. X. trunk lines, private lines and party lines, the subscriber lines 115 and 315 being party lines, each serving a number of subscriber substations, respectively including the subscriber substations A, B and C, D. Each of the subscriber substations is provided with a telephone instrument, a dial mechanism and a ringer, the character of the ringer being determined by the type of ringing utilized in the system. The system is connected and arranged so that either code or harmonic ringing may be employed and the ringing circuit may be of the divided or bridged type, as is more fully explained subsequently. A line circuit is individually associated with each of the subscriber lines, the trunk lines and the alternating current repeaters, the line circuits individually associated with the subscriber line 115 and the alternating current repeater 400 being respectively indicated at 100 and 500. Each of the line circuits includes a line relay, a cut-off relay and a lock-out relay, these relays in the line circuit 100 being respectively indicated in Fig. 1 at R155, R160 and R150.

Preferably each of the links is connected and arranged in a manner similar to that of the link 60 which comprises the finder switch 101 and the connector switch 200, each of these switches including a switching mechanism of the Strowger type. The Strowger mechanism included in the finder switch 101, as best shown in Fig. 1, comprises a bank of fixed contacts 102 arranged in ten vertical levels, each level including ten radial-10 ly disposed contact sets, each terminating a line extending thereto, a wiper set associated with the contact bank 102 and carried by a carriage movable in both vertical and rotary directions, a row of fixed contacts 104 arranged in vertical alignment, each terminating a control conductor, and a contact wiper associated with the row of contacts 104 and carried by the movable carriage. Also this Strowger mechanism includes a vertical magnet M105 for moving the carriage in 15 the vertical direction, a rotary magnet M106 for moving the carriage in the rotary direction, and a release magnet M107 for releasing the carriage and returning it to its normal position. Also associated with this Strowger mechanism are a set 20 of switch springs 108, which are actuated by the movement of the carriage in a vertical direction away from its normal position, and a set of switch springs 109 which are actuated by the movement of the carriage into the eleventh radial 25 position. Also the finder switch 101 comprises a switching relay R180 and a control relay R190. The Strowger mechanism included in the connector switch 200, as best shown in Figs. 2 and 3, comprises a bank of fixed contacts 300 arranged in ten vertical levels, each level including ten radially disposed contacts sets, each terminating a line extending thereto, and a wiper set associated with the contact bank 300 and carried by a carriage movable in both vertical 30 and rotary directions. Also this Strowger mechanism includes a vertical magnet M201 for moving the carriage in the vertical direction, a rotary magnet M346 for moving the carriage in the rotary direction, and a release magnet M344 for 35 releasing the carriage and returning it to its normal position. Also associated with this Strowger mechanism are two sets of switch springs 209 and 345 which are actuated by the movement of the carriage in the vertical direction 40 away from the normal position, two sets of switch springs 210 and 338 which are actuated by the movement of the carriage in a vertical direction to the level of contacts in the contact bank 300 terminating the lines in the second group of 45 trunk lines, and a set of switch springs 249 which are actuated by the movement of the carriage in the vertical direction to the level of contacts in the contact bank 300 terminating the lines in the first group of trunk lines. It is noted that 50 the first group of trunk lines terminate in the tenth level of contacts in the contact bank 300 of this Strowger mechanism; the second group of trunk lines terminate in the ninth level of contacts in the contact bank 300 of this mechanism; and the subscriber lines terminate in the 55 first to the eighth, inclusive, levels of contacts in the contact bank 300 of this mechanism. Furthermore, it is noted that the Strowger mechanism included in the connector switch 200 is of the automatic trunk hunting type; viz., an idle line in the first group of trunk lines is seized thereby when the single digit 0 is dialed into the connector switch 200, and an idle line in the second group of trunk lines is seized thereby when the first digit 9 followed by a predetermined sec-

ond digit is dialed into the connector switch 200. Also a particular subscriber line is seized and rung by the connector switch 200 when the three digits corresponding to the directory number of the particular subscriber line are successively dialed into the connector switch, regardless of whether the particular subscriber line is the calling subscriber line, which is seized on a reverting call, or an independent subscriber line. In calling a particular subscriber line, the first 10 and second digits dialed into the connector switch 200 correspond to the position of the subscriber line in the contact bank 300 of the Strowger mechanism included therein, while the third digit dialed into the connector switch determines the 15 character of the ringing current to be projected over the seized line and the type of ringing circuit to be used, as is more fully explained subsequently. The connector switch 200 also comprises a 20 minor switch 325 which includes three rotary switches 326, 330 and 334, each including a contact bank and an associated wiper, the contact banks of these switches being indicated, respectively, at 329, 333 and 331, and the associated 25 wipers thereof being indicated, respectively, at 327, 331 and 335. The minor switch 325 also includes a rotary magnet M345 for driving the wipers of the rotary switches and a release magnet M343 for releasing the minor switch so that the wipers of the rotary switches may be automatically returned to their normal positions. Also associated with the minor switch 325 is a set of switch springs 339 which are actuated by the movement of the wipers of the rotary switches 30 thereof away from their normal position. The minor switch 325 is utilized to select the particular frequency or code of the ringing current, depending upon whether harmonic or code ringing is employed in the system, to be projected over a line seized by the connector switch 200 and to select the particular conductor over which the ringing current is to be projected in the event a divided ringing circuit is employed 40 in the system. Certain alternative wiring is provided including the wiring illustrated at "X" and "Y" in Fig. 3, which is connected in a manner more fully described subsequently in order to accommodate the use of the connector switch 200 to different types of ringing employed in the 45 system. More particularly, the "X" wiring is utilized when code ringing is employed in the system and comprises a connection between the ring pick-up lead C822 and the front contact associated with the armature RA399 of the 50 switching relay R395. On the other hand, the "Y" wiring is utilized when harmonic ringing is employed in the system and comprises a connection between ground potential and the front contact associated with the armature RA399 of 55 the switching relay R395. Furthermore, the connector switch 200 comprises a group of relays and their control and controlled circuits, this group of relays including a line relay R260, a hold relay R265, a cut-through relay R240, a battery reversing relay R250, a ring cut-off relay R360, a test relay R370, a ring control relay R390, a switching relay R395, and a number of control relays R210, R220, R225, R230, R270, R280, R345, R350, R355, R380 70 and R385.

A first timing arrangement is incorporated in the connector switch 200 which causes the connector switch to be released and a calling line associated therewith to be locked out, in the 75

event the connector switch is not completely operated to select a line terminating therat, after it has been seized by the calling line. A second timing arrangement is incorporated in the connector switch 200 which is operative to warn the subscribers that an established connection including the subscribers' substations has been held a predetermined time interval, and then to release automatically the established connection and to lock the calling and called lines out in the event the established connection is held an additional time interval.

A signaling arrangement is incorporated in the connector switch 200 which is operative to actuate an alarm in the event that either the Strowger mechanism or the minor switch included therein fails to restore completely after it has been released.

Preferably, each of the distributors is connected and arranged in a manner similar to that of the distributor 700 individually associated with the first group of links which comprises, as best shown in Fig. 7, a rotary switch 701 including four banks of fixed contacts and four wipers individually associated therewith, the corresponding contacts in each bank terminating the control conductors extending to the respective links in the first group of links and the wipers terminating the control conductors extending to the distributor. Also the rotary switch 701 includes a rotary magnet M701 for driving the wipers associated with the contact banks. The distributor 700 also comprises a start relay R720, a switch-over relay R710, a test relay R730, a number of control relays R715, R735, R740, R750, R755 and R760, and the control and controlled circuits therefor.

Also associated with the distributor 700 are a signal lamp 722, which is illuminated in the event the finder switch of the link assigned by the distributor to the use of a calling line does not find the calling line within a predetermined time interval, and a signal lamp 723 which is illuminated in the event that the carriage of the Strowger mechanism included in the finder switch of a link employed in an established connection does not restore to its normal position incident to the release of the established connection. A counting meter M724 is associated with the distributor 700 in order to count the number of calls which are extended by way of the links in the first group of links associated with this distributor.

The distributor 700 is so connected and arranged that a second idle link in the first group of links is assigned to the use of a calling line in the first group of lines, in the event that a first idle link in this group assigned thereto fails to find the calling line during the course of operation thereof. Also a testing arrangement comprising a switch 782 is provided in the distributor 700 in order to provide for automatic testing of the finder switch of each link in the first group of links.

The distributor 700 is of the preselective type in that an idle link in the first group of links is selected to be assigned to the use of a calling line in the first group of lines prior to the initiation of a call on a line therein, and another idle link in the first group of links is automatically selected to be assigned to the use of the next calling line in the first group of lines as soon as the selected link operates to find a calling line in the first group of lines. Also the distributor 700 is so connected and arranged that

when all of the links in the first group of links are busy the start circuit of the distributor 700 is transferred to the distributor associated with the second group of lines, whereby the second-mentioned distributor assigns idle ones of the 5 links in the second group of links to the use of the calling lines in the first group of lines.

Preferably, each of the alternating current repeaters is connected and arranged in a manner similar to that of the alternating current repeater 400 which comprises, as best shown in Figs. 4 to 6, inclusive, a transformer 600, a control trunk 130 having a line circuit 500 individual thereto, and a minor switch 625 including two rotary switches 615 and 618. Also the minor switch 625 includes a rotary magnet M612 for driving the wipers thereof, and a release magnet M613 for returning the wipers thereof to their normal positions. The minor switch 625 comprises a portion of an arrangement for warning 20 the subscribers holding an established connection including the repeater 400 that the established connection has been held for a predetermined time interval and then for automatically interrupting the established connection including the 25 repeater 400 after an additional time interval.

The repeater 400 also comprises a line relay R405, a battery reversing relay R410, two impulse relays R420 and R680, a timer start relay R450, two switching relays R460 and R550, an answer relay R565, a ring-up relay R630, a group of control relays R425, R430, R435, R440, R445, R455, R505, R510, R515, R520, R525, R530, R535, R540, R560, R625, R635, R640, R645, R650 and R670, 30 the control and controlled circuits therefor, and three impedance elements Z403, Z503 and Z655. In addition to the two-way trunk line 694, two incoming trunk lines 320 and 486 are associated with the repeater 400, the line 320 being employed when battery reversing supervision on 40 the calling line is utilized and the line 486 being employed when this type of supervision is not utilized.

Ordinary substation to substation calls within the 45 suboffice

An ordinary call which is to be extended from one subscriber substation to another within the suboffice is initiated at the calling substation by removing the receiver of the telephone instrument thereof from its hook. For example, in extending a call from the subscriber substation A to the subscriber substation C within the suboffice 50, the call is first initiated at the substation A by removing the receiver of the telephone instrument thereof from its hook, thereby to complete a bridge path at the telephone instrument at the substation A between the line conductors C116 and C117 of the subscriber line 115 extending to the substation A. When this bridge path is completed between the line conductors of the subscriber line 115 a circuit is completed for energizing the line relay R155 in the line circuit 100 individually associated with the subscriber line 115, which extends from battery at the upper 55 winding of R155 by way of the upper winding of R155, RA162, C116, the bridge path between C116 and C117, C117, RA163, and the lower winding of R155 to ground. When energized over the above-traced circuit the line relay R155 operates 60 to complete, at RA156, an obvious path for applying direct ground potential to the control conductor C119 of the subscriber line 115 extending from the connector switches of the links having 65 access thereto, thereby to mark the subscriber 70 75

line 115 as busy to the connector switches. Also the line relay R155 completes, at RA158, a path for applying ground potential to the conductor C135, thereby to mark with ground potential in 5 the contact banks of the Strowger mechanisms included in the finder switches of the first group of links, the level in which the subscriber line 115 is terminated, and for applying ground potential to the start lead C137 extending to the distributor 10 700 individually associated with the first group of links. The path for marking the level in the contact bank 104 of the Strowger mechanism included in the finder switch 101 of the link illustrated extends from ground, at RA158, 15 by way of RA153 and the back contact associated therewith, C135 and C135' to the contact 104' in the contact bank 104. The path for applying ground potential to the start lead C137, extending to the distributor 700, extends from ground, 20 at RA158, by way of RA153 and the back contact associated therewith, C135, and the resistor 195 to the start conductor C137. It is noted that the contact 104' is the first contact in the contact bank 104 of the Strowger mechanism included in 25 the finder switch 101. Accordingly, the subscriber line 115 is terminated in the first level in the contact banks of the Strowger mechanisms included in the finder switches of the first group of links. Also, upon operating, the line relay 30 R155 completes, at RA157, a path for applying battery potential to the control conductor C118 of the subscriber line 115, thereby to mark the radial position of the contact sets in the contact banks of the Strowger mechanisms included in 35 the finder switches of the links terminating the subscriber line 115. This path for applying battery potential to the control conductor C118 extends from battery at the winding of the cut-off relay R160 by way of the winding of R160, RA151, 40 and RA157 to C118.

This application of ground potential to the start lead C137 extending to the distributor 700 completes a circuit for energizing the start relay R1720, which extends from the grounded start lead C137 by way of RA113 and the front contact associated therewith, and the winding of R1720 to battery. When energized over the 45 above-traced circuit the start relay R1720 operates to initiate operation of the distributor 700, 50 thereby to cause the idle one of the links in the first group, previously selected by the distributor 700, to be assigned to the use of the calling subscriber line 115. More particularly, upon operating, the start relay R1720 prepares, at RA171, 55 a circuit for illuminating the signal lamp 722, which circuit is completed by apparatus, not shown, in the event the start relay R1720 remains operated for a predetermined time interval indicating that the calling subscriber line 115 has 60 not been seized by the finder switch of a link in the first group of links within a predetermined time interval. Also the start relay R1720 completes, at RA1720, a circuit for energizing the rotary magnet M701 of the rotary switch 701 65 in series with the relay R1740, this circuit extending from ground, at RA1758, by way of RA1732, RA1720, the winding of R1740, RA1711, the self-interrupting contact MA701 of the rotary magnet M701, and the winding of M701 to battery. When 70 the above-traced series circuit is completed the rotary magnet M701 does not operate due to the high series resistance of the winding of the relay R1740. However, the relay R1740 operates. Upon operating, the relay R1740 prepares, at 75 RA1741, a holding circuit, traced hereinafter, for

energizing the winding thereof and completes, at RA1743, a path for applying ground potential to the control conductor C740, thereby to initiate operation of the finder switch of the previously selected idle link in the first group. Assuming 5 that the illustrated link 60 in the first group of links is the idle link previously selected by the distributor 700, this application of ground potential to the control conductor C740 completes a circuit for energizing the relay R190 in the 10 finder switch 101 of this link, this circuit extending from the grounded control conductor C740 by way of the wiper 704 and the associated contact 708 in the rotary switch 701, the conductor C144, and the winding of R190 to battery. 15 Also the relay R740 prepares, at RA1742 and the front contact associated therewith, a circuit, traced hereinafter, for energizing the rotary magnet M701 of the rotary switch 701, and completes, at RA1741, a holding circuit for energizing 20 the relay R710, the latter circuit extending from ground, at RA1741, by way of C762 and the winding of R710 to battery. This holding circuit for the relay R710 retains this relay in its operated position during the operation of the distributor 25 700, thereby to prevent the relay R710 from restoring in the event that the link 60 is the last idle link in the first group of links. Also, upon operating, the relay R740 completes, at RA1746, an 30 obvious circuit for energizing the relay R150, prepares, at RA1744, a circuit traced hereinafter for energizing the vertical magnet M105 of the Strowger mechanism included in the finder switch 101, and prepares, at RA1745, a circuit traced hereinafter for energizing the upper winding of 35 the test relay R730.

When energized the relay R150 operates to complete, at RA1751, the holding circuit for energizing the relay R740, this circuit extending from ground, at RA1751, by way of RA1747, the winding of R740, RA1711, the self-interrupting contacts MA701 of the rotary magnet M701, and the winding of M701 to battery. Also the relay R750 prepares, at RA1751, a holding circuit for energizing the lower winding of the test relay 40 R730, and sets its own weighted armature RA1752 into vibration, thereby to complete intermittently, at RA1752, the circuit for energizing the lower winding of the relay R755, this circuit extending, when completed, from ground, at RA1752, by way of WA1752, RA1734, and the lower winding of R755 45 to battery. The relay R755 is of the slow-to-operate type and does not operate at this time due to this characteristic and the fact that the circuit for energizing the lower winding thereof is only intermittently completed, at RA1752 and WA1752.

When energized over the previously traced circuit the relay R190 in the finder switch 101 operates to interrupt, at RA194 and the back contact associated therewith, the path for applying ground potential in the finder switch 101 to the all trunks busy conductor C142. At this time multiple ground potential in the remaining idle links in the first group of links is applied to the 6 all trunks busy conductor C142, thereby to retain the relay R710 in its operated position subsequent to the restoration of the relay R1740 to interrupt, at RA1741, the holding circuit of the relay R710. Also the relay R190 completes, at 7 RA194 and the front contact associated therewith, an obvious path for applying ground potential to the control conductor C123 extending from the finder switch 101 into the associated connector switch 200. This application of ground po- 7

tential to the control conductor C123 also prepares a circuit traced hereinafter for energizing the lower winding of the relay R180. Further the relay R190 interrupts, at RA193 and the back contact associated therewith, the connection between the control conductor C123 and the guard conductor C741, thereby to prevent the operation of the rotary magnet M701 of the rotary switch 701 in the distributor 700 prior to the operation 10 of the finder switch 101 to seize the calling subscriber line 115, this connection between the control conductor C123 and the guard conductor C741, prior to interruption, extending from the control conductor C123 by way of the switch springs 111 and 110 of the vertical off-normal springs 108, RA193 and the back contact associated therewith, and C143 to the guard conductor C741. Further the relay R190 prepares, at RA192, and at RA193 and the front contact associated therewith, a circuit traced hereinafter for energizing the rotary magnet M701 of the rotary switch 701 in the distributor 700 subsequent to the operation of the finder switch 101 to seize the calling subscriber line 115, and prepares, at 15 RA192, a circuit traced hereinafter for energizing the rotary magnet M106 of the Strowger mechanism included in the finder switch 101. Finally the relay R190 completes, at RA191, a circuit for energizing the vertical magnet M105 of the 20 Strowger mechanism included in the finder switch 101, this circuit extending from ground, at RA758, by way of RA744, RA761, RA731 and the back contact associated therewith, C142, the wiper 705 and associated contact 709 of the rotary switch 701, C145, RA191, and the winding of M105 to battery.

When energized over the above-traced circuit the vertical magnet M105 operates to move the carriage of the Strowger mechanism included in 25 the finder switch 101 one step in the vertical direction, and to complete, at MA105, a circuit for energizing the relay R760, this circuit extending from ground, at MA105, by way of C146, and the winding of R760 to battery. Also, at 30 MA105, the vertical magnet M105 prepares a circuit for short-circuiting the upper winding of the test relay R730, this circuit extending, when completed, from ground, at MA105, by way of C146, RA745, the upper winding of R730, RA733 and the back contact associated therewith, C743, 35 the wiper 702 and associated contact 706 of the rotary switch 701, C140, and the control wiper to the associated grounded contact in the row of contacts 104 in the contact bank of the Strowger mechanism included in the finder switch 101. When the carriage of the Strowger mechanism included in the finder switch 101 is moved one step in the vertical direction, the vertical off-normal springs 108 associated therewith are actuated, thereby to prepare, at the switch springs 113 and 112 thereof, a circuit traced hereinafter for energizing the release magnet M107 of the Strowger mechanism included in the finder switch 101, and to prepare, at the contact springs 110 and 110' thereof, a circuit traced hereinafter for energizing the rotary magnet M701 of the rotary switch 701 by way of the guard conductor C741. When energized over the above-traced circuit the relay R760 operates to interrupt, at 40 RA761, the previously traced circuit for energizing the vertical magnet M105 of the Strowger mechanism included in the finder switch 101. The vertical magnet M105 then restores to interrupt, at MA105, the previously traced circuit for 45 energizing the relay R760 and the previously traced prepared path for short-circuiting the upper winding of the relay R730. The relay R760 then restores to recomplete, at RA761, the previously traced circuit for energizing the vertical magnet M105 of the Strowger mechanism included in the finder switch 101. The vertical magnet M105 and the relay R760 continue to interact, as described above, until the carriage of the Strowger mechanism included in the finder switch 101 is moved in a vertical direction to the 50 level in which the calling subscriber line is terminated. In the present instance the calling subscriber line 115 is terminated in the first level. Accordingly, the vertical magnet M105 of the Strowger mechanism included in the finder switch 101 is energized only once, thereby to cause the carriage of the Strowger mechanism to be moved in the vertical direction only one step, at which time the control wiper carried thereby engages the contact 104' in the row of contacts 55 104 in the contact bank of the Strowger mechanism, thereby to complete a circuit for energizing the upper winding of the test relay R730 in series with the winding of the relay R760. This circuit extends from ground, at RA158, by way of RA153 and the back contact associated therewith, C135, C135', the contact 104', the control wiper associated therewith, C140, the wiper 702 and associated contact 706 of the rotary switch 701, C743, RA733 and the back contact associated 60 therewith, the upper winding of R730, RA745, and the winding of R760 to battery. During the pulsing of the vertical magnet M105 of the Strowger mechanism included in the finder switch 101, the relay R755 does not operate due to its slow-to-operate characteristic and to the fact that the circuit for energizing the lower winding thereof is only intermittently completed, at RA752 and WA752. When energized over the above-traced circuit the relay R760 remains operated, and the relay R730 partially operates to 65 close its "X" contacts associated with its armature RA733', thereby to complete a holding circuit for energizing the lower winding of R730, this circuit extending from ground, at RA751, by way of RA733', and the lower winding of R730 to battery. When this holding circuit is completed, the relay R730 completely operates to interrupt, at RA732, the original circuit for energizing the relay R740, and interrupts, at RA733 70 and the back contact associated therewith, the circuit for energizing the relay R760, thereby to cause the latter relay to restore. Also the relay R730 prepares, at RA733 and the front contact associated therewith, a circuit traced hereinafter for energizing the upper winding of the switching relay R180. Further the relay R730 interrupts, at RA731 and the back contact associated therewith, a point in the circuit for energizing the vertical magnet M105 of the Strowger mechanism included in the finder switch 101, thereby to prevent further vertical movement of the carriage of this Strowger mechanism, and completes, at RA731 and the front contact associated therewith, a circuit for energizing the rotary magnet M106 of the Strowger mechanism included in the finder switch 101 subsequent to the restoration of the relay R760, the latter circuit extending from ground, at RA758, by way of RA744, RA761, RA731 and the front contact associated 75 therewith, C141, RA192, RA184 and the back contact associated therewith, and the winding of M106 to battery. Also the relay R730 completes, at RA733', a circuit for energizing the relay R735, this circuit extending from ground, at RA751, 75

by way of RA133', and the winding of R135 to battery. Finally, the relay R130 interrupts, at RA134, a point in the circuit for energizing the lower winding of the relay R155. When energized over the above-traced circuit the relay R135 operates to set its weighted armature WA136 into vibration, thereby to complete intermittently, at RA136, a circuit for energizing the upper winding of the relay R155, this circuit extending from ground, at RA136, by way of WA136, and the upper winding of R155 to battery. As the field produced by the upper winding of the relay R155 is in opposition to that originally produced by the lower winding thereof, and the facts that the relay R155 is of the slow-to-operate type and the circuit for energizing the upper winding thereof is only intermittently completed, at RA136 and WA136, operation of this relay is further delayed.

When the rotary magnet M106 of the Strowger mechanism included in the finder switch 101 is energized over the previously traced circuit, it

operates to rotate the carriage thereof one step in the radial direction, and to complete, at MA106, a circuit for energizing the relay R160, this circuit extending from ground, at MA106, by way of C146, and the winding of R160 to battery. The relay R160 then operates to interrupt, at RA161, the circuit for energizing the rotary magnet M106, thereby to cause the rotary magnet M106 to restore and interrupt, at MA106, the circuit for energizing the relay R160. The relay R160 then restores to complete, at RA161, the circuit for energizing the rotary magnet M106, thereby to cause the rotary magnet M106 to operate and rotate the carriage of the Strowger mechanism included in the finder switch 101 a further step in the radial direction, and to complete, at MA106, the circuit for energizing the relay R160. The rotary magnet M106 and the relay R160 continue to interact, as described above, thereby to cause the carriage of the Strowger mechanism included in the finder switch 101 to be rotated step by step in the rotary direction until the wipers carried by the carriage thereof engage the contacts in the contact bank 102 of the Strowger mechanism terminating the calling subscriber line 115. As previously noted the relay R155 is of the slow-to-operate type and does not operate during the pulsing of the rotary magnet M106.

When the wipers carried by the carriage of the Strowger mechanism included in the finder switch 101 engage the contacts in the contact bank 102 thereof terminating the calling subscriber line 115, a circuit is completed for energizing the upper winding of the switching relay R180, this circuit extending from ground, at RA133, and the front contact associated therewith, by way of C143, the wiper 702 and associated contact 706 of the rotary switch 701, C140, the upper winding of R180, the control conductor C126, the wiper carried by the carriage of the Strowger mechanism terminating this control conductor, the contact in the contact bank 102 terminating the control conductor C118 of the calling subscriber line 115, C118, RA157, RA151, and the winding of R160 to battery. When energized over the above-traced circuit the relay R180 operates to connect, at RA181 and at RA182, the conductors C124 and C125, respectively, to the conductors C121 and C122 of the trunk line 120 extending between the finder switch 101 and the connector switch 200, thereby to connect the calling subscriber line 115 through to the connector switch 200, and to interrupt, at

RA184 and the back "X" contact associated therewith, a point in the circuit for energizing the rotary magnet M106 in the Strowger mechanism included in the finder switch 101, thereby to prevent further operation of the rotary magnet M106. Also the relay R180 completes, at RA184 and the front contact associated therewith, a holding circuit for energizing the lower winding thereof in series with the winding of the rotary magnet M106, this circuit extending from the grounded control conductor C123 by way of the lower winding of R180, RA184 and the front contact associated therewith, and the winding of the rotary magnet M106 to battery. When the rotary magnet M106 is energized over the above-traced circuit it does not operate due to the high series resistance of the lower winding of the relay R180. Further the relay R180 completes, at RA183, an obvious connection between the grounded control conductor C123 and the control conductor C126.

When direct ground, as applied to the control conductor C123, is applied to the control conductor C126, the winding of the cut-off relay R160 is energized by way of a circuit extending from the grounded control conductor C126, C118, RA157, RA151, and the winding of R160 to battery. When energized over the above-traced circuit the cut-off relay R160 operates to complete, at RA161, a holding circuit for itself extending from the grounded control conductor C118 by way of RA161, and the winding of R160 to battery. Also the cut-off relay R160 interrupts, at RA162 and at RA163, points in the bridge path for energizing the line relay R155, thereby to free the subscriber line 115 of impedance elements, and to cause the line relay R155 to restore. Further the cut-off relay R160 completes, at RA164 and the front contact associated therewith, a connection between the control conductor C118 and the paystation tone lead C147 in the event that the subscriber substation A is of the paystation type, this connection extending from the paystation tone lead C147 by way of the condenser 148, RA164 and the front contact associated therewith, and RA161 to the control conductor C118 of the subscriber line 115. In the event the subscriber substation A is of the paystation type, paystation tone current is projected over the control conductor C118 of the subscriber line 115 by way of the operated finder switch 101 into the associated connector switch 200 for a purpose more fully described subsequently. Finally, the cut-off relay R160 completes, at RA165 and the front contact associated therewith, an obvious circuit for energizing the lockout relay R150. Upon restoring, the line relay R155 interrupts, at RA158, a point in the path for applying ground potential to the start lead C137 extending into the distributor 700, and in the path for applying marking ground potential to the conductor C135' terminated by the contact 104' in the contact bank 104 of the Strowger mechanism included in the finder switch 101. When thus energized, the lock-out relay R150 operates to interrupt, at RA153 and the back contact associated therewith, a further point in the paths for applying ground potential to the start lead C137 and the conductor C135'. Also, upon restoring, the relay R155 completes, at RA156 and the back contact associated therewith, a path for applying ground potential from the control conductor C118 of the subscriber line 115 extending to the finder switch 101 to the control conductor C119 of the subscriber line 115 extending

to the contact banks of the Strowger mechanisms included in the connector switches of the links having access to the subscriber line 115, thereby to mark this subscriber line as busy. The last-mentioned path extends from the grounded control conductor C118 by way of RA161 and RA156 and the back contact associated therewith, to the control conductor C119.

Furthermore, upon operating, the relay R180 completes, at RA185, a circuit for energizing the rotary magnet M701 of the rotary switch 701 in the distributor 700, this circuit extending from ground, at RA758, by way of RA744, RA761, RA731, and the front contact associated therewith, C141, RA192, RA185, RA193, and the front contact associated therewith, C143, the wiper 703 and associated contact 707 of the rotary switch 701, C741, RA742 and the front contact associated therewith, and the winding of M701 to battery. Also, at RA185, the relay R180 completes a path for short-circuiting the relay R740, this path extending from ground, at RA751, by way of RA741, the winding of R740, RA711, the self-interrupting contacts MA701 of the rotary magnet M701, RA742 and the front contact associated therewith, C741, the wiper 703 and associated contact 707 of the rotary switch 701, C143, RA193 and the front contact associated therewith, RA185, RA192, C141, RA731 and the front contact associated therewith, RA761, and RA744 to ground, at RA758. When the relay R740 is thus short-circuited it restores to interrupt, at RA747, a point in its holding circuit; and when the rotary magnet M701 is energized over the above-traced circuit it operates to interrupt, at MA701, a point in the original circuit for energizing the relay R740.

At this time, if no other calls have been initiated in the group of subscriber lines including the subscriber line 115 when ground potential is moved from the start lead C137, the start relay R720 restores. Upon restoring, the relay R720 interrupts, at RA720, a further point in the original circuit for energizing the relay R740, and interrupts, at RA721, a point in the prepared circuit for illuminating the signal lamp 722. Upon restoring, the relay R740 interrupts, at RA743, the circuit for energizing the relay R190. However, the relay R190, being of the slow-to-release type, does not restore immediately. Also, upon restoring, the relay R740 interrupts, at RA742 and the front contact associated therewith, a point in the previously traced circuit for energizing the rotary magnet M701 of the rotary switch 701, and prepares, at RA742 and the back contact associated therewith, an alternative circuit traced hereinafter for energizing the rotary magnet M701 of the rotary switch 701. Further, the relay R740 interrupts, at RA746, the circuit for energizing the relay R750, and interrupts, at RA741, the holding circuit for the switch over relay R710. At this time the relay R710 remains operated only in the event there is an idle link in the first group of links. The relay R750 then restores to interrupt, at RA752 and WA752, a further point in the circuit for energizing the lower winding of the relay R755, and interrupts, at RA751, the circuit for energizing the relay R735, and the holding circuit for energizing the lower winding of the relay R730.

When the original circuit for energizing the rotary magnet M701 of the rotary switch 701 is interrupted at RA742 and the front contact associated therewith upon the restoration of the relay R740, the rotary magnet M701 restores in order

to drive the wipers 702, 703, 704, and 705 of the rotary switch 701 one step and into engagement with the next set of contacts terminating the control conductors of the next link in the first group of links. Upon restoring, the rotary magnet M701 also prepares, at its self-interrupting contacts MA701, a point in the original circuit for energizing the relay R740. The test relay R130 then restores, thereby to interrupt, at RA733 and the front contact associated therewith, the path for applying ground potential to the test conductor C743, and to prepare, at RA733 and the back contact associated therewith, the original circuit for energizing the upper winding of the relay R730. Also, upon restoring, the relay R130 interrupts, at RA731 and the front contact associated therewith, a further point in the circuit for energizing the rotary magnet M106 of the Strowger mechanism included in the finder switch 101, and prepares, at RA731 and the back contact associated therewith, a point in the circuit for energizing the vertical magnet M105 of this Strowger mechanism. After a predetermined time interval the relay R190 restores to interrupt, at RA191, a further point in the circuit for energizing the vertical magnet M105 of the Strowger mechanism included in the finder switch 101, to interrupt, at RA192, a further point in the original circuit for energizing the rotary magnet M106 of this Strowger mechanism, and to interrupt, at RA194 and the front contact associated therewith, the path for applying multiple ground potential to the control conductor C123, ground potential being applied to the control conductor C123 at this time in the connector switch 200 associated with the finder switch 101 in a manner more fully described subsequently. Finally, upon restoring, the relay R190 prepares, at RA194 and the back contact associated therewith, a point in a circuit traced hereinafter for energizing the release magnet M107 of the Strowger mechanism included in the finder switch 101, this circuit being interrupted at this time, at RA186 of the operated relay R180, and completes, at RA193 and the back contact associated therewith, a path for applying ground potential to the guard conductor C143, this path extending from ground at the switch spring 110 of the vertical off-normal springs 108 associated with the Strowger mechanism included in the finder switch 101 by way of the switch spring 110 and RA193 and the back contact associated therewith, to the guard conductor C143. This application of ground potential to the guard conductor C143 marks the finder switch 101 of the link 60 as busy 55 to the distributor 700.

At this time the wipers 702, 703, 704, and 705 of the rotary switch 701 in the distributor 700 engage the control conductors extending to the finder switch of the next link in the first group of links, and if this link is busy, ground potential appears upon the guard conductor thereof, thereby to complete a path for applying ground potential to the guard conductor C741. This application of ground potential to the guard conductor C741 completes a circuit for energizing the rotary magnet M701 of the rotary switch 701, this circuit extending from the grounded guard conductor C741, by way of RA742 and the back contact associated therewith, RA711, the self-interrupting contacts MA701 of the rotary magnet M701, and the winding of M701 to battery. Also, this application of ground potential to the guard conductor C741 prepares a point in a path for short-circuiting the winding of the relay R740, thereby 75

- to prevent the latter relay from operating upon operation of the relay R720 incident to the initiation of another call in the group of subscriber lines served by the distributor 700 prior to the 5 operation of the distributor 700 to select an idle link in the first group of links for the use of a calling line. When energized over the above-traced circuit the rotary magnet M701 operates to move the wipers noted of the rotary switch 701 into engagement with the contacts thereof terminating the control conductor of the next link in the first group of links. In the event this link is also busy, ground potential appears upon the guard conductor thereof, thereby to cause the rotary magnet M701 to again operate, as described above. The rotary magnet M701 continues to operate, as described above, until the wipers noted of the rotary switch 701 engage a contact set therein terminating the control conductors of 10 a finder switch of an idle link in the first group of links, at which time the circuit for energizing the rotary magnet M701 is interrupted due to the absence of ground potential upon the guard conductor of the finder switch of this idle link. At 15 this time the distributor 700 is completely released and in condition to assign the selected idle link in the first group of links to the use of a calling line when the next call is initiated on a line in the first group of lines served by the distributor 700. 20
- Should a call be initiated on a line in the first group of lines prior to the operation of the distributor 700 to select an idle link in the first group of links, the start relay R720 operates, as 25 previously explained. However, operation of the relay R720 at this time is ineffective to cause the relay R740 to operate as the latter relay remains short-circuited due to the presence of ground upon the guard conductor C141, as previously noted, so long as the wipers of the rotary switch 701 in the distributor 700 encounter contacts 30 thereof terminating control conductors of finder switches associated with busy links in the first group of links.
- As previously noted, upon the operation of the 35 switching relay R180 incident to the seizure of the calling subscriber line 115 by the finder switch 101 of the link 60, the relay R740 is short-circuited and restores. Upon restoring, the relay 40 R740 interrupts, at RA711, the holding circuit for the switch over relay R710, which latter relay is retained in its operated position only in the event that there are other idle links in the first group of links, due to the fact that ground potential is 45 applied to the all trunks busy conductor C142 only in the event there are other idle links in the first group of links. At this time, in the event all of the links in the first group of links are busy, the relay R710 restores. Upon restoring, the relay 50 R710 interrupts, at RA713 and the front contact associated therewith, the connection between the start lead C137 and the start relay R720, thereby to prevent the distributor 700 from being started into operation when the next call in the 55 group of lines served thereby is initiated on one of these lines. Also, upon restoring, the relay R710 connects, at RA713 and the back contact associated therewith, the start lead C137 to the conductor C165' extending to the distributor individually associated with the second group of lines, thereby rendering the last-mentioned distributor effective to assign an idle link in the second group of links to the use of a calling line in the first group of lines while all of the links in the first group of lines are busy. The operation of 60

the distributor individually associated with the second group of lines to assign a previously selected idle link in the second group of links to the use of a calling line in the first group of lines is otherwise the same as the operation of the distributor 700, previously described. Also, upon restoring, the relay R710 interrupts, at RA711, a point in the circuit for energizing the rotary magnet M701 by way of the guard conductor C141, thereby to prevent unnecessary operation of the rotary magnet M701 when all of the links in the first group of links are busy. 10

In the foregoing description of the operation of the finder switch 101 of the link 60 it was assumed that the carriage of the Strowger mechanism included therein was rotated step by step until the wiper carried by the carriage thereof encountered the contact in the contact bank 102 thereof terminating the control conductor C118 of the calling subscriber line 115, at which time the switching relay R180 was operated to interrupt the circuit for energizing the rotary magnet M106 of the Strowger mechanism included in the finder switch 101, thereby to arrest further rotary movement of the carriage of this Strowger mechanism, and to connect the calling subscriber line through to the connector switch 200, as previously noted. However, should the wipers carried by the carriage of this Strowger mechanism fail to encounter the contact in the contact bank 102 terminating the control conductor C118 of the calling subscriber line 115 or to make imperfect contact therewith such that the switching relay R180 fails to operate, the rotary magnet M106 of this Strowger mechanism operates intermittently until the carriage thereof is moved into its eleventh radial position. When the carriage of this Strowger mechanism is rotated into the eleventh radial position the rotary switch springs 109 are moved into engagement, thereby to complete a path for applying ground potential to the ground conductor C143, this path extending from ground at the rotary switch springs 109 by way of RA183 and the front contact associated therewith to the guard conductor C143. This application of ground potential to the guard conductor C143 completes the previously traced circuit for energizing the rotary magnet M701 of the rotary switch 701 in the distributor 700, thereby to cause the distributor 700 to operate to select the next idle link in the first group of links for the use of the calling subscriber line 115, in the manner previously explained. Thus it will be apparent that the distributor 700 is so connected and arranged that a second idle link in the first group of links is automatically selected for the use of a calling line in the event that the finder switch of a first selected link in the first group of links fails to find the calling line. 30 35 40 45 50 55 60 65 70 75

Also it is noted that an arrangement is incorporated in the distributor 700 for locking this distributor out of service in the event that it fails to operate properly to cause the finder switch of an idle link in the first group of links selected, thereby to seize a calling subscriber line. For example, should either the vertical magnet M105 or the rotary magnet M106 of the Strowger mechanism included in the finder switch 101 of the link 60 fail to cause the relay R760 to transmit operating pulses to either one of these magnets, after a predetermined time interval the operated relay R735 or the operated relay R755 is effective to cause the relay R755 to 75

operate. More particularly, in the event that the vertical magnet M105 fails to operate or to cause the relay R760 to transmit pulses thereto, the operated relay R750 causes the circuit for energizing the lower winding of the relay R755 to be energized a time interval sufficiently long to cause the relay R755 to operate. More particularly, in the event that the rotary magnet M105 fails to operate or to cause the relay R760 to transmit pulses thereto, the operated relay R735 causes the circuit for energizing the upper winding of the relay R755 to be energized a time interval sufficiently long to cause the relay R755 to operate. Upon operating, the relay R755 completes, at RA759, a circuit for energizing the relay R750 by way of the all trunks busy conductor C763 extending to the distributor individually associated with the second group of links, this circuit extending from the grounded all trunks busy conductor C763 by way of the switch 780, RA759, and the winding of R750 to battery. Also the relay R755 completes, at RA757, a path for applying ground potential to the guard conductor C741, this path extending from ground, at RA751, by way of RA747 and RA757 to the guard conductor C741. This application of ground potential to the guard conductor C741 completes the previously traced circuit for energizing the rotary magnet M701 of the rotary switch 701 in the distributor 700, and completes the previously traced path for short-circuiting the winding of the relay R740. The relay R740 then restores and interrupts, at RA742 and the front contact associated therewith, a point in the circuit for energizing the rotary magnet M701 of the rotary switch 701, thereby to cause the rotary magnet M701 to restore and advance the wipers noted of the rotary switch 701 one step and into engagement with the contacts terminating the control conductors of the finder switch in the next link in the first group of links. Also the relay R740 interrupts, at RA741, the holding circuit of the relay R710; and the operated relay R755 interrupts, at RA756, a point in the circuit for energizing the relay R710 by way of the all trunks busy conductor C142, thereby to cause the relay R710 to restore. Upon restoring, the relay R710 interrupts, at RA711, a point in the original circuit for energizing the relay R740 and a point in this circuit for energizing the rotary magnet M701 of the rotary switch 701 in the distributor 700. Furthermore, the relay R710 interrupts, at RA713 and the front contact associated therewith, a point in the circuit for energizing the start relay R720 by way of the start lead C137, and completes, at RA713 and the back contact associated therewith, a connection between the start lead C137 and the conductor C165' extending to the distributor associated with the second group of links. It is noted that the circuit for energizing the relay R750 is completed by way of the all trunks busy conductor C763 of the distributor associated with the second group of links and that the operated relay R750 retains completed the circuit for energizing the lower winding of the relay R755. In turn the operated relay R755 retains the circuit for energizing the relay R750 completed at RA759. Accordingly, the relays R750 and R755 remain in operated positions until the circuit for energizing the relay R750 is interrupted by manually operating the switch 780 to its open position. Thus the distributor 700 associated with the first

group of links is permanently locked out of service until the switch 780 is manually operated.

Before continuing with the operation of the connector switch 200 associated with the finder switch 101 in the link 60, it is noted that the 5 finder switches of the links in the first group of links may be tested automatically and sequentially by operating the test switch 782 to its closed position. When the test switch 782 is thus operated a circuit is completed for energizing the 10 start relay R720, this circuit extending from ground, at the test switch 782, by way of the resistor 781, the start lead C137, RA713 and the front contact associated therewith, and the winding of R720 to battery. When the start relay 15 R720 is thus energized it operates to cause the distributor 700 to assign the previously selected link to the use of a calling line. Assuming that the illustrated link 60 is the link previously selected by the distributor 700 to the use of the calling 20 line, the distributor 700 then operates to cause the vertical magnet M105 of the Strowger mechanism included in the finder switch 101 to operate intermittently, thereby to move the carriage of this Strowger mechanism in the vertical direction. Assuming that no legitimate call is initiated on a line in the first group of lines during the time interval the finder switches of the links in the first group of links are being tested, the carriage of the Strowger mechanism included in 25 the finder switch 101 is moved vertically to the tenth level wherein the previously traced circuit for energizing the upper winding of the relay R730 is completed due to the fact that the tenth contact in the row of contacts 104 in the contact 30 bank of this Strowger mechanism is permanently grounded. The relay R730 then operates, as previously explained, thereby to cause the rotary magnet M106 to be intermittently energized in order to drive the carriage of the Strowger mechanism included in the finder switch 101 step by 35 step in a rotary direction until this carriage is moved into the eleventh radial position. When the carriage of the Strowger mechanism included in the finder switch 101 is moved into the eleventh radial position, the rotary springs 109 are closed, thereby to cause ground potential to be applied to the guard conductor C143. This application of ground potential to the guard conductor C143 causes the rotary magnet M701 of the rotary 40 switch 701 to be energized, thereby to drive the wipers noted of the rotary switch 701 one step and into engagement with the contacts terminating the control conductors of the finder switch in the next idle link. The finder switch of the 45 next idle link is then caused to operate in a manner similar to that described above. This operation of the distributor 700 will continue as long as the test switch 782 remains in a closed position, thereby to test sequentially the finder switches of the idle links in the first group of 50 lines.

In the event that a legitimate call is initiated on a line in the first group of lines during the time interval that the finder switches of the idle links in the first group of links are being tested, 55 the wiper carried by the carriage of the Strowger mechanism included in an operating one of the finder switches will engage the marked contact in the row of contacts corresponding to the row of contacts 104 in the contact bank of this 60 Strowger mechanism prior to the movement of the carriage of this Strowger mechanism in the vertical direction to the tenth level, thereby to cause this operating finder switch to seize the 65 calling line. After this finder switch seizes the 70 calling line. After this finder switch seizes the 75

calling line, the distributor 700 continues to operate as previously described to test the remainder of the finder switches of the idle links in the first group of links.

5 Continuing now with the operation of the connector switch 200 to extend the call from the subscriber substation A to the subscriber substation C, when the relay R190 in the finder switch 101 operates to complete the previously traced 10 path for applying ground potential to the control conductor C123, a circuit for operating the relay R220 is completed, this circuit extending from ground, at RA194 and the front contact associated therewith, by way of the control conductor 15 C123, RA214, and the winding of R220 to battery. Also this application of ground potential to the control conductor C123 completes a circuit for energizing the upper winding of the relay R270, this circuit extending from the grounded control 20 conductor C123 by way of the vertical off-normal springs 209 associated with the Strowger mechanism included in the connector switch 200, and the upper winding of R270 to battery. When energized over the above-traced circuit the relay 25 R270 operates to prepare, at RA271 and RA272, a circuit traced hereinafter for energizing the upper and lower windings of the line relay R260 by way of a loop circuit including the bridge at the substation A across the line conductors C116 30 and C117 of the calling subscriber line 115 subsequent to the operation of the finder switch 101 to seize the calling subscriber line 115.

After the finder switch 101 seizes the calling subscriber line 115, and the switching relay R180 35 operates to connect the calling subscriber line 115 to the trunk line 120, a loop circuit is completed for energizing the relay R260, this circuit extending from ground, at RA271, by way of RA272, the lower winding of R260, RC256, RA255, RC246, 40 RA245, C203, RA212, C122, RA182, C125, the wiper and contact in the Strowger mechanism included in the finder switch 101, the bridge at the substation A between the line conductors C116, C117 and C118 of the subscriber line 115, C116, 45 the contact and wiper of the Strowger mechanism included in the finder switch 101, C124, RA181, C121, RA211, C202, RA242, RC243, RA252, RC253, and the upper winding of R260 to battery. When energized over the above- 50 traced circuit the relay R260 operates to complete, at RA261 and the front contact associated therewith, a circuit for energizing the hold relay R265, this circuit extending from ground, at RA241, by way of RA261 and the front contact 55 associated therewith, and the winding of R265 to battery. When energized over the above-traced circuit the relay R265 operates to complete, at RA265 and the front contact associated therewith, a path for applying multiple ground potential to the control conductor C123, this path 60 extending from ground, at RC236, by way of RA235, C239, and RA265 and the front contact associated therewith, to C123. It is noted that the relay R265 operates to apply multiple ground 65 potential to the control conductor C123 prior to the restoration of the relay R190 in the finder switch 101 due to the slow-to-release characteristic of the latter relay. Also, upon operating, the relay R265 prepares, at RA269, a circuit for 70 impulsing the control magnets of the Strowger mechanism and the minor switch 325 included in the connector switch 200, in a manner more fully described subsequently. Also, it is noted that the ground potential connected to RA271 is 75 connected thereto by way of a dial tone conduct-

tor. Thus it will be apparent that dial tone current is returned to the substation A over the previously traced loop circuit extending thereto in order to actuate the receiver of the telephone instrument thereat, thereby to indicate to the subscriber at the substation A that a link has been seized and that the first digit of the directory number of the called subscriber line may be dialed. Also the relay R265 completes, at RA266, an obvious circuit for energizing the relay 10 R225, which latter relay operates to apply, at RA228, ground potential to the time start lead C229 for a purpose more fully described subsequently.

The subscriber at the substation A then dials 15 the first digit of the directory number of the called subscriber line at the dial mechanism thereat, thereby to transmit a first series of impulses by way of the subscriber loop circuit to the line relay R260. The relay R260 follows the 20 dialed impulses in the usual manner, restoring each time the loop circuit is interrupted, and operating each time the loop circuit is completed. Each time the relay R260 restores it interrupts, at RA261 and the front contact associated therewith, the energizing circuit of the relay R265, and completes, at RA261 and the back contact associated therewith, a circuit for energizing in multiple the lower winding of the relay R270 and the vertical magnet M201 of the Strowger mechanism 25 included in the connector switch 200. The last-mentioned circuit extends from ground, at RA247, by way of RA261 and the back contact associated therewith, and RA269 to RA274 and the front contact associated therewith, one branch of this circuit extending from the front contact associated with RA274 by way of the lower winding of R270 to battery, and the other branch extending from the front contact associated with RA274 by way of the winding of the 30 vertical magnet M201 to battery. The relays R265 and R270 are of the slow-to-release type. Thus, these relays remain operated during 35 pulsing. Each time the vertical magnet M201 is energized the carriage of the Strowger mechanism included in the connector switch 200 is moved one step in the vertical direction. When the carriage of this Strowger mechanism is moved away from its normal position one step in the vertical direction, the vertical off-normal 40 springs 209 and 345 are actuated. The vertical off-normal springs 209 are actuated to interrupt the circuit for energizing the upper winding of the relay R270, and the vertical off-normal springs 345 are actuated to prepare a point in 45 the circuit for energizing the release magnet M344 of this Strowger mechanism. At the conclusion of the first digit dialed the relay R260 re-operates, thereby to interrupt, at RA261 and the back contact associated therewith, the previously 50 traced circuit for energizing in multiple the lower winding of the relay R270, and the winding of the vertical magnet M201. When this circuit is interrupted further operation of the vertical magnet M201 is arrested, thereby to arrest the carriage of the Strowger mechanism included in the connector switch 200 in a vertical position corresponding to the first digit dialed and to the level in the contact bank 300 of this Strowger mechanism in which are disposed the contacts terminating the conductors of the called subscriber line 315 extending to the substation C. Shortly 55 after this circuit is interrupted the relay R270, being of the slow-to-release type, restores to interrupt, at RA271 and RA272, the circuit for re- 60 70 75 80 85 90 95 98 99 100

turning dial tone current to the substation A by way of the loop circuit, and to complete, at RA272 and RC273, an alternative circuit for energizing the relay R260 by way of the previously traced 5 loop circuit. This alternative circuit for energizing the relay R260 extends from ground, at RA268, by way of RC273 and RA272 to the lower winding of R260, the extension of this circuit by way of the loop circuit to battery associated with 10 10 one terminal of the upper winding of R260 being the same as that previously traced. Also, upon restoring, the relay R270 prepares, at RA274 and the back contact associated therewith, a point in a circuit traced hereinafter for energizing 15 15 in multiple the relay R280 and the rotary magnet M346 of the Strowger mechanism included in the connector switch 200.

The subscriber at the substation A then dials the second digit of the directory number of the called subscriber line at the dial mechanism thereat, thereby to transmit a second series of impulses by way of the subscriber loop circuit to the line relay R260. The line relay R260 follows the dialed impulses, as previously explained. Each time the relay R260 operates, it completes, at RA261 and the front contact associated therewith, the previously traced circuit for energizing the relay R265. Each time the relay R260 restores, it completes, at RA261 and the back contact associated therewith, the circuit for energizing in multiple the relay R280 and the rotary magnet M346, this circuit extending from ground, at RA247, by way of RA261 and the back contact associated therewith, RA269, RA274 and the back contact associated therewith, C286, and RA398 to RA378, one branch of this circuit extending from RA378 by way of RA377, C285, and the winding of R280 to battery, and the other branch of this circuit extending from RA378 by way of RA350 and the back contact associated therewith, C288, and the winding of M346 to battery. Due to the slow-to-release characteristics of the relays R280 and R265, these relays do not restore during impulsing. Each time the rotary magnet M346 is energized the carriage of the Strowger mechanism included in the connector switch 200 is moved one step in the rotary direction. At the conclusion of the second digit dialed the carriage of the Strowger mechanism included in the connector switch 200 occupies a radial position corresponding to the second digit dialed, and causes the wipers carried thereby to engage the contacts in the contact bank 300 of this Strowger mechanism terminating the called subscriber line 315. Upon operating, the relay R280 completes, at RA282 and the front contact associated therewith, a circuit for energizing the relay R345, this circuit extending from ground, at RA396 and the back contact associated therewith, by way of C294, RA282 and the front contact associated therewith, C287, and the winding of R345 to battery. When energized over the above-traced circuit the relay R345 operates to complete, at RA348', a path for short-circuiting the relay R350, this path extending from the grounded conductor C287, by way of RA348', RC353, RA351, the winding of R350, and RA363 to the grounded control conductor C123. At the conclusion of the second digit dialed the line relay R260 reoperates to interrupt, at RA261 and the back contact associated therewith, the previously traced circuit for energizing in multiple the relay R280 and the rotary magnet M346, thereby to arrest further operation of the rotary magnet M346, and, consequently, further move-

ment in a rotary direction of the carriage of the Strowger mechanism included in the connector switch 200. Shortly thereafter the relay R280 restores to interrupt, at RA282 and the front contact associated therewith, the previously traced circuit for energizing the relay R345 and, the previously traced path for short-circuiting the relay R350. The relay R350 is then energized in series with the relay R345 by way of a circuit extending from the grounded control conductor C123 by way of RA363, the winding of R350, RA351, RC353, RA348', and the winding of R345 to battery. When energized over the above-traced circuit the relay R350 operates to complete, at RA351 and RA352, a holding circuit for itself extending from the grounded control conductor C123 by way of RA363, the winding of R350, RA351, RA352, and the resistor 350 to battery. Also the relay R350 interrupts, at RA351 and RC353, the original circuit for energizing in series the relays R350 and R345, thereby to cause the relay R345 to restore shortly thereafter. Further the relay R350 prepares, at RA350 and the front contact associated therewith, a circuit for energizing in multiple the relay R280, and the rotary magnet M345 of the minor switch 325.

At this time the subscribed line 315 has been seized by the connector switch 200. However, the subscriber line 315 is not tested in order to determine the idle or busy condition thereof until after the third and last directory digit of the subscriber substation C is dialed, the third directory digit being effective to cause a predetermined type of ringing current to be projected over the subscriber line 315 in the event this subscriber line is idle, in a manner more fully described subsequently. The subscriber at the substation A then dials at the dial mechanism thereat, the third digit of the directory number of the called subscriber substation C, thereby to transmit a third series of impulses by way of the subscriber loop circuit to the line relay R260. The line relay R260 follows the dialed impulses, as previously explained. Each time the relay R260 operates it completes, at RA261 and the front contact associated therewith, the previously traced circuit for energizing the relay R265, and each time the relay R260 restores it completes, at RA261 and the back contact associated therewith, a circuit for energizing in multiple the relay R280 and the rotary magnet M345 of the minor switch 325, this latter circuit extending from ground at RA247, by way of RA261 and the back contact associated therewith, RA269, RA274 and the back contact associated therewith, C286, and RA399' to RA378, one branch of this circuit extending from RA378 by way of RA377, C285, and the winding of R280 to battery, and the other branch of this circuit extending from RA378 by way of RA350 and the front contact associated therewith, C806, and the winding of the rotary magnet M345 to battery. When energized over the above-traced circuit the relay R280 operates to complete, at RA282 and the front contact associated therewith, the previously traced circuit for energizing the relay R345, and interrupts, at RA281, a point in a test circuit traced hereinafter including the control wiper 303 carried by the carriage of the Strowger mechanism. When energized over the above-traced circuit the relay R345 operates to interrupt, at RA345, a point in a busy tone circuit traced hereinafter, and prepares, at RA348 and RA349, a point in the previously mentioned test circuit including the control wiper 303 car-

ried by the carriage of the Strowger mechanism, and prepares, at RA346, a point in a test circuit traced hereinafter including the control wiper 304 carried by the carriage of the Strowger mechanism. At the conclusion of the third digit dialed the wipers 327, 331 and 335 of the rotary switches 326, 330 and 334, respectively, engage the contacts in their respective contact banks 329, 333 and 337 corresponding to the third digit. When the wiper 335 of the rotary switch 334 is rotated away from its normal position the multiplied contacts in the contact bank 337 thereof are connected to the conductor 336, thereby to prepare a point in the previously mentioned test circuit. Also, when the wipers noted of the rotary switches of the minor switch 325 are rotated away from their normal positions, the off-normal springs 339 associated therewith are actuated. When the off-normal springs 339 are actuated the switch springs 340 and 341 are moved into disengagement, thereby to interrupt a point in a circuit traced hereinafter for energizing the release magnet M344 associated with the Strowger mechanism included in the connector switch 200; and the switch springs 341 and 342 are moved into engagement, thereby to prepare a circuit traced hereinafter for energizing the release magnet M343 of the minor switch 325. Shortly after the conclusion of the third digit dialed the relay R280, being of the slow-to-release type, restores to complete, at RA281, the previously mentioned test circuit for determining the idle or busy condition of the called subscriber line 315. More particularly, this test circuit includes the test relay R370 and the control wiper 303 carried by the carriage of the Strowger mechanism included in the connector switch 200. At this time the control wiper 303 engages the contact 309 in the contact bank 300 of this Strowger mechanism, and the previously mentioned test circuit extends from the control conductor C316 of the called subscriber line 315 by way of the contact 309, the control wiper 303, C820, the multiplied contacts in the contact bank 337 of the rotary switch 334, the wiper 335 thereof, the conductor 336, C217, RA281, C284, RA348, RA349, and the winding of R370 to battery. The subsequent operation of the connector switch 200 depends upon whether the called subscriber line 315 is idle or busy. Assuming that the called subscriber line is busy, ground potential appears upon the control conductor C316 thereof which is derived by way of the line circuit associated therewith, thereby to cause the test relay R370 to be short-circuited by way of the previously traced test circuit. Shortly thereafter the relay R345 restores, as previously noted, thereby to complete, at RA348 and RC348, a circuit for energizing the upper winding of the switching relay R395. This circuit extends from ground, at RA261, by way of C299, RA376, C811, the upper winding of R395, C818, RA375 and the back contact associated therewith, RC348, RA348, C284, RA281, C217, the conductor 336 in the rotary switch 334, the wiper 335, a contact in the associated multiplied contact bank 337, C820, C800, the control wiper 303, and the contact 309 in the contact bank 300 of the Strowger mechanism included in the connector switch 200, to battery potential appearing on the control conductor C316 of the subscriber line 315. When energized over the above-traced circuit the relay R395 operates to complete, at RA398, a holding circuit for energizing the lower winding thereof, this circuit extending from ground, at RA268, by way of C283, RA398, and the lower winding of R395 to battery. Also, the relay R395 connects the conductors C811 and C815, at RA395 and RA395', respectively, to the conductors C291 and C293. When the conductors C811 and C815 are respectively connected to the conductors C291 and C293, battery and ground potentials are respectively extended to the wipers 301 and 302 carried by the carriage in the Strowger mechanism included in the connector switch 200. The path for extending battery potential to the wiper 301 extends from battery at the upper winding of the ring cut-off relay R360 by way of the upper winding of R360, C812, RA391 and the back contact associated therewith, C810, RA361 and the back contact associated therewith, C811, RA395, and C291 to the wiper 301. The path for extending ground potential to the wiper 302 extends from ground, at RA381 and the back contact associated therewith, by way of RA391' and 75

calling subscriber substation A. The circuit for returning busy tone current over the loop circuit extending to the calling substation A extends from the ungrounded terminal of a busy tone transformer winding by way of the busy tone lead C819, RA397, RA374, the condenser 345, RA345, C290, the condenser 201, RC243, RA242, C202, and RA211 to the line conductor C121, and from ground, at RA268, by way of RC273, RA272, the lower winding of R260, RC256, RA255, RC246, RA245, C203, and RA212 to the line conductor C122, the connection between the line conductors C121 and C122 of the trunk line 120 including the loop circuit extending to the calling subscriber substation A being the same as that previously traced. When busy tone current is thus returned over the loop circuit to the calling subscriber substation A, the receiver of the telephone instrument thereat is actuated, thereby to indicate to the subscriber thereat that the desired connection cannot immediately be had due to the busy condition of the called subscriber line 315. The subscriber at the calling substation A then releases the operated link 60 including the finder switch 101 and the connector switch 200, and the line circuit 100 by placing the receiver of the telephone instrument at the substation A upon its hook. The exact manner in which these operated pieces of apparatus are released is described in detail hereinafter.

Assuming that the called subscriber line 315 is idle, battery potential appears upon the control conductor C316 thereof which is derived by way of the line circuit associated therewith, thereby to cause the test relay R370 to be short-circuited by way of the previously traced test circuit. Shortly thereafter the relay R345 restores, as previously noted, thereby to complete, at RA348 and RC348, a circuit for energizing the upper winding of the switching relay R395. This circuit extends from ground, at RA261, by way of C299, RA376, C811, the upper winding of R395, C818, RA375 and the back contact associated therewith, RC348, RA348, C284, RA281, C217, the conductor 336 in the rotary switch 334, the wiper 335, a contact in the associated multiplied contact bank 337, C820, C800, the control wiper 303, and the contact 309 in the contact bank 300 of the Strowger mechanism included in the connector switch 200, to battery potential appearing on the control conductor C316 of the subscriber line 315. When energized over the above-traced circuit the relay R395 operates to complete, at RA398, a holding circuit for energizing the lower winding thereof, this circuit extending from ground, at RA268, by way of C283, RA398, and the lower winding of R395 to battery. Also, the relay R395 connects the conductors C811 and C815, at RA395 and RA395', respectively, to the conductors C291 and C293. When the conductors C811 and C815 are respectively connected to the conductors C291 and C293, battery and ground potentials are respectively extended to the wipers 301 and 302 carried by the carriage in the Strowger mechanism included in the connector switch 200. The path for extending battery potential to the wiper 301 extends from battery at the upper winding of the ring cut-off relay R360 by way of the upper winding of R360, C812, RA391 and the back contact associated therewith, C810, RA361 and the back contact associated therewith, C811, RA395, and C291 to the wiper 301. The path for extending ground potential to the wiper 302 extends from ground, at RA381 and the back contact associated therewith, by way of RA391' and 75

the back contact associated therewith, C814, RA362 and the back contact associated therewith, C815, RA395', and C293 to the wiper 302. Also, the relay R395 connects, at RA396 and the front contact associated therewith, direct ground potential to the control wiper 303, this connection extending from ground, at RA396 and the front contact associated therewith, by way of C800 to the control wiper 303. At this time it is noted that the wipers 301, 302, and 303, respectively, engage the contacts 305, 307, and 309 in the contact bank 300 of the Strowger mechanism respectively terminating the conductors C324, C325, and C316 of the called subscriber line 315. This application of direct ground potential to the control wiper 303 completes a path for energizing certain relays in the line circuit associated with the called subscriber line 315, in a manner more fully described subsequently, in order to cause the subscriber line 315 to be marked as a busy line to the connector switches of the links having access thereto. Further, the relay R395 completes, at RA399, a path for energizing the relay R380 by way of the ring pick-up lead C822 in the event code ringing is employed in the system, as is more fully explained subsequently. This path extends from ground potential appearing upon the ring pick-up lead C822 at a predetermined time by way of the "X" wiring illustrated, RA399, RC384, RA383, RA354, and the winding of R380 to battery. Further, the relay R395 completes, at RA399, a path for energizing the relay R380 by way of the lead C821 in the event harmonic ringing is employed in the system, as is more fully explained subsequently. This path extends from the grounded lead C821 by way of the "Y" wiring illustrated to the front contact associated with RA399 and over the previously traced circuit to battery. Furthermore, the relay R395 interrupts, at RA399', a further point in the circuit for energizing the rotary magnet M345 of the minor switch 325, thereby to arrest further operation thereof, and connects, at RA396', the lower winding of the ring control relay R390 to the even contacts in the rotary switch 326 of the minor switch 325 for a purpose more fully explained subsequently. This connection extends from battery at the lower winding of the relay R390 by way of the lower winding of R390, MA346, RA394, RC394, RA396', and C803 to the multiple connected even contacts in the rotary switch 326. Finally, the relay R395 prepares, at RA397' and the front contact associated therewith, a point in a holding circuit traced herein-after for energizing the upper winding of the ring control relay R390.

The subsequent operation of the connector switch 200 depends upon whether code or harmonic ringing is employed in the system and upon whether the third digit dialed is an odd or even digit. In the event that code ringing is employed in the system, the conductors respectively terminating at the ten contacts in the contact bank 329 of the rotary switch 326 of the minor switch 325 are respectively connected to ten different codes of a source of alternating code ringing current comprising different combinations of long and short pulses. In the event harmonic ringing is employed in the system, the conductors respectively terminating at the ten contacts in the contact bank 329 of this rotary switch 326 are respectively connected to ten different frequencies of a source of harmonic ringing current. In the event the third digit dialed is an odd digit the ring control relay R390 is not

operated. On the other hand, in the event that the third digit dialed is an even digit the relay R390 is operated. Also, a divided or a bridged ringing circuit may be employed in the system in a manner more fully described subsequently. 5

Assuming that code ringing is employed in the system and that the third digit dialed is an odd digit (for example, No. 1), a path is completed at this time for projecting code ringing current from the conductor terminating at the first contact in the contact bank 329 of the rotary switch 326 by way of the conductor C293 over the line conductor C325 of the subscriber line 315, this path extending from the ungrounded terminal of a grounded generator in the source of alternating code ringing current by way of the conductor terminating at the first contact in the contact bank 329 of the rotary switch 326, the wiper 327, the multiplied odd contacts in the contact bank 328 of the rotary switch 326, the conductor C802, RA381 and the front contact associated therewith, RA381' and the back contact associated therewith, C814, RA362 and the back contact associated therewith, C815, RA395', C293, the wiper 302, and the contact 307 in the contact bank 300, to the line conductor C325 of the subscriber line 315. In the event that a divided ringing circuit is employed in the system this code ringing current is then conducted from the line conductor C325 of the subscriber line 315 by way of a condenser and a ringer at each of a first group of subscriber substations, including the substation C, to ground, thereby to cause the ringers at each of the substations in the first group and connected between the line conductor C325 and ground to be actuated in accordance with this code ringing current. The subscriber at the substation C is advised that the substation C is the called substation by the characteristic operation of the ringer thereat. In the event that a bridged ringing circuit is employed in the system this code ringing current is then conducted from the line conductor C325 of the subscriber line 315 by way of a condenser and a ringer at each of a group of subscriber substations including the substation C, to the line conductor C324 of the subscriber line 315, thereby to cause the ringers at each of the substations in the group and connected between the line conductors C325 and C324 to be actuated in accordance with this code ringing current. The subscriber at the substation C is advised that the substation C is the called substation by the characteristic operation of the ringer thereat. This code ringing current is then conducted from the line conductor C324 of the subscriber line 315 by way of the contact 305 in the contact bank 300 of the Strowger mechanism included in the connector switch 200, the wiper 301, C291, RA395, C814, RA361 and the back contact associated therewith, C810, RA391 and the back contact associated therewith, C812, and the upper winding of the ring cut-off relay R360 to battery. 40

Assuming that code ringing is employed in the system and that the third digit dialed is an even digit (for example, No. 2), a path is completed at this time for energizing the lower winding of the ring control relay R390, this path extending from the ungrounded terminal of a grounded generator in the source of alternating code ringing current by way of the conductor terminating at the second contact in the contact bank 329 of the rotary switch 326, the wiper 327, the multiplied even contacts in the contact bank 328 of the rotary switch 326, the conductor C803, RA396', 45

70

75

RC384, RA384, MA346, and the lower winding of R380 to battery. When energized over the above-traced circuit the relay R380 operates to complete, at RA383 and RA384, a holding circuit for energizing in series the upper and lower windings thereof, this circuit extending from the grounded control conductor C128 by way of the upper winding of R380, RA381' and the front contact associated therewith, RA383, RA384, MA346 and the lower winding of R380 to battery. Further the relay R380 interrupts, at RA384 and RC384, the original circuit for energizing the lower winding thereof, and completes, at RA381 and the front contact associated therewith, at RA381' and the front contact associated therewith, and, at RA382, a circuit for projecting coded ringing current from the conductor terminating at the second contact in the contact bank 329 of the rotary switch 326 by way of the conductor C291 over the subscriber line conductor C324, this path extending from the ungrounded terminal of the grounded generator in the source of alternating code ringing current by way of the conductor terminating at the second contact in the contact bank 329 of the rotary switch 326, the wiper 327, the multiplied even contacts in the contact bank 328 of the rotary switch 326, the conductor C803, RA395', RA382, RA381 and the front contact associated therewith, RA381' and the front contact associated therewith, C810, RA361 and the back contact associated therewith, C811, RA395, C291, the wiper 301, and the contact 305 in the contact bank 300 to the line conductor C324 of the subscriber line 315. In the event that a divided ringing circuit is employed in the system this coded ringing current is then conducted from the line conductor C324 of the subscriber line 315 by way of a condenser and a ringer at each of a second group of subscriber substations including the substation C to ground, thereby to cause the ringer at each of the substations in the second group, and connected between the line conductor C324 and ground, to be actuated in accordance with this code ringing current. The subscriber at the substation C is advised that the substation C is the called substation by the characteristic operation of the ringer thereat. In the event that a bridged ringing circuit is employed in the system this code ringing current is then conducted from the line conductor C324 of the subscriber line 315 by way of a condenser and a ringer at each of a group of subscriber substations including the substation C to the line conductor C325 of the subscriber line 315, thereby to cause the ringer at each of the substations in this group, and connected between the line conductors C324 and C325, to be actuated in accordance with this code ringing current. The subscriber at the substation C is advised that the substation C is the called substation by the characteristic operation of the ringer thereat. This code ringing current is then conducted from the line conductor C325 of the subscriber line 315 by way of the contact 307 in the contact bank 300 of the Strowger mechanism included in the connector switch 200, the wiper 302, C293, RA395', C815, RA362 and the back contact associated therewith, C814, RA391' and the front contact associated therewith, C812, and the upper winding of the ring cut-off relay R360 to battery.

It is noted that the control relay R380 is energized by way of the previously traced circuit from the ring pick-up lead C822 when code ringing is employed in the system at the beginning of a series of transmitted coded impulses so that a complete series of coded impulses of code ring-

ing current is initially transmitted to the called subscriber substation. When energized over this circuit the control relay R380 operates to complete, at RA382 and RA383, a holding circuit for itself extending from ground, at RA268, by way of C283, RA382, RA383, RA354, and the winding of R380 to battery. Also the relay R380 interrupts, at RA383 and RC384, the original circuit for energizing the winding thereof from the ring pick-up lead C822, and prepares, at RA381 and the front contact associated therewith, a point in the previously traced circuits for projecting ringing current by way of either of the conductors C291 and C293 to the subscriber substation C connected to the called subscriber line 315. Furthermore, the relay R380 completes, at RA380, a circuit for returning ring back tone current over the loop circuit to the calling subscriber substation A, this circuit extending from the ungrounded terminal of a ring back tone transformer winding by way of the ring back tone lead C809, RA380, C813, the condenser 319, C290, the condenser 201, RC243, RA242, C202, and RA211 to the conductor C121, and from ground, at RA268, by way of RC273, RA272, the lower winding of R260, RC256, RA255, RC246, RA245, C203, and RA212 to the conductor C122, the conductors C121 and C122 being connected together by way of the previously traced loop circuit including the telephone instrument at the calling subscriber substation A. Ring back tone current is returned over the above-traced circuit to the receiver of the telephone instrument at the calling subscriber substation A, thereby to indicate to the subscriber thereat that ringing current is being projected over the called subscriber line 315, regardless of whether a divided or bridged ringing circuit is employed in the system.

Assuming that harmonic ringing is employed in the system and that the third digit dialed is an odd digit (for example, No. 1), a path is completed at this time for projecting harmonic ringing current from the conductor terminating at the first contact in the contact bank 329 of the rotary switch 326 by way of the conductor C293 over the line conductor C325 of the subscriber line 315, this path extending from the ungrounded terminal of a grounded generator in the source of harmonic ringing current by way of the conductor terminating at the first contact in the contact bank 328 of the rotary switch 326, the wiper 327, and the multiplied odd contacts in the contact bank 328 of the rotary switch 326, to the conductor C802. This ringing current is then conducted by way of the previously traced circuit including the line conductor C325 of the subscriber line 315 to ground at the subscriber substations in the first group in the event that a divided ringing circuit is employed in the system, or to battery at the upper winding of the ring cut-off relay R360 in the event that a bridged ringing circuit is employed in the system, as previously noted. It is noted that, when this harmonic ringing current is projected over the line conductor C325 of the subscriber line 315, only the ringer at the subscriber substation C which is tuned to the frequency of this harmonic ringing current is actuated thereby.

Assuming that harmonic ringing is employed in the system and that the third digit dialed is an even digit (for example, No. 2), the previously traced path is completed at this time for energizing the lower winding of the relay R390 in order to cause operation of this relay, as previously

explained. Upon operating, the relay R380 completes the previously traced path for projecting harmonic ringing current from the conductor terminating at the second contact in the contact bank 329 of the rotary switch 328 by way of the conductor C291 over the line conductor C324 of the subscriber line 315, this path extending from the ungrounded terminal of the grounded generator in the source of harmonic ringing current 10 by way of the conductor terminating at the second contact in the contact bank 329 of the rotary switch 328, the wiper 327, and the multiplied even contacts in the contact bank 328 to C803. This ringing current is then conducted by way of the 15 previously traced circuit including the line conductor C324 of the subscriber line 315 to ground at the subscriber substations in the second group in the event that a divided ringing circuit is employed in the system, or to battery at the upper 20 winding of the ring cut-off relay R360 in the event that a bridged ringing circuit is employed in the system, as previously noted. It is noted that, when this harmonic ringing current is projected over the line conductor C324 of the subscriber line 315, only the ringer at the subscriber substation C which is tuned to the frequency of this harmonic ringing current is actuated thereby.

It is noted that the ring control relay R380 is energized by way of the previously traced circuit from the grounded conductor C821 when harmonic ringing is employed in the system. When energized over this circuit the control relay R380 operates, as previously explained, in order to cause ring back tone current to be returned over the previously traced circuit including the loop circuit extending to the calling subscriber substation A.

The call is answered at the subscriber substation C by removing the receiver of the telephone instrument thereat from its hook, regardless of whether code ringing or harmonic ringing is employed in the system or whether a divided or bridged ringing circuit is employed therein. 45 When the receiver in the telephone instrument at the subscriber substation C is removed from its hook, a bridge including the telephone instrument thereat is connected across the line conductors C324 and C325 of the called subscriber line 315. This bridge across the line conductors of the called subscriber line 315 completes a low resistance circuit for energizing the upper winding of the ring cut-off relay R360. The circuit for energizing the upper winding of the ring cut-off relay R360 is substantially identical to the previously traced circuit for projecting ringing current over the subscriber line 315 when a bridged ringing circuit is employed in the system. When thus energized the ring cut-off relay R360 50 operates to complete, at RA360, a holding circuit for energizing the lower winding thereof, this circuit extending from ground, at RA268, by way of C283, RA360, and the lower winding of R360 to battery. Also the ring cut-off relay R360 55 interrupts, at RA363, the circuit for energizing the relay R350, thereby to cause the latter relay to restore, and completes, at RA364, an obvious circuit for energizing the relay R355, thereby to cause operation thereof. Further the ring cut-off relay R360 60 interrupts, at RA361 and the back contact associated therewith, or at RA362 and the back contact associated therewith, a point in the circuit for projecting ringing current over the line conductor C324 or C325 of the subscriber line 315. Finally, the ring cut-off relay R360 65

completes, at RA361 and the front contact associated therewith, and at RA362 and the front contact associated therewith, a circuit for energizing the battery reversing relay R250, this circuit extending from ground, at the lower winding of R250, by way of the lower winding of R250, C292, RA362 and the front contact associated therewith, C815, and RA395 to C293, and from battery at the upper winding of R250 by way of the upper winding of R250, C290, RA361 and the front contact associated therewith, C811, and RA395 to C291, the conductors C291 and C293 being connected together by way of the loop circuit including the called subscriber line 315 and extending to the called subscriber substation C. When energized 10 over the above-traced circuit the relay R250 operates to reverse the application of battery and ground potentials applied to the conductors C121 and C122 of the trunk line 120 extending by way of the loop circuit to the calling subscriber substation A, thereby to cause a call registering meter or coin collecting device or the like associated with the calling subscriber line 115 to be operated. More particularly, the relay R250 completes, at RA251 and RA252, a path for applying 15 ground potential to the conductor C121, this path extending from ground, at RA268, by way of RC213, RA272, the lower winding of R260, RA251, RA252, RC243, RA242, C202, and RA211 to C121, and interrupts, at RA252 and RC253, the previously 20 traced circuit for applying battery potential at the upper winding of the relay R260 to the conductor C121. Also the relay R250 completes, at RA254 and RA255, a path for applying battery potential to the conductor C122, this path extending from battery at the upper winding of R260 by way of the upper winding of R260, RA254, RA255, RC246, RA245, C203, and RA212 to C122, and interrupts, at RA255 and RC256, the previously 25 traced circuit for applying ground potential, at RA268, to the conductor C122.

Upon operating, the relay R355 interrupts, at RA358, a point in a circuit traced hereinafter for energizing the release magnet M344 of the Strowger mechanism included in the connector 45 switch 200, and completes, at RA359, a circuit for energizing the release magnet M343 of the minor switch 325, the latter circuit extending from ground at the resistor 209, by way of the resistor 209, C237, RA359, C808, RA387, the 50 switch springs 341 and 342 of the off-normal springs 339 associated with the minor switch 325, and the winding of M343 to battery. When energized over the above-traced circuit the release magnet M343 operates to cause the minor switch 55 325 to be released and restored by a spring arrangement to its initial position in an extremely short interval of time. When the wipers of the rotary switches included in the minor switch 325 are restored to their initial positions, the off-normal springs 339 associated with the minor switch 325 are actuated in order to move the switch springs 341 and 342 into disengagement, and to move the switch springs 341 and 340 into engagement. When the switch springs 341 and 60 342 are moved into disengagement, a point in the circuit for energizing the release magnet M343 is interrupted, and when the switch springs 341 and 340 are moved into engagement a point in the path traced hereinafter for energizing the 65 release magnet M344 of the Strowger mechanism included in the connector switch 200 is prepared.

Also, upon operating, the relay R355 completes, at RA357, an obvious circuit for energizing the relay R385, which latter relay, being of the slow- 70

to-operate type, does not immediately operate. Shortly thereafter the relay R385 operates in a manner more fully described subsequently, and thereafter warns the subscribers at the substations A and C that an established connection including the link 60 has been held a predetermined time interval, and then subsequently automatically releases the link 60 in the event this established connection is held an additional time interval.

Upon restoring, the relay R350 interrupts, at RA354, the circuit for energizing the relay R380, thereby to cause the latter relay to restore. Upon restoring, the relay R380 interrupts, at RA380, the circuit for returning ring back tone current over the loop circuit extending to the calling subscriber substation A.

At this time an established connection is completed between the calling subscriber substation A and the called subscriber substation C, the loop circuit extending to the calling subscriber substation A being supplied with talking battery by way of the line relay R260, and the loop circuit extending to the called subscriber substation C being supplied with talking battery by way of the battery reversing relay R250, and these loop circuits being interconnected by means of the voice frequency coupling condensers 207 and 208. More particularly, the conductors C202 and C203 included in the loop circuit extending to the calling subscriber substation A are respectively connected by way of the condensers 207 and 208 to the conductors C290 and C292 included in the loop circuit extending to the called subscriber substation C.

In the event the called subscriber line 315 is one of a group of trunk lines extending to a central point, such, for example, as a private automatic branch exchange or P. A. B. X., the connector switch 200 operates automatically to hunt for an idle line in this group of trunk lines in the event the called line 315 is busy. For example, assuming that the called line 315 is one of a group of trunk lines extending to a P. A. B. X. and is busy when it is seized by the connector switch 200, the test relay R370 is energized over the previously traced circuit upon the restoration of the relay R280 shortly following the conclusion of the third digit dialed. Also the control wiper 304 carried by the carriage of the Strowger mechanism included in the connector switch 200 engages the contact 311 in the contact bank 300 which is connected by way of the "Z" wiring illustrated to the control conductor C316 of the called line 315. Upon operating, the test relay R370 prepares, at RA374, the previously traced circuit for returning busy tone current over the loop circuit extending to the calling subscriber substation A, prepares, at RA372 and the front contact associated therewith, the previously traced holding circuit for itself, interrupts, at RA371 and at RA378, points in the previously traced pulsing circuit for energizing the relay R280 and the rotary magnet M345 of the minor switch 325, and completes, at RA371, a circuit for energizing the lower winding of the relay R390, this circuit extending from the grounded control conductor C316 of the called line 315 by way of the "Z" wiring illustrated, the contact 311, the control wiper 304, C801, RA371, RA346, C297, RC394, RA394, MA346, and the lower winding of R390 to battery. When energized over the above-traced circuit the relay R390 operates to complete, at RA393 and RA394, the previously traced holding circuit for itself, and

completes, at RA393', an alternative circuit for energizing in multiple the relay R345 and the rotary magnet M346 of the Strowger mechanism included in the connector switch 200, this circuit extending from ground, at RA268, by way of C283, RA398', C216, RA276, RC276, C289 and RA393' to the conductor C288, one branch of this circuit extending from the conductor C288 by way of RA282 and the back contact associated therewith, and the winding of R345 to battery, and the other branch of this circuit extending from the conductor C288 by way of the winding of M346 to battery. When energized over the above-traced circuit the relay R345 remains in its operated position, thereby to retain interrupted, at RA345, the previously traced circuit for returning busy tone current over the loop circuit extending to the calling subscriber substation A. When the rotary magnet M346 is energized over the above-traced circuit it operates to rotate the carriage of the Strowger mechanism included in the connector switch 200 another step in the rotary direction, thereby to cause the connector switch 200 to seize the next line in the group of lines extending to the P. A. B. X. Also, upon operating, the rotary magnet M346 interrupts, at MA346, the holding circuit for energizing the relay R39, thereby to cause the latter relay to restore. At this time the circuit for energizing the test relay R370 is recompleted only in the event that the line seized by the connector switch 200 is busy, in which event this apparatus in the connector switch operates in the above-described manner in order to cause the connector switch 200 to seize the next line in the group of lines extending to the P. A. B. X. This apparatus continues to operate, as described above, until an idle line or the last busy line in the group of lines extending to the P. A. B. X. is seized by the connector switch 200. In the event that an idle line in this group of lines is seized by the connector switch, the test relay R370 is short-circuited, as previously explained. When the test relay R370 fails to operate, the connector switch then operates to cause ringing current to be projected over the seized line extending to the P. A. B. X., in a manner similar to that previously explained. The release of this established connection is the same as the release of the established connection between the calling substation A and the called substation C, more fully described subsequently.

When the last busy line extending to the P. A. B. X. is seized by the connector switch, the previously traced circuit for energizing the test relay R370 is completed. However, the previously traced circuit for energizing the lower winding of the relay R390 is not completed due to the fact that the connection between the control conductor of this line and the contact in the contact bank 300 engaged by the control wiper 304, and corresponding to the "Z" wiring illustrated, is not provided in the last line in this group of lines. Accordingly, shortly after the test relay R370 operates and the relay R280 restores, the relay R345 restores to complete, at RA345, the previously traced circuit for returning busy tone current over the loop circuit extending to the calling subscriber substation A, and to complete, at RA349 and RC349, the previously traced holding circuit for energizing the test relay R370. Upon receiving busy tone the subscriber at the calling substation A releases the link 60 and the line circuit 100, in a manner more fully described subsequently.

The release of the established connection between the calling subscriber substation A and the called subscriber substation C is primarily under the control of the subscriber at the substation A. Assuming that the receivers of the telephone instruments at the substations A and B are replaced upon their associated hooks substantially simultaneously, the circuit for energizing the battery reversing relay R250 is interrupted at the hook switch associated with the substation C, thereby to cause this relay to restore. Upon restoring, the relay R250 interrupts, at RA251 and RA252, the path for applying ground potential to the conductor C121, and completes, at RA252 and RC253, the previously traced path for applying battery potential thereto. Also the relay R250 interrupts, at RA254 and RA255, the path for applying battery potential to the conductor C122, and completes, at RA255 and RC256, the previously traced path for applying ground potential thereto. Also, upon restoring, the relay R250 prepares, at RA257, a point in a circuit traced hereinafter for energizing the relay R230, thereby to effect automatically the release of the link 60 in the event the receiver of the telephone instrument at the substation A is not replaced upon its hook within a predetermined time interval, as is more fully described subsequently. Also the circuit for energizing the line relay R260 is interrupted at the hook switch associated with the substation A, thereby to cause this relay to restore. Upon restoring, the relay R260 interrupts, at RA261 and the front contact associated therewith, the circuit for energizing the hold relay R265, which latter relay, being of the slow-to-release type, does not restore immediately. Shortly thereafter the hold relay R265 restores to interrupt, at RA268, the path for applying ground potential to the control conductor C283, thereby to interrupt the circuits for energizing the lower winding of the relay R360 and the circuit for energizing the lower winding of the relay R395. The relay R360, being of the slow-to-release type, restores shortly thereafter, and the relay R395 restores substantially immediately. Also, upon restoring, the hold relay R265 interrupts, at RA265 and the front contact associated therewith, one of the paths for applying ground potential to the control conductor C123, and interrupts, at RA266, the circuit for energizing the relay R225, which latter relay, being of the slow-to-release type, restores shortly thereafter to interrupt, at RA226 and the front contact associated therewith, the path for applying ground potential to the control conductor C123. Also, upon restoring, the relay R225 interrupts, at RA228, the application of ground potential to the time start lead C229, thereby to arrest further operation of the timer associated therewith. When ground potential is removed from the control conductor C123 the circuit for energizing in series the upper and lower windings of the relay R390 is interrupted, thereby to cause this relay to restore. Upon restoring, the relay R360 interrupts, at RA364, the circuit for energizing the relay R355, thereby to cause the latter relay to restore. Upon restoring, the relay R355 interrupts, at RA351, the circuit for energizing the relay R385, thereby to cause the latter relay to restore in order to arrest the operation of the timing apparatus controlled thereby.

Also, when ground potential is removed from the control conductor C123 the circuit for energizing the relay R220 is interrupted, thereby to cause this relay to restore shortly thereafter,

this relay being of the slow-to-release type. Upon restoring, the relay R220 completes, at RA224, a circuit for energizing the release magnet M344 of the Strowger mechanism included in the connector switch 200, this circuit extending from ground at the resistor 209 by way of the resistor 209, RA224, RA248, C229, the switch springs 341 and 340 of the off-normal springs 339 associated with the minor switch 325, C807, RA358, the vertical off-normal springs 345 associated with this Strowger mechanism, and the winding of the release magnet M344 to battery. When the release magnet M344 is thus energized it operates to release the carriage of the Strowger mechanism included in the connector switch 200 and to return it to its normal position. When the carriage of this Strowger mechanism is returned to its normal position the vertical off-normal springs 345 associated therewith are actuated, thereby to move these contacts into disengagement in order to interrupt the circuit for energizing the release magnet M344. At this time the connector switch 200 is completely released.

Also it is noted that an alarm device, not shown, is commonly included in the previously traced circuits for energizing the respective release magnets M343 and M344 of the minor switch 325 and of the Strowger mechanism included in the connector switch 200, thereby to cause this alarm device to be actuated in the event either of these release magnets fails to cause the associated mechanism to be released and returned to its normal position.

When ground potential is removed from the control conductor C123 the circuit for energizing in series the lower winding of the relay R180 and the winding of the rotary magnet M106 of the Strowger mechanism included in the finder switch 101 is interrupted, thereby to cause the relay R180 to restore. Upon restoring, the relay R180 completes, at RA186, a circuit for energizing in series the release magnet M107 of this Strowger mechanism and the relay R715, this circuit extending from ground, at RA194 and the back contact associated therewith, by way of the switch springs 113 and 112 of the vertical off-normal springs 108 associated with this Strowger mechanism, RA186, the winding of M107, C138, and the winding of R715 to battery. When energized over the above-traced circuit the release magnet M107 operates to cause the carriage of the Strowger mechanism included in the finder switch 101 to be released and returned to its normal position. When the carriage of the Strowger mechanism is returned to its normal position the vertical off-normal springs 108 are actuated, thereby to move the switch springs 112 and 113 into disengagement in order to interrupt the previously traced series circuit. When energized over the above-traced circuit the relay R715 operates to complete, at RA717, an obvious circuit for energizing the winding of the call registering meter M724, thereby to cause operation thereof to register the use of the link 60. Also the relay R715 prepares, at RA716, a circuit for illuminating the release signal lamp 723 which is completed by a timing device, not shown, in the event the relay R715 remains in an operated position for a predetermined time interval, indicating that the carriage of the Strowger mechanism included in the finder switch 101 has not been returned to its normal position in order to actuate the vertical off-normal springs 108 associated therewith, thereby to interrupt the series circuit for energiz-

ing the release magnet M107 and the relay R715. After this circuit is interrupted the relay R715 restores shortly thereafter, this relay being of the slow-to-release type.

- 5 Also, when the carriage of the Strowger mechanism included in the finder switch 101 is returned to its normal position, the vertical off-normal springs 108 associated therewith are actuated to move the switch springs 110 and 110 into disengagement, thereby to interrupt the path for applying ground potential to the guard conductor C143, in order to mark the link 60 as idle to be selected by the associated distributor 700 to the use of a calling line in the first group of lines.
- 10 15 Further the vertical off-normal springs 108 are actuated to move the switch springs 113 and 114 into engagement, thereby to complete the previously traced circuit for applying ground potential to the all trunks busy conductor C142, extending to the distributor 700. At this time the finder switch 101 is completely released.
- 15 20 Also when ground potential is removed from the control conductor C123 the circuit for energizing the cut-off relay R160 in the line circuit 25 30 35 40 45 50 55 60 65 individually associated with the calling subscriber line 115 is interrupted, thereby to cause this relay to restore. Upon restoring, the relay R160 interrupts, at RA161, a further point in its holding circuit and a further point in the circuit for applying ground potential to the control conductor C119 of the subscriber line 115 extending to the connector switches of the links having access thereto. This removal of ground potential from the control conductor C119 of the subscriber line 115 causes battery potential at the winding of the cut-off relay R160 to be applied thereto, thereby to mark the subscriber line 115 as idle to the connector switches of the links having access thereto. Also, upon restoring, the cut-off relay R160 prepares, at RA162 and at RA163, points in the circuit for energizing the line relay R155, interrupts, at RA164 and the front contact associated therewith, the application of paystation tone current to the control conductor C118 of the subscriber line 115 in the event this subscriber line is of the paystation type, and prepares, at RA164 and the back contact associated therewith, a circuit for applying multiple battery potential at the resistor 149 to the control conductor C119 of the subscriber line 115. Further the cut-off relay R160 interrupts, at RA165 and the front contact associated therewith, the circuit for energizing the lock-out relay R150, and prepares, at RA165 and the back contact associated therewith, a path for applying ground potential to the permanent lamp lead C190. Shortly thereafter the lock-out relay R150, being of the slow-to-release type, restores to prepare, at RA153 and the back contact associated therewith, a point in the path for applying ground potential to the start lead C131 extending to the distributor 700. At this time the line circuit 100 associated with the subscriber line 115 is completely released, and the subscriber line 115 is marked as idle in the finder and connector switches of the links having access thereto.

70 It is noted that a timing arrangement is incorporated in the connector switch 200 which is operative to cause the link 60 to be released, and the calling subscriber line 115 to be permanently locked out in the event the connector switch 200 is not operated, as previously explained, to complete an established connection between the calling subscriber line 115 and the called subscriber line 315. For example, this timing arrangement

is operative to accomplish these ends in the event the subscriber at the substation A fails to completely dial the directory number of the called subscriber line 315, to release the link 60 after the subscriber at the substation C replaces the receiver of the telephone instrument thereat upon its hook in order to initiate the release of the established connection, to release the link 60 after receiving busy tone current when the called subscriber line 315 is busy, or to release the link 60 after receiving no answer from the subscriber at the called substation C. More particularly, the operation of the timing arrangement is initiated by the operation of the relay R225 which relay, upon operating, completes, at RA228, a path for applying ground potential to the time start lead C229. This application of ground potential to the time start lead C229 initiates operation of the timer which, after a predetermined time interval, operates to apply ground potential to the time pulse lead C210 and the time cut-off lead C211. This application of ground potential to the time pulse lead C210 completes a circuit for energizing the relay R230, this circuit extending from the grounded time pulse lead C210 by way of RC233, RA232, RA251, RA227, RA222, and the winding of R230 to battery. When energized over the above-traced circuit the relay R230 operates to complete, at RA231 and RA232, a holding circuit for itself extending from ground, at RA231, by way of RA232, RA251, RA227, RA222, and the winding of R230 to battery, and to interrupt, at RA232 and RC233, the original circuit for energizing the winding thereof. Also the relay R230 completes at RA234 and RA235, an alternative path for applying ground potential to the control conductor C123, and interrupts, at RA235 and RC236, the previously traced path for applying direct ground potential to the control conductor C123. This alternative path for applying ground potential to the control conductor C123 extends from the grounded time cut-off lead C211 by way of RA234 and RA235 to C239, one branch extending from C239 by way of RA226 and the front contact associated therewith to C123, and the other branch extending from C239 by way of RA265 and the front contact associated therewith to C123. After an additional time interval the timer operates to remove the application of ground potential from the time cut-off lead C211, thereby to interrupt the previously traced path for applying ground potential to the control conductor C123. When ground potential is removed from the control conductor C123 the link 60 is released, and the calling subscriber line 115 is permanently locked out, in a manner more fully described subsequently. It is noted that in the event an established connection is completed to the called substation C prior to the removal of ground potential from the time cut-off lead C211, the link 60 is not released and the calling subscriber line 115 is not permanently locked out due to the operation of the battery reversing relay R250 incident to the answering of the call at the called subscriber substation C. Upon operating, the battery reversing relay R250 interrupts, at RA251, both the original and the holding circuits for energizing the relay R230, thereby to cause the latter relay to restore. Upon restoring, the relay R230 interrupts, at RA234 and RA235, the previously traced path for applying ground potential by way of the time cut-off lead C211 to the control conductor C123, and completes, at RA235 and RC236, the previously traced path for applying ground potential, at RC236, to the control conductor C123.

In the event the call is not answered at the called subscriber substation C within the predetermined time intervals mentioned, the timing arrangement operates, as previously noted, to cause ground potential to be removed from the control conductor C123. When ground potential is removed from the control conductor C123 the circuit for energizing the relay R220, and the circuit for energizing in series the lower winding of the relay R180, and the winding of the rotary magnet M106 of the Strowger mechanism included in the finder switch 101 are interrupted, thereby to cause these relays to restore. Upon restoring, the relay R180 completes, at RA186, the previously traced circuit for energizing the release magnet M107 of the Strowger mechanism included in the finder switch 101, which release magnet operates to cause the carriage of the Strowger mechanism included in the finder switch 101 to be returned to its normal position, as previously explained, thereby to interrupt the loop circuit extending between the line relay R260 and the telephone instrument at the calling subscriber substation A. The line relay R260 then restores to interrupt, at RA261 and the front contact associated therewith, the previously traced circuit for energizing the hold relay R265. Shortly thereafter the hold relay R265 restores to interrupt, at RA266, the previously traced circuit for energizing the relay R225, which latter relay restores shortly thereafter. Incident to the restorations of the hold relay R265 and the relay R225, the remainder of the operated relays in the connector switch 200 restore, as previously explained. Also the Strowger mechanism included in the connector switch 200 and the minor switch 325 restore in the event they are operated, as previously explained, thereby to cause the connector switch to be completely released. At this time the link 60 is completely released for further use.

Also when ground potential is removed from the control conductor C123 the previously traced circuit for energizing the cut-off relay R160 in the line circuit 100 associated with the calling subscriber line 115 is interrupted, thereby to cause this relay to restore. Upon restoring, the relay R160 completes, at RA162 and RA163, the bridge circuit for energizing the line relay R155 due to the fact that the receiver of the telephone instrument at the calling subscriber substation A is removed from its hook at this time. Also the relay R160 interrupts, at RA165 and the front contact associated therewith, the previously traced circuit for energizing the lock-out relay R150, and completes, at RA165 and the back contact associated therewith, a path for applying ground potential to the permanent lamp lead C190. When energized over the previously traced circuit the line relay R155 operates to complete, at RA156 and the front contact associated therewith, the previously traced path for applying ground potential to the control conductor C119 of the calling subscriber line 115, thereby to mark the calling subscriber line 115 as busy to the connector switches of the links having access thereto. Also the line relay R155 completes, at RA158, an alternative circuit for energizing the lock-out relay R150, thereby to retain the lock-out relay in its operated position, this relay being of the slow-to-release type and being in an operated position at this time. This alternative circuit extends from ground, at RA158, by way of RA153 and the front contact associated therewith, and the winding of the lock-out relay R150

to battery. The application of ground potential to the permanent lamp lead C190 causes the lamp associated therewith to be illuminated, thereby to indicate to an attendant in the suboffice 50 that the calling subscriber line 115 is permanently locked out.

The subscriber at the calling substation A may place the calling subscriber line 115 in use again by replacing the receiver of the telephone instrument thereat upon its hook, thereby to interrupt at the hook switch associated therewith the previously traced bridge circuit for energizing the line relay R155. When this bridge circuit for energizing the line relay R155 is interrupted, this relay restores to interrupt, at RA158, the previously traced alternative circuit for energizing the lock-out relay R150, which latter relay being of the slow-to-release type restores shortly thereafter. Upon restoring, the lock-out relay R150 interrupts, at RA152, a point in the previously traced path for applying ground potential to the permanent lamp lead C190, thereby causing the lamp associated therewith to be extinguished.

Also it is noted that a permanent fault comprising a short-circuit connection between the line conductors C116 and C117 of the subscriber line 115 is effective to initiate a call upon this subscriber line in the same manner that a call is initiated thereon upon the removal of the receiver of the telephone instrument thereat from its hook. When a call is initiated on the subscriber line 115 by the appearance of such a fault thereon the line circuit 100 associated therewith operates, as previously explained, thereby to cause the distributor 700 associated therewith to assign a link to the use of this calling subscriber line. The finder switch of the assigned link then operates to seize the calling subscriber line 115, as previously explained, and subsequently the timing arrangement incorporated in the connector switch of the assigned link operates, due to the fact that no digits are dialed into the connector switch of this link to cause the connector switch thereof to seize a called line, to cause the assigned link to be released and the subscriber line 115 to be permanently locked out, as previously explained. The illumination of the lamp associated with the permanent lamp lead C190 indicates to the attendant at the suboffice 50 that the subscriber line 115 is permanently locked out. The attendant may then cause the fault upon the subscriber line 115 to be removed, whereupon the line circuit 100 associated with the subscriber line 115 operates to place this subscriber line again in service, as previously described.

It is noted that the time interval the established connection is held between the calling subscriber substation A and the called subscriber substation C and routed therebetween by way of the link 60 is timed by a timing apparatus incorporated into the link 60, which is operative in the event the established connection is held a predetermined time interval to warn the subscribers at the substations A and C, and then subsequently to cause the link 60 to be released and the line circuits associated with the subscriber lines 115 and 315 to be operated to lock these subscriber lines out, in the event the established connection is held an additional predetermined time interval. More particularly, when the call is answered at the called subscriber substation C the ring cut-off relay R360 operates, as previously noted, thereby to complete, at RA364, the previously traced circuit for energizing the relay R355. When thus energized the relay R355

operates to complete, at RA357, the previously traced circuit for energizing the relay R385, which latter relay being of the slow-to-operate type operates shortly thereafter. Upon operating, the relay R385 prepares, at RA385, a circuit traced hereinafter for energizing the relay R210, and prepares, at RA386, a circuit traced hereinafter for returning tick tone current by way of the loop circuits extending to the calling and called subscriber substations A and C to the receivers of the telephone instruments thereat. Also, the relay R385 completes, at RA387', a circuit for energizing the rotary magnet M345 of the minor switch 325 from the pulse ground lead C807', this circuit extending from the pulse ground lead C807' by way of RA387', C806, and the winding of M345 to battery. While the established connection is held between the calling subscriber substation A and the called subscriber substation C by way of the link 60, a timer associated therewith operates to apply intermittently ground pulses to the pulse ground lead C807' the rotary magnet M345 of the minor switch 325 is energized. When thus energized the rotary magnet M345 operates to rotate the wipers noted of the rotary switches included in the minor switch step by step away from their normal positions. After a predetermined time interval the wiper 331 of the rotary switch 330 included in the minor switch 325 is rotated nine steps away from its normal position, thereby to complete at the ninth contact in the contact bank 333 of the rotary switch 330 the previously mentioned circuit for returning tick tone current over the loop circuits extending to the calling and called subscriber substations A and C to the receivers of the telephone instruments thereat, this circuit extending from the ungrounded terminal of a source of tick tone current by way of the tick tone lead C805, the condenser 805, RA386, C804, the conductor 332 and the associated wiper 331, to the ninth contact in the contact bank 333 of the rotary switch 330, and therefrom by way of C228 to RC243, from RC246 by way of RA255, RA254, and the upper winding of R260 to battery, RC243 and RC246 being included in the previously traced loop circuits extending to the calling and called subscriber substations A and C, and being connected together by way of the receivers of the telephone instruments thereat. When the subscribers at the substations A and C hear the tick tone produced in the receivers of the telephone instruments thereat by the tick tone current returned therethrough, they are advised that the established connection has been held a predetermined time interval and that shortly thereafter and at the expiration of an additional time interval the established connection will be automatically released.

In the event that the subscriber at the substation A does not release the established connection at this time by replacing the receiver of the telephone instrument thereat upon its hook, shortly thereafter the wiper 331 of the rotary switch 330 included in the minor switch 325 is rotated into its tenth position whereupon the previously mentioned circuit for energizing the relay R210 is completed. This circuit for energizing the relay R210 extends from ground, at RC236, by way of RA235, C239, and C218 to the tenth contact in the contact bank 333 of the rotary switch 330, and therefrom by way of the wiper 331 and associated conductor 332 in the rotary switch 330, C804, C823, RA385, C205, and

the winding of R210 to battery. When energized over the above-traced circuit the relay R210 operates to interrupt, at RA211 and RA212, the loop circuit extending between the subscriber substation A and the line relay R260, thereby to cause the latter relay to restore. Upon restoring, the relay R260 causes the hold relay R265 to restore, which latter relay causes the relay R225 to restore, as previously noted. Also, upon operating, the relay R210 interrupts, at RA214, the original circuit for energizing the relay R220, which latter relay being of the slow-to-release type does not immediately restore, and completes, at RA213, a holding circuit for itself extending from the grounded control conductor C123 by way of RA213, and the winding of R210 to battery. When the hold relay R265 restores it also interrupts, at RA268, the path for applying ground potential to the control conductor C283, thereby to interrupt the circuit for energizing the lower winding of the ring cut-off relay R360, the circuit for energizing the relay R380, and the circuit for energizing the lower winding of the relay R395. Shortly thereafter the relays R220 and R360 restore, and the relays R395 and R380 restore substantially immediately. Upon restoring, the ring cut-off relay R360 interrupts, at RA364, the circuit for energizing the relay R355, thereby to cause the latter relay to restore and interrupt, at RA357, the circuit for energizing the relay R385, thereby to cause the latter relay to restore.

Upon restoring, the relay R220 completes, at RA224, the previously traced circuit for energizing the release magnet M343 of the minor switch 325 by way of the off-normal springs 339 associated therewith, which were actuated to move the switch springs 341 and 342 into engagement incident to the operation of the minor switch 325. The minor switch 325 is then released and the wipers of the rotary switches therein returned to their normal positions, as previously explained. When the wipers of the rotary switches in the minor switch 325 are returned to their normal positions the off-normal springs 339 associated therewith are actuated to move the switch springs 340 and 341 into engagement, thereby to complete the previously traced circuit for energizing the release magnet M344 of the Strowger mechanism included in the connector switch 200. The release magnet M344 then operates, thereby to cause the carriage of the Strowger mechanism included in the connector switch 200 to be returned to its normal position, as previously explained. Shortly after the hold relay R265 restores, the relay R225 restores to interrupt the path for applying ground potential to control conductor C123, thereby to interrupt the holding circuit for energizing the relay R210, in order to cause the latter relay to restore. At this time all of the operated relays in the connector switch 200 are restored, and the connector switch is completely released. Also when ground potential is removed from the control conductor C123 the carriage of the Strowger mechanism included in the finder switch 101 is returned to its normal position, as previously explained, thereby to cause the finder switch 101 to be completely released. At this time, the link 60 is completely released for further use. The line circuit 100 associated with the subscriber line 115, and the line circuit associated with the subscriber line 315, operates to cause the respective subscriber lines to be permanently locked out, in the manner previously described, in the event the receivers of the tele-

phone instruments at the subscriber substations A and C are not immediately returned to their respective hooks.

The operation of the line circuit 100 associated with the subscriber line 115, when the subscriber line is a called line, will best be understood by the description of the extension of a call from a substation within the suboffice to the substation A. For example, in order to extend a call from the subscriber substation C to the subscriber substation A, the receiver of the telephone instrument at the substation C is removed from its hook, thereby to cause the line circuit associated with the subscriber line 315 to operate. The line circuit associated with the subscriber line 315 operates in the previously described manner, thereby to cause the distributor associated with the group of lines including the subscriber line 315 to operate and assign a previously selected idle link to the use of the calling substation C. Assuming that the illustrated link 60 is assigned by the distributor 700 to the use of the calling line 315, the finder switch 101 thereof operates in the previously described manner to seize the subscriber line 315. After the subscriber line 315 is seized the subscriber at the substation C dials successively the three directory digits corresponding to the called substation A whereupon the connector switch 200 operates, in the previously described manner, to seize the called subscriber line 115, and subsequently to project ringing current thereover in the event the subscriber line 115 is idle. Assuming that the called subscriber line 115 is idle when the connector switch 200 seizes the subscriber line 115, ground potential in the connector switch is applied to the control conductor C119 thereof. This application of ground potential to the control conductor C119 completes a circuit for energizing the cut-off relay R160, this circuit extending over the grounded control conductor C119 by way of RA156 and the back contact associated therewith, and the winding of R160 to battery. When energized over the above-traced circuit the cut-off relay R160 operates to interrupt, at RA162 and at RA163, points in the bridge circuit for energizing the line relay R155, and completes, at RA165 and the front contact associated therewith, the previously traced circuit for energizing the lock-out relay R150, which latter relay operates, as previously explained. The interruption, at RA162 and RA163, of the points in the bridge circuit for energizing the line relay R155 prevents operation of this line relay when the call at the subscriber substation A is answered, thereby to prevent ground potential from being applied to the start lead C137 extending to the distributor 700, and the consequent operation of the distributor 700 to assign a previously selected idle link to the use of the called subscriber line 115 at this time. The operation of the connector switch 200 incident to the removal of the receiver of the telephone instrument at the called substation A from its hook, in order to answer the call extending thereto, is the same as that previously described. Also the release of the established connection between the subscriber substations C and A is the same as that previously described.

70 *Reverting substation to substation calls within the suboffice*

A reverting call which is to be extended from one subscriber substation to another on the same subscriber line within the suboffice is initiated 75 at the calling substation by removing the receiver

of the telephone instrument thereat from its hook. For example, in extending a call from the subscriber substation A to the subscriber substation B within the suboffice 50, the call is first initiated at the substation A by removing the receiver of the telephone instrument thereat from its hook, thereby to cause the line circuit 100 associated with the subscriber line 115 to operate, in the previously described manner, and cause the distributor 700 to assign a previously selected 10 idle link in the first group of links to the use of the calling subscriber line 115. Assuming that the illustrated link 60 is assigned to the use of the calling subscriber line 115, the finder switch 101 thereof operates, in the previously described 15 manner, in order to seize the calling subscriber line 115. The subscriber at the substation A then dials successively the three directory digits corresponding to the called subscriber substation B, thereby to cause the connector switch 200 to 20 operate and seize the called subscriber line 115, as previously explained. Due to the fact that the calling subscriber line is the same as the called subscriber line, namely, the subscriber line 115, the called subscriber line is busy and is marked 25 as busy by the application of ground potential to the control conductor C119 thereof. Accordingly, the connector switch 200 operates to return busy tone current over the loop circuit extending to the calling subscriber line 115, in the manner previously explained. 30

Upon hearing the busy tone in the receiver of the telephone instrument at the calling subscriber substation A, the subscriber thereat replaces the receiver of the telephone instrument thereat upon 35 its hook, thereby to interrupt the loop circuit extending to the line relay R260 in the connector switch 200. The line relay R260 then restores to cause the hold relay R265 to restore, as previously explained. Upon restoring, the hold relay 40 R265 completes, at RA265 and the back contact associated therewith, a path for applying multiple ground potential to the control wiper 303 carried by the carriage of the Strowger mechanism included in the connector switch 200, this path 45 extending from ground, at RC236, by way of RA235, C239, RA265 and the back contact associated therewith, C295, RA375 and the front contact associated therewith, the test relay R370 being operated at this time, RC348, RA348, C284, 50 RA281, C217, and the conductor 336 and associated wiper 335 of the rotary switch 334 in the minor switch 325 to the multiple-connected contacts in the contact bank 337 thereof, and therefrom by way of C820 and C800 to the control 55 wiper 303.

This ground potential is fed forwardly by way of the control wiper 303, the control conductor C119 of the called subscriber line 115, RA156 and the back contact associated therewith, RA161, 60 the control conductor C118, the contacts in the operated Strowger mechanism included in the finder switch 101, C126, and RA183 to the grounded control conductor C123. Shortly thereafter the relay R225, being of the slow-to-release type, 65 restores to interrupt, at RA226 and the front contact associated therewith, the multiple path for applying ground potential to the grounded control conductor C123, and to complete at RA226 and the back contact associated therewith, the 70 circuit for energizing the relay R210, this circuit extending from the grounded control conductor C123 by way of RA226 and the back contact associated therewith, RA221, C204, RA373, C205, and the winding of R210 to battery. When energized 75

over the above-traced circuit, the relay R210 operates to complete, at RA213, an obvious holding circuit for itself, and completes, at RA215, a circuit for energizing the lower winding of the switching relay R395, this circuit extending from ground, at RC236, by way of RA235, RA223, RA215, C219, and the lower winding of R395 to battery. When energized over the above-traced circuit the switching relay R395 operates to complete, at RA396 and the front contact associated therewith, a multiple path for applying ground potential to the control wiper 303 carried by the carriage of the Strowger mechanism included in the connector switch 200, and completes, at RA395 or at RA395', the circuit for projecting ringing current over the called subscriber line 115. At this time the ring control relay R390 is operated in the event the third digit dialed is an even digit, as previously noted; and the relay R220 is held in an operated position over a holding circuit extending from the grounded control conductor C123 by way of RA356, C206, and the winding of R220 to battery. Also, the relays R350, R370 and R210 are held in their operated positions by way of the previously traced holding circuits from the grounded control conductor C123. Also, the relay R390 is held in its operated position by way of the previously traced holding circuit therefrom from the grounded control conductor C123 in the event that it is initially operated. Also ringing current is projected over the called subscriber line 115 at this time, in a manner similar to that previously described, thereby to cause the ringer at the called subscriber substation B to be actuated in a characteristic manner.

The call is answered at the subscriber substation B by removing the receiver of the telephone instrument thereat from its hook, thereby to complete a circuit for energizing the ring cut-off relay R360, in a manner similar to that previously explained. Upon operating, the ring cut-off relay R360 interrupts the circuit for projecting ringing current over the called subscriber line 115, and completes, at RA364, the previously traced circuit for energizing the relay R355. When thus energized, the relay R355 operates to interrupt, at RA356, the previously traced holding circuit for energizing the relay R220. Shortly thereafter the relay R220, being of the slow-to-release type, restores to interrupt, at RA223, the previously traced circuit for energizing the lower winding of the switching relay R395, thereby to cause the latter relay to restore. Upon restoring, the relay R395 interrupts, at RA395 and RA395' points in the loop circuit extending to the called subscriber substation B, thereby to cause the ring cut-off relay R360 to restore. Upon restoring, the relay R360 interrupts, at RA364, the previously traced circuit for energizing the relay R355, thereby causing the latter relay to restore. Also, upon restoring, the switching relay R395 interrupts, at RA396 and the front contact associated therewith, the previously traced path for applying multiple ground potential to the control wiper 303. Also, upon restoring, the relay R220 completes, at RA224, the previously traced circuit for energizing the release magnet M343 of the minor switch 325, thereby to cause operation thereof. Upon operating, the release magnet M343 of the minor switch 325 causes the wipers of the rotary switches included therein to be returned to their normal positions. When the wiper 335 of the rotary switch 334 is returned to its normal posi-

tion, the previously traced path for applying ground potential to the control wiper 303 is interrupted. When this ground potential is removed from the control wiper 303 ground potential is completely removed therefrom, thereby to interrupt the previously traced path for applying ground potential to the control conductor C123. When ground potential is removed from the control conductor C123 the holding circuits for energizing the relays R370, R390, in the event it is operated, and R220 are interrupted, thereby to cause these relays to restore. Also, the removal of ground potential from the control conductor C123 causes the carriage of the Strowger mechanism included in the finder switch 101 to be returned to its normal position, thereby to cause the finder switch 101 to be completely released.

Furthermore, when ground potential is removed from the control conductor C123 the circuit for energizing the cut-off relay R160 is interrupted, thereby to cause R160 to restore and complete the circuit for energizing the line relay R155. The line relay R155 then operates to complete the previously traced holding circuit for energizing the lock-out relay R150. At this time, the line circuit 100 associated with the subscriber line 115 is operated to cause this subscriber line to be locked out. Furthermore, the link 60 which was employed in extending the connection between the calling subscriber substation A and the called subscriber substation B is completely released for further use. Shortly after the receiver of the telephone instrument at the substation A is replaced upon its hook, it is again removed therefrom, whereupon the telephone instruments at both the subscriber substations A and B are connected to the subscriber line 115, talking battery being supplied to the loop circuit therebetween by way of the line relay R155. The release of the established connection between the subscriber substations A and B is under the control of the last party to replace the receiver of the telephone instrument upon its hook, thereby to interrupt the bridge circuit for energizing the line relay R155. When the bridge circuit for energizing the line relay R155 is thus interrupted, this relay restores to interrupt the circuit for energizing the lock-out relay R150, thereby to cause the latter relay to restore shortly thereafter. At this time the line circuit 100 associated with the subscriber line 115 is completely released, and this subscriber line is marked as idle to the finder and connector switches of the links having access thereto.

Calls from a substation in the suboffice to a line in the second group of trunk lines

A call which is to be extended from one of the subscriber substations in the suboffice to a line in the second group of trunk lines is initiated at the calling substation by removing the receiver of the telephone instrument thereat from its hook. For example, in extending a call from the subscriber substation A in the suboffice 50 to an idle line in the second group of trunk lines, the call is first initiated at the substation A by removing the receiver of the telephone instrument thereat from its hook, thereby to cause the line circuit 100 associated with the subscriber line 115 to operate, in the previously described manner, in order to cause the distributor 700 to assign a previously selected idle link in the first group of links to the use of this calling subscriber line. Assuming that the illustrated link 60 is assigned 75

to the use of the calling subscriber line 115, the finder switch 101 thereof operates, as previously described, in order to seize the subscriber line 115. The subscriber at the substation A then dials successively a first digit 9 and a predetermined second digit, thereby to cause the connector switch 200 to operate automatically to find an idle line in the second group of trunk lines. More particularly, when the first digit 9 is dialed the carriage of the Strowger mechanism included in the connector switch 200 is moved in a vertical direction to the ninth level of contacts in the contact bank 300 thereof by the vertical magnet M201 thereof, in the previously described manner. When the carriage of the Strowger mechanism included in the connector switch 200 is moved vertically to the ninth level the two sets of switch springs 210 and 338 are actuated, thereby to move the switch springs included in each of these sets of switch springs into engagement. When the switch springs included in the set of switch springs 210 are moved into engagement a circuit traced hereinafter is prepared for energizing the lower winding of the cut-through relay R240, and when the switch springs included in the set of switch springs 338 are moved into engagement a circuit traced hereinafter is prepared for energizing the test relay R370. When the predetermined second digit is dialed the carriage of the Strowger mechanism included in the connector switch 200 is moved radially a corresponding number of steps to the position of the first line included in the second group of trunk lines by the rotary magnet M346 thereof, in the previously described manner, thereby to cause the wipers carried by the carriage of the Strowger mechanism to engage the contacts in the associated contact bank 300 terminating the first line in the second group of trunk lines.

Assuming, for purposes of illustration, that the line 320, which is actually a line in the first group of trunk lines, is a line in the second group of trunk lines, at this time the line wipers 301 and 302 respectively engage the contacts 306 and 308, and the control wipers 303 and 304 respectively engage the contacts 310 and 312. The line conductors C321 and C322 of the trunk line 320 are terminated by the contacts 306 and 308, respectively, while the control conductor C323 thereof is terminated by the contact 310. The contact 312 terminates a conductor connected to the control conductor C323, as indicated by the "W" wiring. It is noted that a similar conductor is connected to the control conductor corresponding to the control conductor C323 of the trunk line 320 in each line in the second group of trunk lines except the last line therein, in which case the "W" wiring illustrated is not employed. As previously noted, the relay R280 is energized in multiple with the rotary magnet M346 of the Strowger mechanism included in the connector switch 200, and operates to complete, at RA282 and the front contact associated therewith, the previously traced circuit for energizing the relay R345, thereby to cause the latter relay to operate. Upon operating, the relay R345 completes, at RA347, a circuit for energizing the lower winding of the cut-through relay R240, this circuit extending from the grounded control conductor C123 by way of RA347, C298, the switch springs 210, and the lower winding of R240 to battery. Also the relay R345 completes, at RA348', the previously traced path for short-circuiting the relay R350, and prepares, at RA348 and RA349,

a circuit traced hereinafter for energizing the test relay R370 by way of a test circuit including the control wiper 303. Further the relay R345 prepares, at RA346, a circuit traced hereinafter for energizing the lower winding of the ring control relay R390 by way of the control wiper 304. When energized over the above-traced circuit the cut-through relay R240 partially operates to complete at the "X" contacts thereof, RA246 and RA249, a path for short-circuiting the upper winding thereof, this path extending from the grounded control conductor C123 by way of RA372 and the back contact associated therewith, C298, RA249, RA246, the upper winding of R240, the switch springs 210, C298, and RA347, to the grounded control conductor C123.

In the event the called line in the second group of trunks is busy, ground potential appears upon the control conductor C323 thereof, as previously explained, and shortly following the predetermined second digit dialed the relay R280 restores, thereby to complete, at RA281, the previously mentioned circuit for energizing the test relay R370, this circuit extending from the grounded conductor C323 by way of the contact 310, the control wiper 303, C800, C820, the switch springs 338, C217, RA281, C284, RA348, RA349, and the winding of R370 to battery. When energized over the above-traced circuit the test relay R370 operates to prepare, at RA374, the previously traced circuit for returning busy tone current over the loop circuit extending to the calling subscriber substation A, this circuit being interrupted at this time, at RA345, due to the fact that the relay R345 is slow to release, and does not restore immediately after the relay R280 restores. Further, the relay R370 completes, at RA371, the previously mentioned circuit for energizing the lower winding of the relay R390, this circuit extending from the grounded control conductor C323 of the line 320 in the second group of trunk lines by way of the "W" wiring illustrated, the contact 312, the control wiper 304, C801, RA371, RA346, C297, RC394, RA394, MA346, and the lower winding of R390 to battery. Also the relay R370 prepares at RA372 and the front contact associated therewith, its previously traced holding circuit. When energized over the above-traced circuit the relay R390 operates to complete, at RA393 and RA394, its previously traced holding circuit, and to interrupt, at RA394 and RC394, the previously traced original circuit for energizing the lower winding thereof. Also, upon operating, the relay R390 completes, at RA393', a circuit for energizing in multiple the relay R345 and the rotary magnet M346 of the Strowger mechanism included in the connector switch 200, this circuit extending from ground, at RA268, by way of C283, RA393', C216, RA276, RC276, C289 and RA393' to the conductor C288, one branch of this path extending from the conductor C288, by way of the winding of the rotary magnet M346 to battery, and the other branch extending from the conductor C288 by way of RA282 and the back contact associated therewith, and the winding of R345 to battery. When the relay R345 is energized over the above-traced circuit, it is retained in its operated position, and when the rotary magnet M346 is energized over the above-traced circuit it operates to move the carriage of the Strowger mechanism included in the connector switch 200 one step in the radial direction, thereby to cause the wipers carried by the carriage of the Strowger mechanism to engage the contacts in the

contact bank 300 terminating the second line in the second group of trunk lines. Also, upon operating, the rotary magnet M346 interrupts, at 5 MA346, a point in the holding circuit for energizing the relay R390, thereby causing the latter relay to restore, and interrupt, at RA393', the previously traced circuit for energizing in multiple the relay R345 and the rotary magnet M346. At this time the wipers carried by the 10 carriage of the Strowger mechanism included in the connector switch 200 engage the contacts in the associated contact bank 300 terminating the second line in the second group of lines, and the subsequent operation of the connector switch 15 200 depends upon the idle or busy condition of this second line. In the event that the second line is busy ground potential appears upon the control conductor thereof, corresponding to the control conductor C323 of the line 320, thereby 20 to cause the test relay R370 to be reoperated, and the apparatus associated therewith to operate, in the previously described manner, in order to cause the carriage of the Strowger mechanism included in the connector switch 200 to be moved another step in the rotary direction.

This apparatus continues to operate in the above described manner until an idle line or the last busy line in the second group of trunk lines is seized by the connector switch 200. When 30 an idle line in the second group of trunk lines is seized by the connector switch the test relay R370 is short-circuited, thereby to arrest further radial movement of the carriage of the Strowger mechanism included in the connector switch 200. 35 When the relay R390 restores to interrupt, at RA393', the circuit for energizing in multiple the relay R345 and the rotary magnet M346, the path for short-circuiting the relay R350 is interrupted. The relay R350 then operates in series with the relay R345, as previously explained. Upon operating, the relay R350 completes, at RA351 and RA352, the previously traced holding circuit for itself, prepares, at RA354, the previously traced circuit for energizing the relay R380, and interrupts, at RA351 and RC353, the circuit for energizing in series the relays R345 and R350. Short- 40 ly thereafter the relay R345, being of the slow-to-release type, restores to interrupt, at RA347, the path for short-circuiting the upper winding of the relay R240, whereupon the lower and upper windings of the cut-through relay R240 are energized in series over a path extending from the grounded control conductor C123 by way of RA372 and the back contact associated therewith, C298, RA249, RA246, and the upper and lower windings of R240 to battery. When energized over the above-traced circuit the relay R240 completely operates to complete, at RA249 and RC246, a path for short-circuiting the upper winding of the switching relay R395, this path 50 extending from ground, at RA287, by way of C299, RA376, C817, the upper winding of R395, C818, RA375 and the back contact associated therewith, RC348, RA348, C284, RA281, C217, RC246, RA249, C296, and RA372 and the back contact associated therewith, to the grounded control conductor C123. When this short-circuiting path is completed, the switching relay R395 is 55 positively prevented from operating. Also, upon fully operating, the relay R240 interrupts, at 60 RA247, a point in the circuit for impulsing the control magnets of the Strowger mechanism included in the connector switch 200 and of the minor switch 325, thereby to positively prevent further operation thereof. Also, at RA247, the 65 relay R240 interrupts the circuit for energizing 70 75

the hold relay R265, thereby to cause the latter relay to restore shortly thereafter. Further, the relay R246 completes, at RA241 and RA242, and at RA244 and RA245, a metallic connection between the subscriber line 115 and the line seized by the connector switch in the second group of trunk lines, this metallic circuit extending from the line conductor C116 by way of the contacts in the Strowger mechanism included in the finder switch 101, C124, RA181, C121, RA211, C282, RA242, RA241, C291, and the line wiper 301 to the contact in the contact bank 300 terminating one line conductor of the seized line, and from the line conductor C117 by way of the contacts in the Strowger mechanism included in the 15 finder switch 101, C125, RA182, C122, RA212, C283, RA245, RA244, C293, and the line wiper 302 to the contact in the contact bank 300 terminating the other line conductor of the seized line. Finally, the relay R240 interrupts, at 20 RA242 and RC243, and at RA245 and RC246, points in the original loop circuit extending between the subscriber substation A and the line relay R260, thereby to cause the latter relay to restore. At this time a metallic connection is 25 extended from the subscriber substation A to the seized line in the second group of trunk lines, and the automatic switch train associated with the seized line is operated to cause ground potential to be returned by way of the control contact 30 in the contact bank 300 terminating the control conductor thereof, the control wiper 303, C800, C820, the switch springs 338, C217, RC246, RA249, C296, and RA372 and the back contact associated therewith, to the control conductor C123. This 35 application of ground potential to the control conductor C123 retains the relays R220, R240 and R350 in their operated positions. Upon restoring, the hold relay R265 interrupts, at RA266, the circuit for energizing the relay R225, thereby to cause the latter relay to restore shortly 40 thereafter. The automatic switch train associated with the seized line in the second group of lines is now in condition to be responsive to a further digit dialed at the substation A in order to forward the connection, the metallic loop circuit between the subscriber line 115 and the seized line in the second group of trunk lines being 45 free of impedance elements.

The established connection between the subscriber substation A and the line in the second group of trunk lines may be released under the control of the subscriber at the substation A. When the subscriber at the substation A replaces the receiver of the telephone instrument thereof upon its hook the loop circuit extending from the substation A to the automatic switch train associated with the line in the second group of lines seized by the connector switch 200 is interrupted, thereby to cause this switch train to be released. When this switch train is released 55 ground potential therein is removed from the control conductor thereof in order to cause ground potential to be removed from the control conductor C123. When ground potential is removed from the control conductor C123 the previously traced circuit for energizing the relay R220, and the previously traced holding circuits for energizing the relays R240 and R350, are interrupted, thereby to cause these relays to restore. Upon restoring, the relay R240 prepares, at 60 RA248, the previously traced circuit for energizing the release magnet M344 of the Strowger mechanism included in the connector switch 200, which circuit is completed, at RA224, upon the restoration of the relay R220. The carriage of 65 70 75

the Strowger mechanism included in the connector switch 200 is then returned to its normal position, as previously explained, thereby to release the connector switch 200. Also the removal of ground potential from the control conductor C123 causes the finder switch 101 to be released, as previously explained, thereby to release the link 60 for further use. Finally, the removal of ground potential from the control conductor C123 causes the line circuit associated with the subscriber line 115 to be released, as previously explained.

As previously noted, the apparatus incorporated in the connector switch 200 continues to operate in the above described manner until an idle line or the last busy line in the second group of trunk lines is seized by the connector switch 200. Assuming that the last busy line in the second group of trunk lines is seized by the connector switch, the previously traced circuit for energizing the test relay R370 is completed, and the previously traced circuit for energizing the lower winding of the relay R390 is not completed due to the fact that the control conductor of this line corresponding to the control conductor C323 is not connected to a contact in the contact bank which is engaged by the control wiper 304. Accordingly, only the test relay R370 operates, and shortly thereafter the relay R345 restores to complete, at RA349 and RC349, the previously traced holding circuit for energizing the test relay R370. Upon operating, the test relay R370 prepares, at RA374, a point in the previously traced circuit for returning busy tone current over the loop circuit extending to the calling subscriber substation A, which circuit is completed, at RA345, upon the restoration of the relay R345. The resultant busy tone produced by the receiver of the telephone instrument at the calling subscriber substation A indicates to the subscriber thereat that all of the lines in the second group of trunk lines are busy and that an established connection including one of these trunk lines can not be completed at this time. The subscriber at the substation A may release the link 60 and the line circuit 100 associated with the subscriber line 115 in the previously described manner by replacing the receiver of the telephone instrument at the substation A upon its hook.

Calls from a substation in the suboffice to the central office routed therebetween by way of a line in the first group of trunk lines

55 A call which is to be extended to the central office from a subscriber substation in the suboffice is routed therebetween by way of one of the lines in the first group of trunk lines, and is initiated at the calling substation by removing the receiver of the telephone instrument thereat from its hook. For example, in extending a call from the subscriber substation A in the suboffice 50 to the central office 698, the call is first initiated at the substation A by removing the receiver of the telephone instrument thereat from its hook, thereby to cause the line circuit 100 associated with the subscriber line 115 to operate in the previously described manner in order to cause the distributor 100 to assign a previously selected idle link in the first group of links to the use of this calling subscriber line. Assuming that the illustrated link 60 is assigned to the use of the calling subscriber line 115, the finder switch 101 thereof operates, as previously explained in order to seize the subscriber line

115. The subscriber at the substation A then dials the single digit 0, thereby to cause the connector switch 200 to operate automatically to find an idle line in the first group of trunk lines extending to the central office 698. More particularly, when the single digit 0 is dialed the carriage of the Strowger mechanism included in the connector switch 200 is moved in the vertical direction to the tenth level of contacts in the contact bank 300 thereof by the vertical magnet M201 thereof, in the previously described manner. When the carriage of the Strowger mechanism included in the connector switch 200 is moved vertically to the tenth level the three sets of switch springs 210, 338 and 249 are actuated, thereby to move the switch springs included in each of these sets of switch springs into engagement. Also the vertical off-normal springs 209 and 345 associated with the carriage of the Strowger mechanism included in the connector switch 200 are respectively moved into disengagement and into engagement, thereby respectively to interrupt the circuit for energizing the upper winding of the relay R270 and to prepare the circuit for energizing the release magnet M344 of this Strowger mechanism, as previously noted. However, before the relay R270 restores this relay, being of the slow-to-release type, a circuit is completed for energizing the lower winding of the relay R390 when the switch springs 249 are moved into engagement, this circuit extending from ground, at RA268, by way of C283, RA398', C216, RA276, RA275, the switch springs 249, C297, RC394, RA394, MA346, and the lower winding of R390 to battery. When energized over the above-traced circuit the relay R390 operates to complete, at RA393 and RA394, a holding circuit for itself extending from the grounded control conductor C123 by way of RA397' and the back contact associated therewith, RA393, RA394, MA346, and the lower winding of R390 to battery. Also, upon operating, the relay R390 interrupts, at RA394 and RC394, the above-traced original circuit for energizing the lower winding thereof, and prepares, at RA393', a circuit traced hereinafter for energizing in multiple the relay R280 and the rotary magnet M346 of the Strowger mechanism included in the connector switch 200.

Upon restoring, the relay R270 completes, at RA276 and RC276, the previously mentioned circuit for energizing in multiple the relay R280 and the rotary magnet M346, this circuit extending from ground, at RA268, by way of C283, RA398', C216, RA276, RC276, C289, and RA393' to the conductor C288, one branch extending from the conductor C288 by way of RA350 and the back contact associated therewith, RA378, RA377, C285, and the winding of R280 to battery, and the other branch extending from the conductor C288 by way of the winding of M346 to battery. When energized over the above-traced circuit the relay R280 operates to complete, at RA282 and the front contact associated therewith, the previously traced circuit for energizing the relay R345. When thus energized the relay R345 interrupts, at RA345, the previously traced circuit for returning busy tone current over the loop circuit extending to the calling subscriber substation A, and completes, at RA348', the previously traced path for short-circuiting the relay R350. Also the relay R345 completes, at RA347, the previously traced circuit for energizing the lower winding of the relay R240, and prepares, at RA348 and RA349, the previously traced circuit

for energizing the test relay R370. When thus energized the relay R240 partially operates to close its "X" contacts, RA246 and RA249, thereby to complete the previously traced path for shortcircuiting the upper winding thereof.

When energized over the above-traced circuit the rotary magnet M346 operates to move the carriage of the Strowger mechanism included in the connector switch 200 one step in the rotary direction, thereby to cause the first line 320 in the first group of trunk lines to be seized. Also, upon operating, the rotary magnet M346 interrupts, at MA346, the previously traced holding circuit for energizing the lower winding of the relay R390, thereby to cause the latter relay to restore. Upon restoring, the relay R390 interrupts, at RA393', the previously traced circuit for energizing in multiple the rotary magnet M346 and the relay R280. The subsequent operation of the connector switch 200 depends upon the idle or busy condition of the line 320. In the event the line 320 is busy, ground potential appears upon the control conductor C323, thereby to complete the previously traced circuit for energizing the test relay R370 subsequent to the restoration of the relay R280. Also ground potential appears upon the contact 312 in the contact bank 300 engaged by the control wiper 304 due to the connection between the contact 312 and the control conductor C323 indicated by the "W" wiring. Thus the previously traced circuit for energizing the lower winding of the relay R390 is completed. Also, upon restoring, the relay R280 prepares, at RA282 and the back contact associated therewith, the previously traced circuit for energizing in multiple the relay R345 and the rotary magnet M346. Also, upon restoring, the relay R280 interrupts, at RA282 and the front contact associated therewith, the previously traced circuit for energizing the relay R345, and the previously traced path for short-circuiting the relay R350. The relay R350 is then energized in series with the relay R345, and operates to complete at RA351 and RA352, the previously traced holding circuit for energizing the winding thereof. The relay R345, being of the slow-to-release type, does not immediately restore. When thus energized the relay R390 re-operates to complete, at RA393', the previously traced circuit for energizing in multiple the relay R345 and the rotary magnet M346. When thus energized, the relay R345 remains in its operated position, and the rotary magnet M346 operates to move the carriage of the Strowger mechanism included in the connector switch 200 another step in the rotary direction. This apparatus operates in the above-described manner until an idle line or the last busy line in the first group of trunk lines is seized by the connector switch 200. In the event that the last busy line in the first group of trunk lines is seized by the connector switch 200, the circuit for energizing the test relay R370 is recompleted, as previously explained. However, the circuit for energizing the lower winding of the relay R390 is not completed due to the fact that the "W" wiring illustrated is not provided in the last line in the first group of trunk lines. Thus, the relay R390 does not operate, and shortly thereafter the relay R345 restores to complete, at RA345, the previously traced path for returning busy tone current over the loop circuit extending to the calling subscriber substation A, the test relay R370 being operated at this time. Also, upon operating, the test relay R370 interrupts, at RA372, a point

in the circuit for energizing the lower winding of the relay R240, thereby to cause the latter relay to restore. Upon receiving busy tone the subscriber at the calling substation A may release the link 60 and the line circuit 100 in the manner previously described.

In the event that an idle line is found in the first group of trunk lines, and assuming that the line 320 is an idle line, battery potential appears upon the control conductor C323 thereof, thereby to complete paths for short-circuiting the test relay R370 and the lower winding of the relay R390, these short-circuiting paths being substantially the same as the circuits for energizing the relay R370 and the lower winding of the relay R390. Shortly thereafter, due to the failure of the relay R390 to operate, the relay R345 restores. Upon restoring, the relay R345 interrupts, at RA347, a point in the previously traced path for short-circuiting the upper winding of the relay R240, thereby to cause the previously traced circuit for energizing in series the upper and lower windings of the relay R240 to be completed. The relay R240 then completely operates to interrupt, at RA241, a point in the circuit for energizing the hold relay R265, and a point in the pulsing circuit for energizing the control magnets of the Strowger mechanism included in the connector switch 200 and of the minor switch 325. Also, the relay R240 completes, at R249 and RC246, the previously traced circuit for short-circuiting the upper winding of the switching relay R395, thereby positively to prevent operation thereof. Also, upon fully operating, the relay R240 completes, at RA241 and RA242, and at RA244 and RA245, the previously traced metallic connection between the calling subscriber line 115 and the line conductors C291 and C293, respectively, extending to the line wipers 301 and 302, respectively. Also, it is noted that at this time the line wipers 301 and 302 engage the contacts 306 and 308, respectively, terminating the line conductors C321 and C322 of the line 320, and the control wiper 303 engages the contact 310 terminating the control conductor C323 of the line 320, the control wiper 303 being connected by way of the conductor C300, C820, the switch springs 338, C217, RC246, RA249, C296, and RA372 and the back contact associated therewith, to the control conductor C123. It is noted that the line 320 extends to the alternating current repeater 400 and that, when this line is seized, the repeater 400 operates in order to apply ground potential to the control conductor C323, and ground potential is conducted by way of the above-traced circuit to the control conductor C123. This application of ground potential to the control conductor C123 retains the relays R240, R350, and R220 in their operated positions. Also, upon operating, the relay R240 interrupts, at RC243 and RA242, and at RC246 and RA245, points in the previously traced loop circuit including the line relay R280, thereby to cause the latter relay to restore. Also, shortly after the complete operation of the relay R240, the hold relay R265 restores. At this time a metallic connection is extended by way of the previously traced circuit from the subscriber line to the repeater 400, which connection is free of impedance elements, and the repeater is operated in a manner more fully described subsequently, thereby to condition it to be responsive to subsequent digits dialed at the calling subscriber substation A.

When the connector switch 200 operates to 75

completely seize the line 320, a circuit is completed for energizing the line relay R405 in the repeater 400, this circuit extending from ground, at the lower winding of R405, by way of the 5 lower winding of R405, C488, RA412, and RC413 to the line conductor C322, and from battery at the upper winding of R405 by way of the upper winding of R405, C487, RA415, and RC416 to the line conductor C321, the line conductors C321 and 10 S322 of the line 320 being connected by way of the operated link 60 to the line conductors C116 and C117, respectively, of the calling subscriber line 115 and included in the loop circuit extending to the substation A. When energized over 15 the above-traced circuit the line relay R405 operates to complete, at RA406, a circuit for energizing the impulse relay R420, this circuit extending from ground, at RA446, by way of C486, RA406, and the winding of R420 to battery. 20 When thus energized the relay R420 operates to complete, at RA422 and the front contact associated therewith, a holding circuit for energizing the winding thereof extending from ground at RA422 and the front contact associated therewith, by way of the resistor 408, RA408, and the winding of R420 to battery. Also, upon operating, the relay R420 completes, at RA423 and the front contact associated therewith, a circuit for energizing the relay R445, this circuit extending 25 from ground, at RA557 and the back contact associated therewith, by way of C479, RA423 and the front contact associated therewith, and the winding of R445 to battery. When energized over the above-traced circuit the relay R445 operates 30 to interrupt, at RA446, the path for applying multiple ground potential to the control conductor C486, and to complete, at RA447 and the front contact associated therewith, an obvious circuit for energizing the timer start relay R450. 35 When thus energized, the relay R450 operates to complete, at RA451, an obvious path for applying ground potential to the timer start lead C456, thereby to initiate operation of the timer associated with the repeater 400. Also, upon operating, the relay R450 completes, at RA453, a circuit for energizing the switching relay R460, this circuit extending from ground, at RA453, by way of C475, RA555 and the back contact associated therewith, C476, and the winding of R460 to battery. When energized over the above-traced circuit, the relay R460 operates to complete, at RA464, an obvious circuit for energizing the relay R505, which latter relay then operates to complete, at RA506, a path for applying 45 ground potential to the control conductor C323 of the line 320, this path extending from ground at the upper winding of the impedance Z503 by way of the upper winding of Z503, and RA506 to C323. As previously noted, the control conductor C323 is connected by way of the operated connector switch 200 to the control conductor C123, thereby to cause ground potential to be applied to the latter control conductor in order to retain operated the relays previously noted in 50 the operated link 60 and the line circuit 100 associated with the subscriber line 115. Also, upon operating, the relay R460 connects, at RA461 and RA462, the line conductors C321 and C322 of the line 320 together by way of the condenser 605 and the windings 601 and 602 of the transformer 600, this connection extending from the line conductor C321 by way of RA461, C466, the winding 601, C580, RA541 and the back contact associated therewith, C581, the condenser 605, 55

the winding 602, C467, and RA462 to the line conductor C322.

Also, upon operating, the relay R460 completes, at RA465, a circuit for energizing the relay R640, this circuit extending from ground, at RA465, by way of C483, RA524, C482, RA646, and the winding of R640 to battery. When energized over the above-traced circuit, the relay R640 operates to complete, at RA644, a holding circuit for energizing the winding thereof by way of the control conductor C323, this circuit extending from the grounded control conductor C323 by way of RA644, RA646, and the winding of R640 to battery. Also, upon operating, the relay R640 completes, at RA641, an obvious circuit for energizing the upper winding of the relay R670, and completes, at RA643, an obvious circuit for energizing the lower winding of the impulse relay R680. When thus energized, the relay R670 operates to prepare, at RA672 and the front contact associated therewith, and at RA673 and the front contact associated therewith, a circuit for projecting alternating current over the trunk line 694 extending to the automatic central office 698. When thus energized, the relay R680 operates to complete, at RA685, an obvious path for short-circuiting the upper winding thereof, thereby to render this relay slow to release. Also, the relay R680 completes, at RA681 and at RA682, the previously mentioned circuit for projecting 30 alternating current over the trunk line 694 extending to the automatic central office 698, thereby to cause a repeater therein to be seized. This circuit extends from the conductor C691 connected to one terminal of a suitable source of 35 alternating current supply 690 by way of RA681, the upper winding of the impedance Z655, and RA672 and the front contact associated therewith, to the line conductor C695 and from the conductor C692 connected to the other terminal 40 of the source of alternating current supply 690 by way of RA682, the lower winding of the impedance Z655, and RA673 and the front contact associated therewith, to the line conductor C697, the line conductors C695 and C697 of the trunk 45 line 694 being connected across a winding of the repeater in the central office 698, thereby to cause this repeater to be seized by the alternating current projected over the trunk line 694. Also the relay R680 completes, at RA684, a circuit for energizing the lower winding of the relay R520, this circuit extending from ground, at RA684, by way of C585, RA556, and the lower winding of R520 to battery. When energized over the above-traced circuit the relay R520 operates 50 to complete, at RA521, an obvious holding circuit for energizing the upper winding thereof by way of the control conductor C323, and prepares, at RA522, a circuit traced hereinafter for energizing in multiple the relay R635, and the lower winding of the relay R670. 55

Also, upon operating, the relay R680 completes, at RA684, a circuit for energizing the relay R650, this circuit extending from ground, at RA684, by way of C585, RA642, and the winding of R650 to 60 battery. When energized over the above-traced circuit the relay R650 operates to complete, at RA651, an obvious circuit for energizing the relay R645, which latter relay, being of the slow-to-operate type, operates shortly thereafter to interrupt, at RA646, the previously traced holding circuit for energizing the relay R640. Shortly thereafter, the relay R640, being of the slow-to-release type, restores to interrupt, at RA643, the circuit for energizing the lower winding of the re- 65 70 75

lay R680, which latter relay, being rendered slow to release, restores shortly thereafter to interrupt, at RA681 and RA682, points in the above-traced circuit for projecting alternating current 5 over the trunk line 694 to the central office 698.

At this time the repeater in the central office 698 has been seized, and the repeater 400 is in condition to be responsive to a series of digits dialed at the calling subscriber substation A. 10 The subscriber at the substation A then dials the first digit corresponding to the directory number of the desired line terminating at the central office 698, thereby to transmit a first series of impulses by way of the loop circuit extending between the calling subscriber substation A and the line relay R405. The line relay R405 follows the dialed impulses in the usual manner, restoring each time the loop circuit is interrupted, and operating each time the loop circuit is completed. 15 Each time the relay R405 restores it interrupts, at RA406, the previously traced circuit for energizing the relay R420, thereby to cause the latter relay to restore and complete, at RA422 and the back contact associated therewith, the previously 20 mentioned circuit for energizing in multiple the relay R635 and the lower winding of the relay R670, this circuit extending from ground, at RA422 and the back contact associated therewith, by way of C474 and RA522 to the conductor C571, 25 one branch of this circuit extending from the conductor C571 by way of the winding of the relay R635 to battery, and the other branch of this circuit extending from the conductor C571 by way of the lower winding of the impulse relay R670 30 to battery. When energized over the above-traced circuit, the relay R635 operates to complete, at RA636, an obvious circuit for energizing the upper winding of the relay R670. When either the upper or the lower winding of the relay R670 is energized, this relay operates. Also, 35 each time the relay R420 restores, it interrupts, at RA423 and the front contact associated therewith, the previously traced circuit for energizing the relay R445, and completes, at RA423 and the back contact associated therewith, a circuit for 40 energizing the lower winding of the impulse relay R680, this circuit extending from ground, at RA557 and the back contact associated therewith, by way of C479, RA423 and the back contact 45 associated therewith, RA459, C478, RA598, RA523, C572, and the lower winding of R680 to battery. When energized over the above-traced circuit, the relay R680 operates to complete at RA683 a circuit for energizing the lower winding 50 of the relay R455, this circuit extending from ground at RA683 by way of C468, RA421, and the lower winding of R455 to battery. When thus energized, the relay R455 operates shortly thereafter, this relay being slow to operate due to the 55 obvious path including RA457 for short-circuiting the upper winding thereof. Upon operating, the relay R455 interrupts at RA457 the path for short-circuiting the upper winding thereof, completes at RA456 a holding circuit extending from ground at RA451 by way of RA456, C468, RA421, and the lower winding of R455 to battery for energizing the lower winding thereof, and completes at RA458 an obvious path for applying ground potential to the control conductor C486, thereby to 60 prepare a supplementary circuit for reenergizing the relay R420 when the line relay R405 reoperates. 65

Each time the relay R420 operates it interrupts, at RA422 and the back contact associated therewith, the previously traced circuit for energiz- 70

ing in multiple the relay R635, and the lower winding of the relay R670. The relay R635, being of the slow-to-release type, remains operated during impulsing and retains completed the circuit for energizing the upper winding of the relay R670, thereby to retain the latter relay in its operated position during pulsing. Also, each time the relay R420 operates it interrupts, at RA423 and the back contact associated therewith, the previously traced circuit for energizing the lower winding of the impulse relay R680, thereby to cause the latter relay to restore. Also, each time the relay R420 operates it completes, at RA423 and the front contact associated therewith, the previously traced circuit for energizing the relay R445, and interrupts at RA421 the previously traced holding circuit for energizing the lower winding of the relay R455, thereby to cause the latter relay to restore. The relay R445, being of the slow-to-release type, remains operated during impulsing, thereby to retain the timer start relay R450 in its operated position. 10

Thus, the impulse relay R420 follows the impulses received by the line relay R405 and repeats these impulses to the impulse relay R680, which latter relay operates to repeat a similar series of alternating current impulses by way of the trunk line 694 to the repeater in the central office 698, thereby to cause this repeater to repeat a suitable series of switch control impulses to an automatic switch train in the central office, which switch train operates to seize the desired called line and to project ringing current thereover, in the usual manner. When a subscriber at a substation associated with the called line answers the call by removing the receiver of the telephone instrument thereat from its hook, the automatic switch train in the central office 698 operates to cause the repeater therein to transmit a pulse of alternating current by way of the trunk line 694 to the repeater 400 in the suboffice 50, this repeater being conditioned to be operative in response to the pulse of alternating current transmitted thereto at the conclusion of the last digit dialed at the calling substation A. At the conclusion of the digit dialed at the substation A the line relay R405 reoperates, thereby to cause the impulse relay R420 to reoperate, and consequently, the impulse relay R680 to restore, and the relays R635 and R670 to restore shortly thereafter. Upon restoring, the relay R670 prepares, at RA672 and the back contact associated therewith, and at RA673 and the back contact associated therewith, a circuit traced hereinafter for energizing the ring up relay R630. The previously mentioned circuit for energizing the ring up relay R630 is completed when the repeater in the central office 698 operates to cause a pulse of alternating current to be transmitted over the trunk line 694 to the repeater 400, this circuit extending from the conductor C695 by way of RA672 and the back contact associated therewith, C699, the winding 603 of the transformer 600, the condenser 608, the winding of R630, the winding 604 of the transformer 600, C582, the lower winding of the impedance element Z503, C583, and RA673 and the back contact associated therewith, to the conductor C697, the line conductors C695 and C697 of the trunk line 694 being connected to a suitable source of alternating current in the repeater in the central office 698. When energized over the above-traced circuit, the ring up relay R630 operates to complete, at RA631 and the front contact associated therewith, a circuit for energizing the 75

relay R425, this circuit extending from ground, at RA631 and the front contact associated therewith, by way of C470, RA463 and the front contact associated therewith, C471, RA418 and the back contact associated therewith, and the winding of R425 to battery. When energized over the above-traced circuit, the relay R425 operates to complete, at RA428, a path for short-circuiting the winding of the battery reversing relay R410, this path extending from ground, at RA454, by way of C471, RA431, RA426, the winding of R410, RA418 and the back contact associated therewith, C471, RA463 and the front contact associated therewith, C470, and RA631 and the front contact associated therewith, to ground. At the termination of the pulse of alternating current transmitted from the central office 698 by way of the trunk line 694 to the repeater 400, the ring up relay R630 restores, thereby to interrupt, at RA631 and the front contact associated therewith, a point in the previously traced path for short-circuiting the battery reversing relay R410, thereby to cause the latter relay to be energized in series with the relay R425 over a circuit extending from ground at RA454 by way of C471, RA431, RA426, the winding of R410, and the winding of R425 to battery. When energized over the above-traced circuit the battery reversing relay R410 operates to interrupt, at RA415 and RC416, the previously traced path for applying battery potential, at the upper winding of R405, to the line conductor C321, and to complete, at RA411 and RA412, a path for applying ground potential at the lower winding of R405 to the line conductor C321, this path extending from ground, at the lower winding of R405, by way of the lower winding of R405, C488, RA412 and RA411 to C321. Also, the battery reversing relay R410 interrupts, at RA412 and RC413, the previously traced path for applying ground potential, at the lower winding of R405, to the line conductor C322, and completes, at RA414 and RA415, a path for applying battery potential, at the upper winding of R405, to the line conductor C322, this path extending from battery, at the upper winding of R405, by way of the upper winding of R405, C487, RA415, and RA414 to C322. This reversal of battery potential, as applied to the line conductors C321 and C322 of the trunk line 320, causes a call registering device or the like associated with the calling line to be operated for supervisory purposes. Also, upon operating, the battery reversing relay R410 completes, at RA419, a circuit for energizing the relay R685, this circuit extending from ground, at RA454, by way of C471, RA419, C485, and the winding of R685 to battery. When energized over the above-traced circuit, the relay R685 operates to complete, at RA688, a holding circuit for energizing the winding thereof extending from ground, at RA454, by way of C471, C484, RA688, and the winding of R685 to battery. Also, upon operating, the relay R685 prepares, at RA686, a circuit traced hereinafter for energizing the rotary magnet M612 of the minor switch 625 associated with the repeater 400, and interrupts, at RA687, a point in a circuit traced hereinafter for energizing the release magnet M613 thereof. The minor switch 625 is utilized to time the duration of the established connection including the repeater 400. Also, upon operating, the battery reversing relay R410 completes, at RA417, a circuit for energizing the relay R440, this circuit extending from ground, at RA452, by way of the winding of R440 to battery at RA417. When thus

energized, the relay R440 operates to set its vibratory armature WA441 into operation, thereby to complete intermittently, at RA441, an obvious circuit for energizing the relay R510. The latter relay does not operate immediately due to the facts that it is of the slow-to-operate type, and the circuit for energizing it is only intermittently completed at this time.

In the event the calling subscriber substation A is of the paystation type, paystation tone current is conducted from the ungrounded terminal of a suitable source of supply by way of the paystation tone lead C141, the condenser 148, RA164, and the front contact associated therewith, RA161, C118 and the previously traced circuit in the operated link 60 to the control conductor C323, and therefrom by way of RA506 and the upper winding of the impedance element Z503 to ground. This paystation tone current traversing the upper winding of the impedance element Z503 induces a similar paystation tone current in the lower winding thereof which is included in the previously traced connection between the windings 603 and 604 of the transformer 600 and the repeater in the central office 698, thereby to cause paystation tone to be reproduced in the central office 698 in order to indicate to an operator therein that the calling line is of the paystation type. After a predetermined time interval the amplitude of vibration of the weighted armature WA441 of the relay R440 decreases sufficiently to cause the relay R510 to operate. Upon operating, the relay R510 completes, at RA511, an obvious path for short-circuiting the lower winding of the impedance element Z503, thereby to arrest the transmission of paystation tone current to the central office 698.

As previously noted, upon operating, the relay R685 prepares, at RA686, a circuit for energizing the rotary magnet M612 of the minor switch 625, this circuit being completed in the timer associated with the repeater 400 and extending therefrom over a circuit by way of the pulse ground lead C632, RA628, RA686, and the winding of M612 to battery. When energized over the above-traced circuit the rotary magnet M612 operates to drive the wipers 616 and 619, respectively, of the rotary switches 615 and 618 included in the minor switch 625 one step away from their normal positions. Periodically, the timer associated with the repeater 400 completes the above-traced circuit for energizing the rotary magnet M612, thereby to cause the wipers noted of the rotary switches included in the minor switch 625 to be driven step by step away from their normal positions at a predetermined rate. After the established connection, including the repeater 400, has been held a predetermined time interval, the wiper 619 of the rotary switch 618 engages the ninth contact in the associated contact bank 620, thereby to complete a circuit for returning tick tone current over the loop circuit extending to the calling subscriber substation and the loop circuit extending to the central office 698, this circuit extending from the ungrounded terminal of a suitable source of tick tone current by way of the tick tone lead C648, the wiper 619, and the ninth contact in the associated contact bank 620 of the rotary switch 618, the condenser 607, C647, C467 and RA462 to the conductor C322, and from the conductor C321 by way of RA411, RA412, C488, and the lower winding of R405 to ground, the line conductors C321 and C322 being connected together by way of the loop circuit including the operated link 60 extending to the calling

subscriber substation A. Also, a portion of this tick tone current is conducted over a portion of the above-traced circuit to the conductor C461, and therefrom by way of the winding 602, the 5 condenser 605, C681, RA641 and the back contact associated therewith C680, the winding 601, C466 and RA461 to the conductor C321, and therefrom over another portion of the previously traced circuit. This portion of the tick tone current traversing the windings 601 and 602 of the transformer 600 induces a similar tick tone current in the windings 603 and 604 thereof included in the loop circuit extending by way of the trunk line 694 to the repeater in the central office 698. This tick 10 tone current returned by way of the loop circuits extending to the calling subscriber substation A and to the central office 698 causes tick tone to be produced in the receivers of the telephone instruments at the calling substation A and at the 15 called substation associated with the central office 698, thereby to indicate to the subscribers thereat that the established connection between the substation A and the substation associated with the central office 698 has been held a predetermined time interval. In the event the subscribers at these substations do not release the established connection by replacing the receivers of the telephone instruments thereat upon their hooks in a short time interval, the established 20 connection is automatically blocked. More particularly, when the wiper 616 is driven into engagement with the tenth contact in the associated contact bank 617 of the rotary switch 615, a circuit is completed for energizing the relay R625, 25 this circuit extending from the grounded wiper 616 by way of the tenth contact in the associated contact bank 617 of the rotary switch 615, C684, and the winding of R625 to battery. When energized over the above-traced circuit the relay 30 R625, being of the slow-to-operate type, operates shortly thereafter. Upon operating, the relay R625 completes, at RA626 and at RA627, obvious paths for short-circuiting the windings 601 and 602, respectively, of the transformer 600, thereby 35 to alter the inductive coupling between the primary and secondary windings 601, 602, and 603, 604, respectively, of the transformer 600 and to prevent further communication over the established connection. Also, upon operating, the relay 40 R625 interrupts, at RA628, a point in the circuit for energizing the rotary magnet M612, thereby to arrest further operation thereof. Also, it is noted that when the wipers noted of the rotary switches included in the minor switch 625 are 45 driven away from their normal positions, the off-normal springs 614 are actuated, thereby to prepare a point in the previously mentioned circuit for energizing the release magnet M613 of the minor switch 625. 50 The release of the established connection between the calling subscriber substation A and the called subscriber substation associated with the central office 698 is primarily under the control of the subscriber at the calling substation A. 55 When the subscriber at the calling substation A replaces the receiver of the telephone instrument thereat upon its hook prior to the time the subscriber at the called substation associated with the central office 698 replaces the receiver of 60 the telephone instrument thereat upon its hook, the loop circuit between the subscriber substation A and the line relay R405 in the repeater 400 is interrupted, thereby to cause this relay to restore. Upon restoring, the relay R405 interrupts, 65 70 at RA406, the previously traced circuit for ener-

gizing the relay R428, thereby to cause the latter relay to restore and complete, at RA422 and the back contact associated therewith, the previously traced circuit for energizing in multiple the winding of the relay R635, and the lower winding of 5 the relay R670. When energized over the above-traced circuit the relay R635 operates to complete, at RA636, the previously traced circuit for energizing the upper winding of the relay R670. When the windings of the relay R670 are thus 10 energized, this relay operates to prepare, at RA672 and the front contact associated therewith, and at RA673 and the front contact associated therewith, the previously traced circuit for projecting alternating current over the trunk line 694 extending to the central office 698. Also, upon restoring, the relay R428 completes, at RA423 and the back contact associated therewith, the previously traced circuit for energizing the lower winding of the impulse relay R680, thereby 15 to cause the latter relay to operate and complete, at RA681 and at RA682, the previously mentioned circuit for projecting alternating current over the trunk line 694 extending to the central office 698. This alternating current projected over the trunk line 694 causes the repeater in the central office 698 to operate and cause the switch train associated therewith to be released, thereby to release the seized line extending to the called subscriber substation. 20

Also, upon restoring, the relay R420 interrupts, at RA423 and the front contact associated therewith, the previously traced circuit for energizing the relay R445. The latter relay, being of the slow-to-release type, restores shortly thereafter to interrupt, at RA447 and the front contact associated therewith, the circuit for energizing the relay R450. Shortly thereafter the relay R450 restores and interrupts, at RA451, the path for applying ground potential to the timer start 25 lead C450, thereby to arrest further operation of the timer associated with the repeater 400. Also, upon restoring, the relay R450 interrupts, at RA452, at RA453, and at RA454, the circuits for energizing respectively the relays R440, R460, and R685, thereby to cause these relays to restore, the relays R440 and R685 restoring substantially 30 immediately, and the relay R460, being of the slow-to-release type, restoring shortly thereafter. Upon restoring, the relay R440 interrupts, at RA441, the previously traced circuit for energizing the relay R510, thereby to cause the latter relay to restore. Upon restoring, the relay R685 completes, at RA687, the previously mentioned circuit for energizing the release magnet M613 35 of the minor switch 625, this circuit extending from the grounded switch springs 614 by way of RA687, and the winding of M613 to battery. When energized over the above-traced circuit the release magnet M613 operates to release the minor switch 625 and to cause the wipers of the rotary switches 615 and 618 to be returned to their normal positions. When the wipers of the rotary switches noted, included in the minor switch 625, are returned to their normal positions, 40 the switch springs 614 are actuated into disengagement, thereby to interrupt the circuit for energizing the release magnet M613. Upon restoring, the relay R460 interrupts, at RA464, the circuit for energizing the relay R505, which latter relay, being of the slow-to-release type, restores shortly thereafter to interrupt, at RA506, the path for applying ground potential at the upper winding of the impedance element Z503 to the control conductor C323. When ground po- 45 50 55 60 65 70 75 80 85 90 95 100

tential is removed from the control conductor C323 the circuit for energizing the upper winding of the relay R520 is interrupted, thereby to cause this relay to restore. Also, upon restoring, 5 the relay R505 interrupts, at RA508, a point in the circuit for energizing the impulse relay R680, thereby to cause the latter relay to restore. When the relays R450 and R505 restore ground potential is removed from the control conductor C477, thereby to cause the relays R410 and A425 to restore. Upon restoring, the relay R520 also 10 interrupts, at RA522, the previously traced circuit for energizing in multiple the winding of the relay R635, and the lower winding of the relay R670, thereby to cause the relay R635 to restore shortly thereafter and interrupt, at RA636, the previously traced circuit for energizing the upper winding of the relay R670, thereby to cause the latter relay to restore. 15

When the path for applying ground potential to the control conductor C323 is interrupted, at RA506, by the restoration of the relay R505, ground potential is removed from the control conductor C123 extending into the operated link 60, thereby to cause the operated relays in the connector switch 200, and the finder switch 101 of the link 60, to restore in order to cause the link 60 to be completely released, as previously 20 explained. Also, when ground potential is removed from the control conductor C123 the line circuit 100 associated with the subscriber line 115 is released, as previously explained. 25

When the subscriber at the called substation associated with the central office 698 replaces 30 the receiver of the telephone instrument thereat upon its hook prior to the time the subscriber at the calling substation A replaces the receiver of the telephone instrument thereat upon its hook, the repeater in the central office 698 is operated to cause a pulse of alternating current to be projected over the trunk line 694 extending to the 35 suboffice 50, thereby to complete the previously traced circuit for energizing the ring-up relay R630. When the ring-up relay R630 is thus energized it completes, at RA631 and the front contact associated therewith, a circuit for energizing the upper winding of the relay R435, this circuit extending from ground, at RA631 and the front contact associated therewith, by way of 40 C470, RA463 and the front contact associated therewith, C471, RA418 and the front contact associated therewith, RA431, and the upper winding of R435 to battery. When energized over the 45 above-traced circuit the relay R435 operates partially to prepare, at RA438, a holding circuit for energizing the upper and lower windings thereof in series, which is completed subsequent to the termination of the A. C. pulse; and extends, when completed, from ground, at RA454, by way of C471, RA431, RA438, the lower and upper windings of R435 to battery. When this circuit is completed the relay R435 then operates fully to interrupt, at RA437, the previously traced circuit for energizing the upper winding thereof. Also, 50 the relay R435 completes, at RA436, an obvious circuit for energizing the relay R430, which latter relay, being of the slow-to-operate type, operates shortly thereafter to interrupt, at RA431, the holding circuit for energizing in series the 55 upper and lower windings of the relay R435, and the holding circuit for energizing in series the windings of the relays R410 and R425, thereby to cause these relays to restore. Upon restoring, the relay A410 causes battery potential to be reversed over the line conductor C321 and C322 of 60

the trunk line 320 for supervisory purposes, in the manner previously described. Also, upon restoring the relay R410 interrupts, at RA417, the circuit for energizing the relay R440, thereby to cause the latter relay to restore and interrupt, at RA441, 5 the circuit for energizing the relay R510, thereby to cause the latter relay to restore.

When the party at the calling subscriber substation A then replaces the receiver of the telephone instrument thereat upon its hook, the loop circuit extending between the substation A and the line relay R405 is interrupted, thereby to cause the latter relay to restore. Upon restoring, the relay R405 interrupts, at RA406, the circuit for energizing the relay R420, thereby to cause 15 the latter relay to restore. Upon restoring, the relay R420 causes the remainder of the operated relays in the repeater 400 to restore, in the manner previously explained, and the minor switch 625 to be completely released, thereby to completely release the repeater 400. When the repeater 400 is released the operated link 60 and the line circuit 100 associated with the subscriber line 115 are released, in the previously described manner. 25

Calls from the central office to a substation in the suboffice routed therebetween by way of a line in the first group of trunk lines

A call from the central office 698 which is to be extended to a subscriber substation in the suboffice 50 is routed therebetween by way of an idle line in the first group of lines and is initiated in the central office 698 by the seizure of a repeater therein associated with an idle line in the first group of trunk lines. For example, a call initiated in the central office 698 which is to be extended to the subscriber substation A in the suboffice 50, and which is routed therebetween by way of the trunk line 694, is initiated when the repeater in the central office seizes the trunk line 694 and causes a pulse of alternating current to be projected thereover, thereby to complete the previously traced circuit for energizing the ring-up relay R630. When energized over the above-traced circuit the ring-up relay R630 operates to complete, at RA631 and the front contact associated therewith, a circuit for energizing in multiple the relays R535 and R540, this circuit extending from ground, at RA631 and the front contact associated therewith, to the conductor C470, one branch of this path extending from the conductor C470 by way of the winding of R540 to battery, and the other branch of this path extending from the conductor C470 by way of RA463 50 and the back contact associated therewith, C469, RA554, RA531, and the winding of R535 to battery. Also, upon operating, the ring-up relay R630 interrupts, at RA631 and the back contact associated therewith, a circuit for energizing the relay R530, this circuit extending from ground, at RA631 and the back contact associated therewith, by way of C574, RA529, and the winding of R530 to battery. The relay R530, being of the slow-to-release type, does not restore immediately 55 this circuit is interrupted. Upon operating, the relay R540 completes, at RA541 and the front contact associated therewith, a path for short-circuiting the winding 601 of the transformer 600, this path extending from the lower terminal of the winding 601, by way of C580, RA541 and the front contact associated therewith, C466, and the winding 601 to the lower terminal thereof, and completes, at RA541 and the front contact associated therewith, a path for connecting the 60

75

winding 602 of the transformer 600 in series with the resistor 641 and across the line conductors C466 and C467, this path extending from the conductor C466 by way of RA541 and the front 5 contact associated therewith, the resistor 541, C581, the condenser 605, and the winding 602, to the conductor C467.

When energized over the above-traced circuit the relay R535 operates to complete, at RA538, 10 a path for short-circuiting the winding of the switching relay R550, this path extending from ground, at RA538, by way of the winding of R550, RA554, C469, RA463 and the back contact associated therewith, C470, and RA631 and 15 the front contact associated therewith, to ground. Also, upon operating, the relay R535 completes, at RA535, an obvious path for applying ground potential to the control conductor C323, and completes, at RA537, an obvious path 20 for short-circuiting the lower winding of the impedance element Z503. Further the relay R535 completes at RA536 a path for applying battery potential to the pulse lead C568, this path extending from battery at the winding of 25 the relay R525 by way of the winding of R525, RA527, RC528, RA536 and RA562 to the pulse lead C568. Further, the relay R535 completes, at RA539, an obvious path for applying ground potential to the timer start lead C535, thereby 30 to initiate operation of the timer associated with the repeater 400. At the conclusion of the pulse of alternating current projected over the trunk line 694 from the central office 698 the ring-up relay R630 restores to interrupt, at RA631 and 35 the front contact associated therewith, a point in the previously traced path for short-circuiting the winding of the switching relay R550, thereby to cause a circuit to be completed for energizing the relays R535 and R550 in series, 40 this circuit extending from ground, at RA538, by way of the winding of R550, RA531, and the winding of R535 to battery. When this series circuit is completed the relay R550 operates to 45 prepare, at RA551, at RA552, and at RA553, a circuit for energizing the upper winding of the relay R565 over a loop circuit extending to the line circuit 500, this circuit extending from the conductor C577 by way of RA553, C467, the winding 602 of the transformer 600, C584, the 50 upper winding of R565, C578, RA552, C579, RA630, C633, the winding 601 of the transformer 600, C466, and RA551 to the conductor C576, the conductors C577 and C576 of the trunk line 55 575 being subsequently connected by way of the line circuit 500 to the line conductors C171 and C172 of the control trunk 130. This circuit is completed when the control trunk is found by 60 the finder switch of an idle link, in a manner more fully described subsequently. Also, upon operating, the relay R550 completes, at RA557 and the front contact associated therewith, by way of C573, and the lower winding of R565 to battery 65 for energizing the lower winding of the relay R565. When the above-traced circuits for energizing the upper and lower windings of R565 are completed the relay R565 remains restored, as the upper and lower windings thereof are arranged in differential relation.

A relay in the line circuit 500 is energized in response to the connection of the trunk line 575 to the repeater 400, and operates to connect the line conductors C576 and C577 of the trunk line 70 75 575 to the line conductors C171 and C172 of the

control trunk 130, as previously noted. Also, this relay operates to apply battery potential to the control conductor C173, and ground potential to the control conductor C134 of the control trunk 130. The line conductors C171 and C172, and the control conductor C173 of the control trunk 130, are terminated in the contact banks of the Strowger mechanisms included in the finder switches of the links. In the illustrated link 60 these conductors of the control trunk 130 are terminated in the contact bank 102 of the Strowger mechanism included in the finder switch 101. Also, the control conductor C134 of the control trunk 130 is connected to the conductor C135 and by way of the resistor 195 to the start lead C137 extending to the distributor 700. This application of ground potential to the control conductor C134 causes ground potential to be applied by way of the above-traced path to the start lead C137, thereby to initiate operation of the distributor 700. The distributor 700 then operates to assign a previously selected idle link in the first group of links to the use of the calling control trunk 130, as previously described. Assuming that the illustrated link 60 is the link 25 in the first group of links assigned by the distributor 700 to the use of the calling control trunk 130, the finder switch 101 thereof operates to seize the control trunk 130 in the previously described manner, the level in the contact bank 102 of the Strowger mechanism included in the finder switch 101, in which the control trunk 130 is terminated, being marked by the presence of ground potential upon the control conductor C134, and the radial position 30 of the control trunk 130 in this level being marked by the presence of battery potential upon the control conductor C173. When the finder switch 101 operates to seize the control trunk 130, the associated connector switch 200 40 is conditioned to be responsive to a series of digits dialed thereinto, in the previously described manner. Also, when the control trunk 130 is seized by the finder switch 101 the line conductors C171 and C172 of the control trunk 45 130 are connected by way of the operated finder switch 101 to battery and ground potential in the connector switch 200 and a path including the upper and lower windings of the line relay R260. This path completes the previously mentioned circuit for energizing the upper winding of the relay R565 in the repeater 400. The line relay R260 then operates and causes the hold relay R265 to operate, which latter relay completes the previously traced path for applying 50 ground potential to the control conductor C123, thereby to retain the link 60 operated.

In the event the repeater 400 is falsely seized by way of the trunk line 694 extending from the central office 698, or the subscriber at the calling 60 substation connected to the trunk line 694 fails to continue the call by failing to dial the required number of digits into the connector switch 200 to cause it to seize the subscriber line 115, the timer associated with the repeater 400 operates 65 after a predetermined time interval to apply ground potential to the pulse ground lead C568. This application of ground potential to the pulse ground lead C568 completes a circuit for energizing the relay R525, this circuit extending 70 from the pulse ground lead C568 by way of RA562, RA536, RC528, RA527, and the winding of R525 to battery. When energized over the above-traced circuit the relay R525 operates to complete, at RA526 and RA527, a holding circuit for 75

energizing the winding thereof extending from the grounded control conductor C323 by way of RA561, RA526, RA527, and the winding of R525 to battery. Also, upon operating, the relay R525 5 interrupts, at RA527 and RC528, the previously traced original circuit for energizing the winding thereof, and completes, at RA525, a circuit for energizing the relay R515, this circuit extending from ground as applied to the pulse ground lead C568' by the timer after an additional time interval by way of RA525, C570, and the winding of R515 to battery. When energized over the above-traced circuit the relay R515 operates to interrupt, at RA516, the circuit for energizing the relay R530, a point in the multiple circuit for energizing the relay R530 being previously interrupted, at RA529, upon the operation of the relay R525, thereby to cause the relay R530 to restore shortly thereafter. Upon restoring, the relay R530 10 interrupts, at RA531, the circuit for energizing in series the relays R535 and R550, thereby to cause the latter relays to restore. Upon restoring, the relay R535 interrupts, at RA535, the path for applying ground potential to the control conductor C323, and upon restoring, the relay R550 interrupts, at RA551, RA552, and RA553, the previously traced loop circuit including the upper and lower windings of the line relay R260 in the connector switch 200 and the upper winding of the relay R565 in the repeater 400. When ground potential is removed 15 from the control conductor C323 the holding circuit for energizing the winding of the relay R525 is interrupted, thereby to cause the latter relay to restore. At this time all of the operated relays in the repeater 400 are restored and this repeater is completely released. When the previously mentioned loop circuit is interrupted the line relay R260 in the connector switch 200 20 restores to cause ground potential to be removed from the control conductor C123, thereby to cause the link 60 and the line circuit 500 to be released in the previously described manner.

Continuing now with the operation of the repeater 400 to cause the connector switch 200 of the link 60 to operate and seize the subscriber line 115, the subscriber at the calling substation associated with the central office 698 dials a first digit, thereby to cause a first series of alternating current impulses to be transmitted by way of the trunk line 694 to the repeater 400. Each time an alternating current impulse is transmitted by way of the trunk line 694 to the repeater 400, the ring-up relay R630 operates, and between the successive alternating current impulses the ring-up relay R630 restores. Each time the ring-up relay R630 operates it completes, at RA631 and the front contact associated therewith, the previously traced circuit for energizing the relay R540 and interrupts, at RA631 and the back contact associated therewith, the previously traced circuit for energizing the relay R530. Due to the fact that both the relays R530 and R540 are of the slow-to-release type, they remain 30 operated during impulsion. Upon operating, the relay R540 completes, at RA541' and at RA541 and the front contact associated therewith, a path for short-circuiting the windings 601 and 602 of the transformer 600, and for completing a metallic connection including the upper winding of the relay R565 between the line conductors C576 and C577 of the trunk line 575, this connection extending from the line conductor C576 by way of RA551, C466, RA541 and the front contact associated therewith, C580, C633, RA630,

C579, RA552, C578, RA541', C467, and RA553 to the line conductor C577. Also it is noted that this connection including the upper winding of the relay R565 between the line conductors C576 and C577 is interrupted, at RA630, each time 5 the ring-up relay R630 operates, and completed, at RA630, each time the ring-up relay R630 restores, thereby to cause a corresponding series of impulses to be transmitted by way of the control trunk C130 to the line relay R260 in the 10 connector switch 200 of the link 60.

The subscriber at the calling substation associated with the central office 698 dials successively the three digits corresponding to the directory number of the called subscriber substation A, thereby to cause the connector switch 200 to operate, in the previously described manner, and seize the subscriber line 115. Also, the connector switch 200 operates to cause ringing current to be projected over the subscriber line 115 in the 15 event this subscriber line is idle, which ringing current is characteristic to the substation A, thereby to indicate to the subscriber thereat that the substation A is the called substation. In the event the called subscriber line 115 is busy 20 the connector switch 200 operates to cause busy tone current to be returned by way of the control trunk C130, the repeater 400, and the trunk line 694, to the calling subscriber substation associated with the central office 698 in the usual 25 manner.

At the conclusion of the third digit dialed, the ring-up relay R630 restores and interrupts, at RA631 and the front contact associated therewith, the previously traced circuit for energizing the relay R540, which latter relay, being of the slow-to-release type, restores shortly thereafter. Upon restoring, the relay R540 30 interrupts, at RA541', and at RA541 and the front contact associated therewith, the previously traced path 35 for short-circuiting the windings 601 and 602 of the transformer 600 included in the repeater 400, and completes, at RA541 and the back contact associated therewith, the previously traced path for connecting the windings 601 and 602 of the 40 transformer 600 across the line conductors C576 at C577 of the trunk line 575 extending to the line circuit 500, thereby to complete an inductive connection at the transformer 600 between the control trunk C130, connected to the called sub- 45 50 55 60 65 70 75 80 85 90 95 100 105 110 115 120 125 130 135 140 145 150 155 160 165 170 175 180 185 190 195 200 205 210 215 220 225 230 235 240 245 250 ated at this time. This operation of the relay R560 positively causes the relay R525 to remain restored or to restore, thereby to arrest further operation of the timing apparatus. Also, upon 5 operating, the relay R560 completes, at RA563 and the front contact associated therewith, a circuit for energizing the relay R640, this circuit extending from ground at RA557 and the front contact associated therewith, by way of RA563 10 and the front contact associated therewith, C481, RA427 and the back contact associated therewith, C482, RA646, and the winding of R640 to battery. When energized over the above-traced circuit the relay R640 operates to complete, at 15 RA641, an obvious circuit for energizing the upper winding of the relay R670, and to complete, at RA643, an obvious circuit for energizing the lower winding of the impulse relay R680. When energized over the above-traced circuits the relays R670 and R680 operate to complete the previously traced circuit for projecting alternating current over the trunk line 694 extending to the repeater in the central office 698. Also, upon 20 operating, the relays R640 and R680 complete, at RA642 and at RA684, respectively, points in a circuit for energizing the relay R650, this circuit extending from ground, at RA684, by way of C585, RA642, and the winding of R650 to battery. When thus energized, the relay R650 operates to complete, at RA651, an obvious circuit for energizing the relay R645, which relay, being of the slow-to-operate type, operates shortly thereafter, and completes, at RA652, a circuit for energizing the relay R425, this circuit extending from ground, at RA557 and the front contact associated therewith, by way of C573, RA652, C471, RA418 and the back contact associated therewith, and the winding of R425 to battery. When energized over the above-traced 30 circuit the relay R425 operates to complete, at RA426, a path for short-circuiting the relay R410, this path extending from ground, at RA539, by way of C471, RA431, RA426, the winding of R410, and RA418 and the back contact associated therewith, to the grounded conductor C471. Upon operating, the relay R646 interrupts, at RA646, the previously traced circuit for energizing the relay R640, thereby to cause the latter relay, which is of the slow-to-release type, to 40 restore shortly thereafter. Upon restoring, the relay R640 interrupts, at RA641, at RA642, and at RA643, the previously traced circuits for energizing the upper winding of the relay R670, the winding of the relay R650, and the lower winding of the relay R680, thereby to cause these relays to restore. Upon restoring, the relays R670 and R680 interrupt the previously traced circuit for projecting alternating current over the trunk line 694 extending to the repeater in the central office 698. Also, upon restoring, the relay R670 completes, at RA672 and the back contact associated therewith, and at RA673 and the back contact associated therewith, the previously traced loop circuit between the windings 603 and 65 604 of the transformer 600 in the repeater 400 and the repeater in the central office 698. Upon restoring, the relay R650 interrupts, at RA652, the previously traced circuit for energizing the winding of the relay R425, and the previously traced path for short-circuiting the winding of the relay R410, thereby to cause a circuit for energizing in series the windings of the relays R410 and R425 to be completed, this circuit extending from ground, at RA539, by way of C471, 70 RA431, RA426, the winding of R410, and the

winding of R425 to battery. When thus energized the relay R410 operates to complete, at RA419, the previously traced circuit for energizing the relay R685, which latter relay operates to complete, at RA688, the previously traced holding circuit for energizing the winding thereof. Also, upon operating, the relay R685 completes, at RA686, the previously traced circuit for energizing the rotary magnet M612 of the minor switch 625 by way of the pulse ground lead C632, 10 and interrupts, at RA687, a point in the previously traced circuit for energizing the release magnet M613 of the minor switch 625.

The rotary magnet M612 of the minor switch 625 is intermittently energized, thereby to cause 15 the timing arrangement including the minor switch 625 to operate, as previously explained. After a predetermined time interval this arrangement operates to complete a circuit for projecting tick tone current over the loop circuits extending 20 to the repeater in the central office 698 and to the called subscriber substation A, this circuit extending from the ungrounded terminal of the source of tick tone current by way of the tick tone lead C648, the wiper 619 and the associated 25 ninth contact in the contact bank 620 of the rotary switch 618 in the minor switch 625, the condenser 607, C647, C467, RA553, and the line conductor C577 of the trunk line 575 extending to the line circuit 500, and therefrom by way 30 of the line conductor C172 of the control trunk 130, the operated Strowger mechanism included in the finder switch 101, C125, RA182, C122, RA212, C203, RA245, RC246, and the condenser 208 to the line conductor C292, and from the 35 line conductor C290 by way of the condenser 207, RA252, RA251, the lower winding of R260, RA272, RC273, and RA268 to ground, the line conductors C290 and C292 being connected together by way of the loop circuit extending to the called subscriber substation A. Also, a portion of this tick tone current is conducted from the tick tone lead C648 by way of a portion of the previously traced circuit to C467, and therefrom by way of the winding 602, the condenser 605, C581, RA541 and 40 the back contact associated therewith, C580, the winding 601, C466, RA551 and the line conductor C576 of the trunk line 575 extending to the line circuit 500, and therefrom by way of the line conductor C171 of the control trunk 130, the operated Strowger mechanism included in the finder switch 101, C124, RA181, C121, RA211, C202, RA242, RC243 and the condenser 207 to the line conductor C290, the line conductor being connected by way of a portion of the previously 55 traced circuit to ground at RA268. This tick tone current traversing the windings 601 and 602 of the transformer 600 induces a similar tick tone current in the windings 603 and 604 thereof included in the loop circuit extending to the repeater in the central office 698, thereby to cause tick tone current to be returned to the calling substation associated therewith.

The resultant tick tones produced by the receivers of the telephone instruments at the 65 calling and called subscriber substation indicate to the subscribers thereof that the established connection between the substation A and the substation associated with the central office 698 has been held a predetermined time interval. In the 70 event that this established connection is not released within a short time interval, the timing arrangement including the minor switch 625 operates after an additional time interval to complete in the rotary switch 615 the previously 75

traced circuit for energizing the relay R625. The latter relay then operates to complete the previously traced path for short-circuiting the windings 601 and 602 of the transformer 600, thereby to prevent further communication over the established connection.

The release of the established connection between the calling subscriber substation associated with the central office 698 and the called subscriber substation A is primarily under the control of the subscriber at the calling substation associated with the central office. However, a portion of the apparatus is released when the subscriber at the called substation A replaces the receiver of the telephone instrument thereat upon its hook, thereby to interrupt the circuit extending from the subscriber substation A to the battery reversing relay R250 in the connector switch 200, which causes battery to be reversed over the loop circuit extending by way of the control trunk 130 and the line circuit 500 to the repeater 400, and including the upper winding of the relay R565, and the windings 601 and 602 of the transformer 600. When battery is reversed over this loop circuit the windings of the relay R565 in the repeater 400 are energized in differential relation, thereby to cause this relay to restore and interrupt, at RA566, the circuit for energizing the relay R560. The relay R560 then restores to complete, at RA563 and the back contact associated therewith, a circuit for energizing the relay R640, this circuit extending from ground, at RA551 and the front contact associated therewith by way of C573, RA563 and the back contact associated therewith, C480, RA427 and the front contact associated therewith, C482, RA646, and the winding of R640 to battery. When energized over the above-traced circuit the relay R640 operates to complete, at RA641 and at RA643, respectively, the previously traced circuits for energizing the upper winding of the relay R670 and the lower winding of the impulse relay R680. When thus energized the relays R670 and R680 operate to complete the previously traced path for projecting alternating current over the trunk line 694 extending to the central office 698. Also, upon operating, the relay R680 completes, at RA684, the previously traced circuit for energizing the relay R650, thereby to cause operation thereof, upon operating, the relay R650 completes, at RA651, the circuit for energizing the relay R645, which latter relay then operates shortly thereafter to interrupt, at RA646, the circuit for energizing the relay R640. Also, upon operating, the relay R650 completes, at RA652, a circuit for energizing the upper winding of the relay R435, this circuit extending from ground, at RA551 and the front contact associated therewith by way of C573, RA652, C471, RA418 and the front contact associated therewith, RA437, and the upper winding of R435 to battery. Shortly thereafter the relay R640 restores to interrupt, at RA641, at RA642, and at RA643, the circuit for energizing the upper winding of the relay R670, the circuit for energizing the winding of the relay R650, and the circuit for energizing the lower winding of the relay R680, thereby to cause the relays R670, R650, and R680 to restore. Upon restoring, the relays R670 and R680 interrupt the path for projecting alternating current over the trunk line 694 extending to the central office 698. Upon restoring, the relay R650 interrupts, at RA651, the circuit for energizing the relay R645, thereby to cause the latter relay to restore.

Upon operating, the relay R435 completes, at RA438, a circuit for energizing the upper and lower windings thereof in series, this circuit extending from ground, at RA539, by way of C471, RA431, RA438, and the lower and upper windings of the relay R435 to battery. Also, upon operating, the relay R435 completes, at RA436, the previously traced circuit for energizing the relay R430, thereby to cause the latter relay to operate shortly thereafter. Upon operating, the relay R430 interrupts, at RA431, the previously traced circuits for energizing in series the upper and lower windings of the relay R435, and for energizing in series the windings of the relays R410 and R425, thereby to cause these relays to restore.

When the circuit for projecting alternating current over the trunk line 694 is completed, as previously noted, the subscriber at the calling substation associated with the central office is given release supervision. When the subscriber at the calling substation then replaces the receiver of the telephone instrument thereat upon its hook, the repeater in the central office 698 is released and causes a long release pulse of alternating current to be projected over the trunk line 694 to the repeater 400, thereby to cause the circuit for energizing the ring-up relay R630 to be completed. When thus energized the ring-up relay R630 operates to interrupt, at RA631 and the back contact associated therewith, the previously traced circuit for energizing the relay R530, the ring-up relay R630 being operated a sufficiently long interval of time to cause the relay R530 to restore. Upon restoring, the relay R530 interrupts, at RA531, the previously traced circuit for energizing in series the windings of the relays R535 and R550, thereby to cause the latter relays to restore. Upon restoring, the relay R535 interrupts, at RA535, the path for applying ground potential to the control conductor C323, thereby to interrupt the circuit for energizing the relay R430, in order to cause the latter relay to restore. Upon restoring, the relay R550 interrupts, at RA551, RA552, and RA553, the previously traced loop circuit extending by way of the line circuit 500 and the control trunk 130 between line relay R260 in the connector switch 200 and the windings 601 and 602 of the transformer 600 in the repeater 400. When this loop circuit is interrupted the line relay R260 restores to cause ground potential to be removed from the control conductors C123 and C173 of the control trunk 130. When ground potential is removed from the control conductor C123 the operated link 60 and the line circuit 100 associated with the subscriber line 115 are released, as previously explained. Also, when ground potential is removed from the control conductor C173 of the control trunk 130, the line circuit 500 is released, as previously noted. At this time the link 60 and the repeater 400 are completely released for further use, and the line circuit 100 is released, thereby to mark the subscriber line 115 as idle.

Conclusions

From the foregoing it is apparent that a telephone system comprising a number of interconnected automatic exchanges is provided, which includes improved switching links and improved alternating current repeaters each having incorporated therein a timing means. The timing means incorporated in the switching link is effective to cause warning current to be connected to an established connection between two of the subscriber lines terminating at the same ex-

- change a first predetermined time interval after the connection therebetween is set up by way of the link, and to cause the link to be released a second predetermined time interval after the connection therebetween is set up by way of the link. The timing means incorporated in the repeater is effective to cause warning current to be connected to an established communication connection between two of the subscriber lines respectively terminating in two of the exchanges a first predetermined time interval after the connection therebetween is set up, and to cause the communication connection to be blocked a second predetermined time interval after the connection therebetween is set up.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, first and second exchanges, a trunk line including a first portion extending to said first exchange and a second portion extending to said second exchange, means including two windings respectively connected to said portions of said trunk line and inductively coupled with respect to each other for establishing a two-way communication connection between said portions of said trunk line, means in each of said exchanges for routing a connection by way of said trunk line to the other of said exchanges, a control switch operative to short-circuit one of said windings, thereby to block the communication connection between said portions of said trunk line, and timing means for automatically operating said control switch a predetermined time interval after a connection is routed by way of said trunk line between said exchanges.

2. In a telephone system, first and second exchanges, a trunk line including a first portion extending to said first exchange and a second portion extending to said second exchange, means including two windings respectively connected to said portions of said trunk line and inductively coupled with respect to each other for establishing a two-way communication connection between said portions of said trunk line, means in each of said exchanges for routing a connection by way of said trunk line to the other of said exchanges, a source of warning current, means operative to connect said source of warning current to a connection routed by way of said trunk line between said exchanges, a control switch operative to short-circuit one of said windings, thereby to block the communication connection between said portions of said trunk line, a stepping switch having a normal position, a timer, control means governed by said timer for operating said stepping switch step by step away from said normal position, means responsive to the routing of a connection by way of said trunk line between said exchanges for rendering the operation of said stepping switch under the control of said control means, means controlled by the operation of said stepping switch a first predetermined number of steps away from said normal position for operating said control switch.

3. In a telephone system, first and second exchanges, a trunk line including a first portion extending to said first exchange and a second portion extending to said second exchange, means including a reactance element reactively coupled between said portions of said trunk line for establishing a two-way communication connection between said portions of said trunk line, means in each of said exchanges for routing a connection by way of said trunk line to the other of said exchanges, a control switch operative to change the reactive coupling of said reactance element between said portions of said trunk line, thereby to block the communication connection between said portions of said trunk line, and timing means for automatically operating said control switch a predetermined time interval after a connection is routed by way of said trunk line between said exchanges.

4. In a telephone system, first and second exchanges, a trunk line including a first portion extending to said first exchange and a second portion extending to said second exchange, means including a reactance element reactively coupled between said portions of said trunk line for establishing a two-way communication connection between said portions of said trunk line, means in each of said exchanges for routing a connection by way of said trunk line to the other of said exchanges, a source of warning current, a control switch operative to change the reactive coupling of said reactance element between said portions of said trunk line, thereby to block the communication connection between said portions of said trunk line, and timing means for connecting said source of warning current to a connection routed by way of said trunk line between said exchanges a first predetermined time interval after the connection is routed therebetween and for automatically operating said control switch a second predetermined time interval after the connection is routed therebetween.

5. In a telephone system, first and second exchanges, a trunk line including a first portion extending to said first exchange and a second portion extending to said second exchange, means including a reactance element reactively coupled between said portions of said trunk line for establishing a two-way communication connection between said portions of said trunk line, means in each of said exchanges for routing a connection by way of said trunk line to the other of said exchanges, a control switch operative to change the reactive coupling of said reactance element between said portions of said trunk line, thereby to block the communication connection between said portions of said trunk line, a stepping switch having a normal position, a timer, control means governed by said timer for operating said stepping switch step by step away from said normal position, means responsive to the routing of a connection by way of said trunk line between said exchanges for rendering the operation of said stepping switch under the control of said control means, and means controlled by the operation of said stepping switch a predetermined number of steps away from said normal position for operating said control switch.

6. In a telephone system, first and second exchanges, a trunk line including a first portion extending to said first exchange and a second portion extending to said second exchange, means including a reactance element reactively coupled between said portions of said trunk line for establishing a two-way communication connection

between said portions of said trunk line, means in each of said exchanges for routing a connection by way of said trunk line to the other of said exchanges, a source of warning current, means operative to connect said source of warning current to a connection routed by way of said trunk line between said exchanges, a control switch operative to change the reactive coupling of said reactance element between said portions of said 5 trunk line, a stepping switch having a normal position, a timer, control means governed by said timer for operating said stepping switch step by step away from said normal position, means responsive to the routing of a connection by way of 10 said trunk line between said exchanges for rendering the operation of said stepping switch under the control of said control means, means controlled by the operation of said stepping switch a first predetermined number of steps away from 15 said trunk line between said exchanges for rendering the operation of said stepping switch under the control of said control means, means controlled by the operation of said stepping switch a first predetermined number of steps away from 20 said normal position for operating said connecting means, and means controlled by the operation of said stepping switch a second predetermined number of steps away from said normal position for operating said control switch.

25 7. In a telephone system, first and second exchanges, a trunk line extending between said exchanges, an automatic switch in each of said exchanges having access to said trunk line, means including said automatic switches and said trunk 30 line for setting up a two-way communication connection between said exchanges, control means for operating and for releasing said switches, means operative to block a communication connection set up between said exchanges 35 without releasing said automatic switches, whereby said automatic switches may be released under the control of said control means, and timing means for automatically operating said blocking means a predetermined time interval after a communication connection is set up between said exchanges.

40 8. In a telephone system, first and second exchanges, a trunk line extending between said exchanges, an automatic switch in each of said exchanges having access to said trunk line, means including said automatic switches and said trunk line for setting up a two-way communication connection between said exchanges, control means for operating and for releasing said switches, a 45 source of warning current, means operative to block a communication connection set up between said exchanges without releasing said automatic switches, whereby said automatic switches may be released under the control of said control means, and timing means for connecting said source of warning current to a communication connection set up between said exchanges a first predetermined time interval after the connection is set up therebetween and for automatically operating said blocking means a second predetermined time interval after the connection is set up therebetween.

45 9. In a telephone system, first and second exchanges, a trunk line extending between said exchanges, an automatic switch in each of said exchanges having access to said trunk line, means including said automatic switches and said trunk line for setting up a two-way communication connection between said exchanges, control 50 means for operating and for releasing said switches, a source of warning current, means operative to connect said source of warning current to a communication connection set up between said exchanges, means operative to block a communication connection set up between said exchanges.

55 changes without releasing said automatic switches, whereby said automatic switches may be released under the control of said control means, a stepping switch having a normal position, a timer, control means governed by said timer for operating said stepping switch step by step away from said normal position, means responsive to the setting up of a communication connection between said exchanges for rendering the operation of said stepping switch under 60 the control of said last-mentioned control means, means controlled by the operation of said stepping switch a first predetermined number of steps away from said normal position for operating said connecting means, and means controlled by the operation of said stepping switch a second predetermined number of steps away from said normal position for operating said blocking means.

65 10. In a telephone system, first and second exchanges, a trunk line extending between said exchanges, an automatic switch in each of said exchanges having access to said trunk line, means including said automatic switches and said trunk line for setting up a two-way communication connection between said exchanges, a source of alternating current in each of said exchanges, means in each of said exchanges for transmitting alternating current impulses from the source of alternating current therein by way of said trunk line 70 to the other of said exchanges, control means in each of said exchanges and responsive to the alternating current impulses transmitted thereto from the other of said exchanges for controlling the operation and the release of the automatic switch therein, means operative to block a communication connection set up between said exchanges without releasing said automatic switches, whereby the automatic switch in at least one of said exchanges may be released under 75 the control of the control means therein, and timing means for automatically operating said blocking means a predetermined time interval after a communication connection is set up between said exchanges.

80 11. In a telephone system, first and second exchanges, a trunk line extending between said exchanges, an automatic switch in each of said exchanges having access to said trunk line, means including said automatic switches and said trunk line for setting up a two-way communication connection between said exchanges, a source of alternating current in each of said exchanges, means in each of said exchanges for transmitting alternating current impulses from the source of alternating current therein by way of said trunk line 85 to the other of said exchanges, control means in each of said exchanges and responsive to the alternating current impulses transmitted thereto from the other of said exchanges for controlling the operation and the release of the automatic switch therein, a source of warning current, means operative to connect said source of warning current to a communication connection set up between said exchanges, means operative to 90 block a communication connection set up between said exchanges without releasing said automatic switches, whereby the automatic switch in at least one of said exchanges may be released under the control of the control means therein, and timing means for operating said connecting means a first predetermined time interval after a communication connection is set up between said exchanges and for operating said blocking means a second 95

predetermined time interval after the communication is set up therebetween.

12. In a telephone system, first and second exchanges, subscriber lines terminating at each of said exchanges, a trunk line extending between said exchanges, an automatic switch in each of said exchanges having access to said subscriber lines terminating thereat and to said trunk line, means including said automatic switches and said trunk line for setting up a two-way communication connection between two of said subscriber lines respectively terminating at said exchanges, first control means in each of said exchanges for causing the automatic switch therein to seize a calling one of the subscriber lines terminating thereat, second control means in each of said exchanges for causing the automatic switch therein to seize said trunk line, a source of alternating current in each of said exchanges, means in each of said exchanges for transmitting alternating current impulses from the source of alternating current therein by way of said trunk line to the other of said exchanges, third control means in each of said exchanges and responsive to the alternating current impulses transmitted thereto from the other of said exchanges for causing the automatic switch therein to seize a called one of the subscriber lines terminating thereat, additional control means in each of said exchanges and responsive to alternating current impulses transmitted thereto from the other of said exchanges for causing the automatic switch therein to be released, means operative to block a communication connection set up between said exchanges without releasing said automatic switches, whereby the automatic switch in at least one of said exchanges may be released under the control of the additional control means therein, and timing means for automatically operating said blocking means a predetermined time interval after a communication connection is set up between said exchanges.

13. In a telephone system, first and second exchanges, subscriber lines terminating at each of said exchanges and having subscriber substations associated therewith, a trunk line extending between said exchanges, an automatic switch in each of said exchanges having access to said subscriber lines terminating thereat and to said trunk line, means including said automatic switches and said trunk line for setting up a two-way communication connection between two of the subscriber substations respectively associated with two of the subscriber lines respectively terminating at said exchanges, first control means in each of said exchanges for causing the automatic switch therein to seize a calling one of the subscriber lines terminating thereat, second control means in each of said exchanges for causing the automatic switch therein to seize said trunk line, a source of alternating current in each of said exchanges, means in each of said exchanges for transmitting alternating current impulses from the source of alternating current therein by way of said trunk line to the other of said exchanges, means at each of said subscriber substations for governing the second control means and for governing the transmitting means in the associated terminating exchange, third control means in each of said exchanges and responsive to the alternating current impulses transmitted thereto from the other of said

exchanges for causing the automatic switch therein to seize a called one of the subscriber lines terminating thereat, further control means in each of said exchanges operative to release the automatic switch therein, additional control means in each of said exchanges and responsive to alternating current release impulses transmitted thereto from the other of said exchanges for causing the automatic switch therein to be released, means responsive to the performance of a release function at each of said subscriber substations for operating the further control means in the associated terminating exchange and for causing the transmitting means in the associated terminating exchange to transmit alternating current release impulses from the source of alternating current therein by way of said trunk line to the distant exchange, means operative to block a communication connection set up between said exchanges without releasing said automatic switches, whereby the automatic switches may be released under the control of said further control means and said additional control means, and timing means for automatically operating said blocking means a predetermined time interval after a communication connection is set up between said exchanges.

14. In a telephone system, first and second exchanges, a trunk line extending between said exchanges, a line terminating at said second exchange, a repeater in said second exchange connected to said trunk line, a control trunk in said second exchange associated with said repeater, an automatic switch in said second exchange having access to said first-mentioned line and to said control trunk, means including said trunk line, said repeater, said control trunk and said automatic switch for setting up a two-way communication connection between said first exchange and said first-mentioned line, means responsive to received impulses projected over said trunk line to said second exchange for operating said repeater, first control means responsive to the operation of said repeater for causing said automatic switch to seize said control trunk, second control means governed by said repeater for causing said automatic switch to seize said first-mentioned line, thereby to extend a call from said first exchange to said first-mentioned line, a timer included in said repeater, means responsive to the operation of said repeater for initiating a timing operation of said timer, further control means governed by the completion of the timing operation of said timer for releasing said repeater, and means responsive to the answering of the call on said first-mentioned line for terminating the timing operation of said timer.

15. In a telephone system, first and second exchanges, a trunk line extending between said exchanges, a line terminating at said second exchange, a repeater in said second exchange connected to said trunk line, a control trunk in said second exchange associated with said repeater, an automatic switch in said second exchange having access to said first-mentioned line and to said control trunk, means including said trunk line, said repeater, said control trunk and said automatic switch for setting up a two-way communication connection between said first exchange and said first-mentioned line, means in said first exchange for seizing said trunk line, means responsive to the seizure of said trunk line for operating said repeater, first control means responsive to the operation of said repeater for causing said automatic switch to seize said control trunk, second control means governed by the completion of the timing operation of said timer for releasing said repeater, and means responsive to the answering of the call on said first-mentioned line for terminating the timing operation of said timer.

- trol trunk, second control means governed by said repeater for causing said automatic switch to seize said first-mentioned line, thereby to extend a call from said first exchange to said first-mentioned line, a timer included in said repeater, means responsive to the operation of said repeater for initiating a timing operation of said timer, further control means governed by the completion of the timing operation of said timer for releasing said repeater, and means responsive to the answering of the call on said first-mentioned line for terminating the timing operation of said timer.
16. In a telephone system, first and second exchanges, a trunk line extending between said exchanges, a line terminating at said second exchange, a repeater in said second exchange connected to said trunk line, a control trunk in said second exchange associated with said repeater, an automatic switch in said second exchange having access to said first-mentioned line and to said control trunk, means including said trunk line, said repeater, said control trunk and said automatic switch for setting up a two-way communication connection between said first exchange and said first-mentioned line, means in said first exchange for seizing said trunk line, means responsive to the seizure of said trunk line for operating said repeater, said repeater being operative to connect said control trunk to said trunk line, first control means responsive to the connection of said control trunk to said trunk line for causing said automatic switch to seize said control trunk, second control means governed by said repeater for causing said automatic switch to seize said first-mentioned line, thereby to extend a call from said first exchange to said first-mentioned line, a timer included in said repeater, means responsive to the operation of said repeater for initiating a timing operation of said timer, further control means governed by the completion of the timing operation of said timer for releasing said repeater, and means responsive to the answering of the call on said first-mentioned line for terminating the timing operation of said timer.
17. In a telephone system, first and second exchanges, a trunk line extending between said exchanges, a line terminating at said second exchange, a repeater in said second exchange connected to said trunk line, a control trunk in said second exchange associated with said repeater, an automatic switch in said second exchange having access to said first-mentioned line and to said control trunk, means including said trunk line, said repeater, said control trunk and said automatic switch for setting up a two-way communication connection between said first exchange and said first-mentioned line, a source of alternating current in said first exchange, means included in said first exchange for transmitting alternating current impulses from said source of alternating current therein by way of said trunk line to said repeater, first impulse responsive means included in said repeater for operating said repeater, said repeater being operative to connect said control trunk to said trunk line, first control means responsive to the connection of said control trunk to said trunk line for causing said automatic switch to seize said control trunk, second impulse responsive means for causing said automatic switch to seize said first-mentioned line, thereby to extend a call from said first exchange to said first-mentioned line, said first impulse responsive means being operative in response to alternating current impulses transmitted thereto by way of said trunk line to transmit automatic switch control impulses to said second impulse responsive means by way of said control trunk, a timer included in said repeater, means responsive to the operation of said repeater for initiating a timing operation of said timer, further control means governed by the completion of the timing operation of said timer for releasing said repeater, and means responsive to the answering of the call on said first-mentioned line for terminating the timing operation of said timer.
18. In a telephone system, first and second exchanges, a trunk line extending between said exchanges, a line terminating at said second exchange, a repeater in said second exchange connected to said trunk line, a control trunk in said second exchange associated with said repeater, an automatic switch in said second exchange having access to said first-mentioned line and to said control trunk, means including said trunk line, said repeater, said control trunk and said automatic switch for setting up a two-way communication connection between said first exchange and said first-mentioned line, means in said first exchange for seizing said trunk line, means responsive to the seizure of said trunk line for operating said repeater, first control means responsive to the operation of said repeater for causing said automatic switch to seize said control trunk, second control means governed by said repeater for causing said automatic switch to seize said first-mentioned line, thereby to extend a call from said first exchange to said first-mentioned line, third control means responsive to the release of said repeater for releasing said automatic switch, a timer included in said repeater, means responsive to the operation of said repeater for initiating a timing operation of said timer, further control means governed by the completion of the timing operation of said timer for releasing said repeater, additional control means for releasing said repeater, means responsive to the answering of the call on said first-mentioned line for terminating the timing operation of said timer, means operative to block a communication connection set up between said first exchange and said first-mentioned line without releasing said repeater, whereby said repeater may be released under the control of said additional control means, and timing means for automatically operating said blocking means a predetermined time interval after a communication connection is set up between said first exchange and said first-mentioned line.

EDWARD SIGFORD PETERSON.
